TELEGRAPH SWITCHING SYSTEM

Morris E. Griffins, Chicago, Ill., assignor to Associated Electric Laboratories, Inc., Chicago, Ill., a corporation of Delaware

Application February 17, 1939, Serial No. 256,909

46 Claims.

(Cl. 178—2)

The present invention relates to automatic telegraph systems and more particularly to telegraph switching systems wherein communication connections may be selectively established 5 between any of a number of printing stations associated with a number of different telegraph lines.

An automatic telegraph system conventionally comprises a number of telegraph lines of the 10 single conductor type connected to a source of current, each of the telegraph lines having a number of printing stations associated therewith. An automatic selector switch is individually connected in each telegraph line at each 15 station and has access to printing mechanism arranged in the station. Also dialing and transmitting mechanisms are arranged in each station whereby both dial and telegraphic impulses may be transmitted over each of the telegraph 20 lines at the station. Certain of the stations are associated with two or more of the telegraph lines and repeaters individually connected in the last-mentioned telegraph lines are arranged in the stations, which repeaters are accessible 25 to the selector switches in the stations, whereby a communication connection may be established between a particular telegraph line and another telegraph line by causing the selector switch connected in the particular telegraph line to 30 seize the repeater connected in the other telegraph line.

The selector switches connected in a given telegraph line are so connected and arranged 35 that they are operative to corresponding positions in response to series of dialed impulses transmitted over the given telegraph line, each selector switch comprising normally effective impulse responsive means for causing the selector switch to be selectively operated to a number of 40 different positions. Each selector switch is operative to one or more particular positions which particular positions comprise non-corresponding positions of the selector switches in the system. When a selector switch is operated to a particular 45 position it is switched through and seizes the printing line extending to the printing mechanism or the trunk line extending to the repeater in the associated station. In the event a printing line is seized by the selector switch, the printing mechanism associated therewith is rendered 50 operative in response to subsequent telegraphic impulses transmitted over the telegraph line associated with the selector switch; and in the event a trunk line is seized by the selector switch, the repeater associated therewith is rendered ef-

fective to repeat over the telegraph line connected thereto both dial and telegraphic impulses subsequently transmitted over the telegraph line associated with the selector switch. Also, upon switching through, the selector switch 5 transmits an answer-back signal over the telegraph line associated therewith. Furthermore, each selector switch comprises normally effective means responsive to the transmission of an answer-back signal thereto for causing the selector switch to be released, and means controlled by the switching through of the selector switch for rendering ineffective the last-mentioned means and the impulse responsive means in the selector switch. Moreover, a release device is connected in each telegraph line at each 10 station which is operative to transmit a release signal over the telegraph line; and each selector switch comprises means responsive to the transmission of a release signal thereto for causing 15 the selector switch to be released. Also each selector switch comprises automatic release means which is responsive to an incomplete operation of the selector switch, due to the transmission of an induction surge over the associated 20 telegraph line caused by lightning or the like, for causing the selector switch to operate and transmit a release signal over the associated 25 telegraph line, whereby each selector switch associated with the telegraph line is released. 30

In setting up a communication connection between two or more stations in a telegraph system of the character described, the operator in one of the stations first actuates the dialing mechanism thereat in order to transmit first 35 predetermined series of dial impulses over a given telegraph line, thereby to cause the selector switches associated with the given telegraph line to be operated to corresponding positions. This position of one of the selector switches 40 comprises a particular position thereof, thereby to cause the one selector switch to switch through and seize a printing line, trunk line, etc., over which dial or telegraphic impulses are to be transmitted. Upon switching through, the one 45 selector switch causes each of the other selector switches associated with the given telegraph line to be released. The operator then repeats the above-described operation one or more times, as desired, in order to cause the communication 50 connection to be extended to another telegraph line or to cause printing mechanisms in other of the stations to be operatively associated in the communication connection. After the communication connection has been set up, the op- 55

erator in the one station operates the transmitting mechanism, thereby to transmit telegraphic impulses over the communication connection whereupon the printing mechanisms associated with the printing lines included in the communication connection operate automatically to print the telegraphic message. The established connection may be released by the operator in the one station upon operating the release device thereat in order to transmit a release signal over the communication connection whereupon each of the selector switches, which is switched through and included in the communication connection, is released.

15 While reasonably satisfactory operation is obtained in a telegraph system of the type described, there are several objectionable features thereto. In the first place, each selector switch which has not been switched through and is included in an established communication connection tends to be operated by the telegraphic impulses transmitted over the communication connection. More particularly, at this time, the selector switch is released and the impulse responsive means therein is effective to respond to dial impulses, thereby to cause the selector switch to be operated. Although telegraphic impulses are considerably different from dial impulses and are not ordinarily effective to cause the selector switch to be operated, this difference resides only in the relatively high rate of the telegraphic impulses; and occasionally a telegraphic impulse is transmitted over the communication connection which is sufficiently similar to a dial impulse to cause the selector switch to be partially operated. Moreover, lightning surges and the like occasionally cause impulses to be transmitted over the communication connection which closely resemble dial impulses, thereby to cause the selector switch to be partially operated. When the selector switch is partially operated, the automatic release means therein responds to transmit a release signal over the communication connection which results in the automatic release of the established communication connection prior to the completion of the telegraphic message and against the will of the operator.

Accordingly, it is an object of the present invention to provide, in a telegraph system of the type described, an arrangement for rendering non-responsive to dial impulses each of the selector switches included in an established connection prior to the transmission of telegraphic impulses over the established communication connection.

55 Another object of the invention is to provide, in a telegraph system of the type described, a number of selector switches associated with the telegraph lines therein which are so connected and arranged that they are operative to corresponding positions, including switching and lock-out positions, in response to series of dial impulses, each of the selector switches being so connected and arranged that it is rendered non-responsive to further dial impulses when it is operated to a switching position or to a lock-out position.

60 A further object of the invention is to provide, in a telegraph system of the type described including two stations associated with a group of telegraph lines and another station associated with a given telegraph line, a selector switch of the trunk hunting type individually associated with the given telegraph line and having access to each telegraph line in the group, whereby a

6 communication connection may be routed between the other station and either one of the two stations by way of the given telegraph line and an idle one of the telegraph lines in the group.

65 A further object of the invention is to provide, in a telegraph system of the type described including first stations associated with a first group of telegraph lines and second stations associated with a second group of telegraph lines, selector 10 switches of the trunk hunting type individually associated with the telegraph lines in each of the groups, whereby a communication connection may be routed in either direction between either one of the first stations and either one of the 15 second stations by way of an idle telegraph line in the first group and an idle telegraph line in the second group.

20 A further object of the invention is to provide, in a telegraph system of the type described, an improved arrangement utilizing a selector switch associated with a loop circuit and a repeater for operatively associating with a telegraph line a printing mechanism accessible to the selector switch.

25 A further object of the invention is to provide, in a telegraph system of the type described, an improved arrangement utilizing a selector switch associated with a loop circuit and a repeater for operatively associating with a telegraph line another 30 telegraph line having a potential of a given polarity impressed thereupon and accessible to the selector switch.

35 The features of the present invention are illustrated as being incorporated in a telegraph system comprising first terminal stations associated with a first group of telegraph lines, second terminal stations associated with a second group of telegraph lines, a third terminal station associated with a third telegraph line, and a central 40 switching station commonly associated with each of the telegraph lines in the first and second groups and with the third telegraph line. Also one or more wayside stations may be associated with each of the telegraph lines. In each of the 45 terminal and wayside stations and in the central switching station there are provided dialing and transmitting mechanisms operative to transmit dial and telegraphic impulses, respectively, over any one of the telegraph lines at the station. 50 Also in each of the stations mentioned there is printing mechanism which is operative in response to telegraphic impulses transmitted thereto to print the telegraphic message, a group of printing mechanisms being provided in at least 55 the central switching station. In each of the stations a selector switch is individually associated with each telegraph line thereat, each selector switch having access to the printing mechanism at the station.

60 Each of the telegraph lines in the first and second groups is connected to a source of current and is normally arranged in a closed circuit; while the third telegraph line has a potential of a predetermined polarity impressed upon the 65 end thereof in the third terminal station and is normally arranged in an open circuit.

66 In accordance with one feature of the invention, the selector switches in the central switching station are arranged in first and second 70 groups, the selector switches in the first group being individually associated with corresponding ones of the telegraph lines in the first group, and the selector switches in the second group being individually associated with corresponding ones 75

of the telegraph lines in the second group. More particularly, each of the selector switches in the first group is provided with a control network connected in a loop circuit individually thereto, the loop circuit being normally connected to a local source of current and being operatively associated by way of a repeater individual thereto with the corresponding telegraph line in the first group. On the other hand, each of the selector switches in the second group is provided with a control network which is connected directly in the corresponding telegraph line in the second group. Also, there is provided in the central switching station a first group of trunk lines individually extending to corresponding ones of the selector switches in the first group and a second group of trunk lines individually extending to corresponding ones of the selector switches in the second group, each of the trunk lines in the first group being accessible to each of the selector switches in the second group, and each of the trunk lines in the second group being accessible to each of the selector switches in the first group.

Each of the selector switches in the first and second groups is of the trunk hunting type, each of the selector switches in the first group being operative in response to a predetermined operation thereof to select a trunk line in the second group extending to a selector switch in the second group associated with an idle telegraph line in the second group and each of the selector switches in the second group being operative in response to a predetermined operation thereof to select a trunk line in the first group extending to a selector switch in the first group associated with an idle telegraph line in the first group. Means is provided in each of the selector switches in the first group which is operative when the selector switch operates to seize the trunk line in the second group to disconnect the loop circuit from the local source of current and for causing the selector switch to switch through, thereby to connect the control network of the selector switch in series with the trunk line in the second group. Means is provided in each of the selector switches in the second group which is responsive to the seizure of the trunk line in the second group extending thereto for causing the selector switch to operate and connect the trunk line in series with the control network thereof, whereupon subsequent impulses transmitted over the control network of the previously-mentioned selector switch in the first group are also transmitted over the control network of the last-mentioned selector switch in the second group and over the corresponding telegraph line in the second group. Means is provided in each of the selector switches in the second group which is operative when the selector switch operates to seize the trunk line in the first group to cause the selector switch to switch through, thereby to connect the control network of the selector switch in series with the trunk line in the first group. Means is provided in each of the selector switches in the first group which is responsive to the seizure of the trunk line in the first group extending thereto for disconnecting the local source of current from the loop circuit associated with the selector switch and for causing the selector switch to operate and connect the trunk line in series with the control network thereof, whereupon subsequent impulses transmitted over the control network of the previously-mentioned selector switch in the second group are also transmitted over the control network of the last-mentioned selector switch in the first group.

group are also transmitted over the control network of the last-mentioned selector switch in the first group and over the corresponding telegraph line in the first group.

In accordance with another feature of the invention, each of the selector switches in the first and second groups is operative to select an idle printing mechanism in the group of printing mechanisms in the central switching station. More particularly, means is provided in each of the selector switches in the first group for causing the selector switch to operate as a trunk hunting selector switch and seize a printing line extending to an idle printing mechanism in the central switching station. Also means is provided in each of the selector switches in the first group which is responsive to the seizure of the idle printing line for causing the selector switch to switch through and connect the idle printing line in series with the control network thereof, whereby subsequent telegraphic impulses transmitted over the control network of the last-mentioned selector switch are transmitted over the seized printing line, thereby to cause the printing mechanism associated therewith to operate and print the telegraphic message. Also means is provided in each of the selector switches in the second group for causing the selector switch to operate as a trunk hunting selector switch and seize a printing line extending to an idle printing mechanism in the central switching station. Also means is provided in each of the selector switches in the second group which is responsive to the seizure of the idle printing line for causing the selector switch to switch through and connect the idle printing line in series with the control network thereof, whereby subsequent telegraphic impulses transmitted over the control network of the last-mentioned selector switch are transmitted over the seized printing line, thereby to cause the printing mechanism associated therewith to operate and print the telegraphic message.

At least one of the selector switches in each of the first and second groups is operative to select the third telegraph line. More particularly, means is provided in the one selector switch in the first group which is operative to cause the last-mentioned selector switch to seize the third telegraph line. Also means is provided in the last-mentioned selector switch and responsive to the seizure of the third telegraph line for disconnecting the local source of current from the loop circuit associated with the selector switch and for causing the selector switch to switch through, thereby to connect the control network thereof in series with the third telegraph line, whereupon subsequent impulses transmitted over the control network of the selector switch are transmitted over the third telegraph line. Means is provided in the one selector switch in the second group which is operative to cause the last-mentioned selector switch to seize a trunk line extending to a repeater individually associated with the third telegraph line. Also means is provided in the last-mentioned selector switch and responsive to the seizure of the trunk line extending to the last-mentioned repeater for causing the selector switch to switch through, thereby to connect the control network thereof in series with the last-mentioned trunk line, whereupon subsequent impulses transmitted over the control network of the selector switch are transmitted over the last-mentioned trunk line. Also it is noted that the impulses transmitted

over the last-mentioned trunk line are repeated by the last-mentioned repeater over the third telegraph line.

- Means is provided in each of certain ones of the selector switches in the first and second groups for positively preventing these selector switches from having access to the third telegraph line. More particularly, means is provided in each of the last-mentioned selector switches which is operative in response to the operation thereof to a given position corresponding to the third telegraph line for causing the selector switch to switch through and then automatically to be released.
- In accordance with another feature of the invention, the selector switches associated with a given telegraph line are so connected and arranged that they are operative to corresponding positions in response to series of impulses transmitted over the given telegraph line. Each of the selector switches is also operative to first and second particular positions, the first particular positions being non-corresponding positions of the selector switches and the second particular positions being corresponding positions of the selector switches. Means is provided in each of the selector switches which is responsive to the operation thereof to its first particular position for causing the selector switch to switch through and perform a given switching function to extend a connection; and means is provided in each of the selector switches which is responsive to the operation thereof to its second particular position for causing the selector switch to switch through without performing the given switching function. Normally effective impulse responsive means is provided in each of the selector switches to cause the selector switch to be selectively operated; and normally effective release means responsive to the transmission of an answer-back signal thereto is provided in each of the selector switches for causing the selector switch to be released. Means is provided in each of the selector switches which is controlled when the selector switch switches through for transmitting an answer-back signal over the control network thereof and for rendering ineffective the release means in the selector switch. Also means is provided in each of the selector switches which is operative in response to the seizure of a busy telegraph line, trunk line or printing line by the selector switch to cause a busy signal to be transmitted over the control network of the selector switch. Furthermore, timing means is incorporated in each of the selector switches which is responsive to an incomplete operation of the selector switch for causing a release signal to be transmitted over the control network of the selector switch. Also a release device is provided in each of the stations which is operative to transmit a release signal over any one of the telegraph lines thereat. Finally, means is provided in each of the selector switches which is responsive to the transmission of a release signal over the control network of the selector switch to render effective the release means in the selector switch, whereby the selector switch is released.

Further features of the invention pertain to the particular arrangement of the circuit elements thereof whereby the above-outlined and additional features are attained.

The novel features believed to be characteristic of the invention, both as to its organization and method of operation, together with further ob-

jects and advantages thereof, will best be understood by reference to the following specification taken in connection with the accompanying drawings, in which Figure 1 illustrates the general arrangement of a telegraph system embodying the present invention; Figs. 2 to 8, inclusive, taken together, illustrate the details of a system having incorporated therein the features of the system as briefly outlined above; and Fig. 9 illustrates the mode of combining Figs. 2 to 8, inclusive, to form a unified system.

Description of the apparatus incorporated in the telegraph system

Referring now more particularly to Fig. 1 of the drawings, the telegraph system there illustrated comprises two terminal stations N and S having a number of telegraph lines, including the telegraph lines 101 and 102, extending therebetween, two terminal stations E and W having a number of telegraph lines, including the telegraph lines 501 and 502, extending therebetween, a central switching station C commonly associated with the telegraph lines 101, 102, 501 and 502, and a terminal station X having a telegraph line 601 extending to the central switching station C. Also, a number of wayside stations, not shown, may be associated with each of the telegraph lines 101, 102, 501, 502 and 601. Preferably, each of the telegraph lines is of the single conductor type and the terminal end thereof has impressed thereon in the associated terminal stations a predetermined battery potential. More particularly, the terminal ends of the telegraph lines 101 and 102 terminating at the station N have positive battery potential impressed thereupon; the terminal ends of the telegraph lines 101 and 102 terminating at the station S have negative battery potential impressed thereupon; the terminal ends of the telegraph lines 501 and 502 terminating at the station W have negative battery potential impressed thereupon; the terminal ends of the telegraph lines 501 and 502 terminating at the station E have positive battery potential impressed thereupon; the terminal ends of the telegraph lines 501 and 502 terminating at the station X have positive battery potential impressed thereupon; and the terminal end of the telegraph line 601 terminating at the central switching station C is adapted to have negative battery potential impressed thereupon, the telegraph line 601 being included in a normally open circuit. A repeater included in the central switching station C is individually associated with each of the telegraph lines extending between the stations N and S, the repeater 100 being individually associated with the telegraph line 101 and the repeater 105 being individually associated with the telegraph line 102. Also a repeater 570 is individually associated with the telegraph line 601 for a purpose more fully explained subsequently.

A selector switch included in each of the terminal and wayside stations is individually associated with each of the telegraph lines extending thereto. Similarly, a selector switch included in the central switching station C is individually associated with each of the telegraph lines extending between the stations E and W, the selector switch 520 being individually associated with the telegraph line 502 extending therebetween, and the selector switch 700 being individually associated with the telegraph line 501 extending therebetween. Also, a selector switch included in the central switching

station C is individually associated with each of the repeaters individually associated with the telegraph lines extending between the stations N and S, the selector switch 300 being individually associated with the repeater 100 individually associated with the telegraph line 101, and the selector switch 510 being individually associated with the repeater 105 individually associated with the telegraph line 102. More particularly, the selector switch 300 is individually associated with the repeater 100 by way of a loop circuit 301 extending therebetween; and the selector switch 510 is individually associated with the repeater 105 by way of a loop circuit 510 extending therebetween.

Transmitting and printing mechanisms are included in each of the stations and are individually included in each of the telegraph lines extending thereto or are disassociated with the telegraph lines extending thereto, as desired. When the transmitting and printing mechanisms are disassociated with the telegraph lines extending to a station, the printing mechanisms are arranged to be selected by the selector switches at the station and the transmitting mechanisms are adapted to be inserted into any one of the telegraph lines extending thereto by means of jacks or the like in a well-known manner.

Referring now more particularly to Figs. 2 to 8, inclusive, of the drawings, it will be observed that a number of printing mechanisms, including the first, second and third printing mechanisms 490, 497 and 498, respectively, are arranged in the central switching station C, these printing mechanisms being disassociated with the telegraph lines extending thereto. Also, a number of unitary dial-transmitting-printing mechanisms, including the mechanism 160, are arranged in the central switching station C. It is noted that the printing mechanisms 490, 497 and 498 included in the central switching station C are so connected and arranged that they are individually accessible to the selector switches 300, 510, 520 and 700 at the central switching station C. More particularly, these printing mechanisms are so connected and arranged that the selector switches 300, 510, 520 and 700 are operative to select an idle one of these printing mechanisms when a predetermined series of digits is dialed into one of these selector switches, in a manner more fully described subsequently. Also, it is noted that a jack is arranged in each of the telegraph lines 101, 102, 501 and 502 extending to the central switching station C and that each of the dial-transmitting-printing mechanisms in the central switching station C is provided with a plug, whereby the dial-transmitting-printing mechanisms included in the central switching station C may be individually and selectively included in the telegraph lines extending thereto by selectively inserting the plugs into the jacks mentioned. More particularly, the jacks 103, 104, 503 and 504 are individually included in the telegraph lines 101, 102, 501 and 502, respectively; and the dial-transmitting-printing mechanism 160 is provided with a plug 105.

Preferably, the transmitting and printing mechanisms included in each of the terminal and wayside stations are provided with a dial mechanism and comprise a dial-transmitting-printing unit which is included directly in one of the telegraph lines extending thereto. Referring more particularly to Fig. 8, for example,

it will be observed that the dial-transmitting-printing mechanisms 810 and 830 included in the station S are arranged directly in the telegraph lines 101 and 102, respectively, extending thereto.

Each of the selector switches included in the central switching station C is so connected and arranged that it has access to each of the printing mechanisms 490, 497 and 498 included in the central switching station C and is operative to search this group of printing mechanisms for an idle printing mechanism therein, as previously noted. Also, the selector switches 300 and 510 individually associated with the repeaters 100 and 105, respectively, are so connected and arranged that they have access to each of the selector switches 520 and 700 individually associated with the telegraph lines 502 and 501, respectively, and are operative to search for an idle one of the two last-mentioned selectors. Similarly, each of the selector switches 520 and 700 individually associated with the telegraph lines 502 and 501, respectively, are so connected and arranged that they have access to each of the selector switches 300 and 510 individually associated with the repeaters 100 and 105 and are operative to search for an idle one of the two last-mentioned selector switches. Also, the selector switches 300 and 520 have access to the telegraph line 601; while each of the selector switches 510 and 700 is provided with an arrangement individual thereto for positively preventing the associated selector switch from having access to the telegraph line 601, in a manner more fully described subsequently. From the foregoing description of the connection and arrangement of the selector switches 300, 510, 520 and 700 included in the central switching station C, it will be understood that each of the telegraph lines 501 and 502 may be individually connected to either one of the telegraph lines 101 and 102; each of the telegraph lines 101 and 102 may be individually connected to either one of the telegraph lines 501 and 502; while only the telegraph lines 101 and 502 may be individually connected to the telegraph line 601. Also, it will be understood that each of the dial-transmitting-printing mechanisms included in the central switching station C may be individually connected directly into the telegraph lines 101, 102, 501 and 502 by way of the associated plugs and jacks previously mentioned; while each of the last-mentioned mechanisms may be individually connected to the telegraph line 601 by way of the telegraph line 502 and the selector switch 520 associated therewith or by way of the telegraph line 101, the repeater 100 individually associated with the telegraph line 101 and the selector switch 300 individually associated with the repeater 100, in a manner more fully described subsequently. Accordingly, each of the terminal stations N, S, E and W, each of the wayside stations associated with the telegraph lines 101, 102, 501 and 502, and the central switching station C may originate and receive telegraphic calls; while the terminal station X and the wayside stations associated with the telegraph line 601 may not originate telegraphic calls.

Each of the selector switches included in the terminal, wayside and central switching stations may be substantially identical to the selector switches 300 and 700 included in the central switching station C and illustrated in Figs. 3, 4, and 7, 6, respectively. The selector switch 300 comprises a Strowger switching mechanism 480 and a minor switch 390 comprising a portion 75

of a timing arrangement, described in detail hereinafter. The Strowger mechanism 480 includes a bank of fixed contacts arranged in ten vertical levels, each level including ten radially disposed contact sets, each contact set being adapted to terminate a telegraph or printing mechanism line extending thereto, and a wiper set, including the wipers 481, 482, 483 and 484, associated with the contact bank and carried by 10 a carriage movable in both vertical and radial directions. Also, the Strowger mechanism 480 includes a vertical magnet M387 for moving the carriage in the vertical direction, a rotary magnet M386 for moving the carriage in the radial direction, and a release magnet M385 for releasing the carriage and returning it to its normal position. Also associated with the Strowger mechanism 480 are a number of sets of switch springs S387, S386, S488, S485, S486 and S487 15 which are actuated by the various movements of the carriage thereof. More particularly, the sets of switch springs S387, S386 and S488 are actuated when the carriage of the Strowger mechanism 480 is moved vertically away from 20 its normal position; the set of switch springs S486 is actuated when the carriage is moved vertically to a predetermined level; and the sets of switch springs S485 and S487 are actuated when the carriage is moved vertically to a different predetermined level. The minor switch 390 includes a rotatable wiper 391 and an associated radially disposed contact bank 392 comprising a number of contacts adapted to terminate a group of control conductors for a purpose more fully described subsequently. Also, the minor switch 390 includes a rotary magnet M393 for rotating the wiper 391 across the associated contact bank 392 and a release magnet M394 for releasing the wiper 391 and returning 25 it to its normal position. Also, a set of switch springs S395 is associated with the minor switch 390 which is actuated by the movement of the wiper 391 away from its normal position.

Furthermore, the selector switch 300 comprises 45 a group of relays and their control and controlled circuits, this group of relays including a line relay R318, a hold relay R320, a test relay R450, a busy relay R450, a switch-through relay R470, and a number of control relays R338, R340, 50 R350, R360, R370, R380, R385, R400, R418, R428, R440 and R460. Also, it is noted that the selector switch 300 is so connected and arranged that it is adapted to operate as a trunk hunting switch to search for an idle line in a particular 55 group of lines and is individually associated with the repeater 100 by way of the loop circuit 301 including the conductors C302 and C303. Finally, it is noted that a supervisory lamp L388 is individually associated with the selector switch 300 60 for a purpose more fully described subsequently.

In general, the selector switch 700 is connected and arranged in a manner substantially identical to the selector switch 300 and comprises a Strowger switching mechanism 680 and a minor switch 65 700 comprising a portion of a timing arrangement, described in detail hereinafter. The Strowger mechanism 680 is identical to the Strowger mechanism 480 and comprises a wiper set, including the wipers 681, 682, 683 and 684, 70 and vertical, rotary and release magnets M751, M756 and M755, respectively, for controlling the movements of the carriage thereof, in the previously described manner. Also there are associated with the Strowger mechanism 680 a number of sets of switch springs S761, S736, S688,

S685, S686 and S687 corresponding to the sets of switch springs S387, S386, S488, S485, S486 and S487, respectively, which are actuated in a similar manner. The minor switch 700 comprises a rotatable wiper 701 and an associated 5 radially disposed contact bank 702 including a number of contacts adapted to terminate the control conductors C711, C712 and C713, for a purpose more fully described subsequently. Also, the minor switch 700 includes rotary and release 10 magnets M783 and M784, respectively, for controlling the movements of the wiper 701, in the previously described manner.

Furthermore, the selector switch 700 comprises a group of relays and their control and controlled 15 circuits, this group of relays including a line relay R710, a hold relay R720, a test relay R650, a busy relay R650, a switch-through relay R670 and a number of control relays R730, R740, R750, R760, R770, R780, R785, R800, R810, R820, R840 and 20 R860. Also, a supervisory lamp L788 is individually associated with the selector switch 700 for a purpose more fully described subsequently. Furthermore, the selector switch 700 is directly included in the telegraph line 501, as previously 25

Each of the printing mechanisms included at the central switching station C may be identical to the printing mechanism 480 which is preferably of the well-known Morkrum-Kleinschmidt 30 type. This printing mechanism includes a printing magnet M491, connected to the line conductors C581 and C582 of a printing line, and an operating motor 492. The operating motor 492 is included in a control circuit comprising a battery 35 493 and a contact RA495, the latter contact being controlled by a start relay R494 connected to the control conductor C583 of the printing line, the line conductors C581 and C582 and the control conductor C583 of the printing line being 40 terminated at corresponding contact sets in the contact banks of the Strowger mechanisms of the selector switches included in the central switching station C. Similarly, the conductors of the printing lines extending to the printing mechanisms 487 and 488 are terminated at corresponding 45 contact sets in the contact banks of the Strowger mechanisms of the last-mentioned selector switches. The contact sets mentioned in each of the contact banks of the Strowger mechanisms are arranged adjacent each other and in 50 corresponding positions in the contact banks in order to accommodate hunting by the selector switches for an idle printing line.

Each of the dial-transmitting-printing mechanisms included in the central switching station C 55 may be identical to the mechanism 160, which is of the Morkrum-Kleinschmidt type, and comprises a dial mechanism 161 including cooperating contact springs, a key switch 167, a transmitting mechanism 162, and a printing mechanism 163. Also, this mechanism comprises an operating motor 164 included in an operating circuit including a battery 165 and a manually operable switch 166. The dial mechanism 161, the key switch 167, the contacts of the transmitting mechanism 162 and the printing magnet PM163 are arranged in series 60 circuit relationship and connected to conductors terminated by the respective tip and ring of the 65 plug 165.

Each of the dial-transmitting-printing mechanisms included in each of the terminal and way-side stations may be identical to the mechanisms 810 and 830 included in the station S, the mechanism 810 being of the Morkrum-Kleinschmidt 70 75

type and including a dial mechanism 811, a key switch 814, a transmitting mechanism 812 and a printing mechanism provided with a printing magnet PM813 arranged in series circuit relationship and directly included in the telegraph line 101. Also, the mechanism 810 comprises an operating motor 828 arranged in two parallel operating circuits, one of the operating circuits including the motor 828, a battery 826 and a manually operable switch 825; and the other operating circuit including the motor 828, the battery 826 and the contact RA821 of a start relay R820. The start relay R820 is provided with an energizing circuit which, when completed, includes the wiper 15 801 of the selector switch 800. Also a supervisory lamp L827 is connected across the terminals of the motor 828 in order to provide an indication of the operating condition of this motor.

Similarly, the mechanism 830 includes a dial mechanism 831, a key switch 834, a transmitting mechanism 832, and a printing mechanism provided with a printing magnet PM833 arranged in series circuit relationship and directly included in the telegraph line 102. Also, the mechanism 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 N or S may be routed thereto by way of either one of the telegraph lines 101 or 102; however, a connection which is to be extended from the central switching station C to a particular wayside station associated with the telegraph lines 101 or 102 must be routed over the particular one of the telegraph lines 101 or 102 with which the wayside station is associated. For example, in order to extend a connection from the central switching station C to the terminal station S by way of the telegraph line 101 or to a wayside station associated with the telegraph line 101, the operator at the central switching station C first inserts the plug of one of the dial-transmitting printing mechanisms thereof into the jack 103 included in the telegraph line 101. For example, assuming that the plug 105 of the mechanism 160 is inserted into the jack 103, the original and normally completed circuit including the telegraph line 101 extending between the terminal stations N and S is interrupted and the circuit of the mechanism 160 is included in the above-traced circuit. The original circuit extending between the terminal stations N and S extends from the positive terminal of battery in the terminal station N by way of the telegraph line 101, the lower windings of the relays R110 and R120 in the repeater 100, RA111, the jack 103 and the dial-transmitting printing mechanism 160 to the negative terminal of battery in the selector switch 800 in the terminal station S by way of the previously traced circuit to the one switch spring of the jack 103 and from the negative terminal of battery in the selector switch 800 in the terminal station S by way of the previously traced circuit to the other switch spring of the jack 103, the switch springs of the jack 103 being connected together by way of a circuit including the tip of the plug 105, the contact springs of the dial mechanism 161, the key switch 167, the contact springs of the transmitting mechanism 162, the winding of the printing magnet PM163 and the ring of the plug 105 arranged in series circuit relationship. The operator at the central switching station C then operates the switch 166, thereby to complete the obvious circuit for operating the motor 164 of the mechanism 160, thereby to condition the mechanism 160 to transmit telegraphic impulses. The operator at the central station C then operates the key 167 in order to move the switch springs thereof into disengagement, thereby to interrupt the circuit including the telegraph line 101 extending between the terminal stations N and S in order to insure that all of the selector switches included in the stations associated with the telegraph line 101 initially occupy their normal positions. The key switch 167 is then operated, after a predetermined time interval, to move the switch springs thereof back into engagement at which time the apparatus associated with the telegraph line 101 is in condition to be responsive to a series of digits dialed at the dial mechanism 161. The operator at the central switching station C then operates the dial mechanism 161, thereby to cause the contact springs thereof to interrupt the circuit including the telegraph line 101 a predetermined number of times corresponding to the first digit dialed and to transmit a corresponding number of impulses over the telegraph line 101. This series 75

Extending connections from the station C to the stations N or S or wayside stations on the telegraph lines 101 or 102

A connection which is to be extended from the central switching station C to the terminal stations

of impulses transmitted over the telegraph line 101 causes each of the selector switches included in the stations associated with the telegraph line 101 to be operated. More particularly, the carriages of the Strowger mechanisms are operated in the vertical direction to the level corresponding to the first digit dialed. The operator at the central switching station C then operates the dial mechanism 161 to transmit a second series of digits over the telegraph line 101, thereby to cause the carriages of the Strowger mechanisms noted to be operated in the radial direction to the radial position of the contact set corresponding to the second digit dialed. At this time the wiper 801 carried by the carriage of the Strowger mechanism included in the selector switch 800 in the station S engages the contact terminating the conductor included in the circuit for energizing the start relay R820; and the wipers 804 and 806 engage the contacts terminating the shorting strap 805. On the other hand, the wipers carried by the carriages of the Strowger mechanisms of the selector switches included in the other stations associated with the telegraph line 101 engage corresponding contacts which terminate no conductor. Accordingly, only the selector switch 800 is further operated to switch through. Upon switching through, the selector switch 800 completes an obvious circuit for energizing the start relay R820, operates to return an answer-back signal over the telegraph line 101, and operates to connect the wipers 804 and 806 and the shorting strap in the series circuit including the telegraph line 101.

Also, it is noted that the two digits dialed at the mechanism 161 are repeated by way of the repeater 100 to the loop circuit 301 extending between the repeater 100 and the selector switch 300 individually associated therewith. The exact manner in which the repeater 100 operates to repeat the two digits from the telegraph line 101 to the loop circuit 301 will be described in detail hereinafter. These two digits repeated to the selector switch 300 cause this selector switch to be operated, thereby to cause the carriage of the Strowger mechanism 480 to be moved in the vertical and radial directions to a position corresponding to the positions of the carriages of the other selector switches, included in the other stations associated with the telegraph line 101. The exact manner in which the selector switch 300 is operated to move the carriage thereof in the vertical and radial directions is described in detail hereinafter.

When the selector switch 800 operates to return the answer-back signal over the telegraph line 101, the repeater 100 operates, in a manner to be described hereinafter, to repeat the answer-back signal to the loop circuit 301 extending between the repeater 100 and the selector switch 300. More particularly, the repeater causes the previously mentioned loop circuit to be interrupted for a predetermined time interval, thereby to cause the line relay R310 included in this loop circuit to restore. Upon restoring, the line relay R310 completes, at RA314, an obvious circuit for energizing the supervisory lamp L388, thereby to indicate to the operator at the central switching station C that the printing mechanism at the called terminal station S has been seized. Shortly thereafter the hold relay R320 in the selector switch 300 restores, thereby to cause a circuit, traced hereinafter, for energizing the release magnet M355 to be completed in order to cause the selector switch 300 to be released and

returned to its normal position. The exact manner in which the selector switch 300 is released is described in detail hereinafter.

Similarly, the selector switches included in each of the stations associated with the telegraph line 101 are released when the answer-back signal is transmitted over the telegraph line 101 by the selector switch 800. Shortly thereafter the selector switch 800 operates to terminate the return of the answer-back signal over the telegraph line 101 and to recomplete the circuit including the telegraph line 101 extending between the terminal stations S and N. When the return of the answer-back signal over the telegraph line 101 is terminated, the repeater 100 operates to recomplete the loop circuit 301 extending between the repeater 100 and the selector switch 300, thereby to cause the line relay R310 to reoperate. Upon reoperating, the line relay R310 interrupts, at RA314, the above-mentioned circuit for energizing the supervisory lamp L388, thereby to indicate to the operator at the central switching station C that the return of the answer-back signal over the telegraph line 101 has terminated.

The operator at the central switching station C then operates the dial mechanism 161, thereby to transmit two additional series of impulses over the telegraph line 101 which are repeated by the repeater 100 to the loop circuit 301 in the previously mentioned manner. These two series of impulses constitute the two digits of a lockout number and are effective to cause the selector switch 300 and each of the selector switches in the stations associated with the telegraph line 101 to be operated to a lockout position. The exact manner in which the selector switch 300 is operated to a lockout position is described in detail hereinafter. When the selector switches noted are operated to their lockout positions, they are rendered inoperative. Accordingly, the Strowger mechanisms therein do not follow the telegraphic impulses which are subsequently transmitted over the telegraph line 101.

When the previously mentioned circuit for energizing the start relay R820 is completed, the latter relay operates to complete the previously mentioned circuit for operating the motor 828 and for illuminating the supervisory lamp L827, respectively. Upon operating, the motor 828 renders the mechanism 810 in condition to receive and print telegraphic impulses transmitted thereto. The illumination of the supervisory lamp L827 indicates the operating condition of the operating motor 828 to the operator at the station S. Also, upon switching through, the selector switch 800 interrupts the path for applying negative battery potential to the telegraph line 101 incoming to the selector switch 800 and the path for applying positive battery potential to the line outgoing from the selector switch 800 to the mechanism 810 and completes a connection between the telegraph line 101 incoming thereto and the last-mentioned line outgoing therefrom. At this time the circuit extending from positive battery potential in the station N is extended by way of the selector switch 800, the dial mechanism 811, the key switch 814, the contact springs of the transmitting mechanism 812, the winding of the printing magnet PM813 and the selector switch 800 to the telegraph line 101 connected to the negative terminal of battery in the station S.

At this time an established connection is completed by way of the telegraph line 101 between the mechanism 160 in the central switching sta-

tion C and the mechanism 810 in the terminal station S; and the selector switches in the remainder of the stations associated with the telegraph line 101 and the selector switch 300 associated with the repeater 100 occupy locked out positions. Accordingly, only the mechanism 810 is adapted to follow the telegraphic impulses transmitted from the transmitting mechanism 162 included in the mechanism 160 in the central switching station C. The operator at the central switching station C then operates the transmitting mechanism 162, thereby to transmit telegraphic impulses over the circuit including the telegraph line 101; and the printing magnet 15 PM813 of the mechanism 810 included in the station S follows the telegraphic impulses transmitted thereto and operates the associated printer included in the mechanism 810 to print the telegraphic message.

As previously noted, the dialed impulses transmitted over the telegraph line 101 are repeated by the repeater 100 to the loop circuit 301 extending between the repeater 100 and the selector switch 300. The lower windings of the relays R110 and R120 are included in series circuit relationship with the telegraph line 101; and the lower windings of the relays R130 and R140 are included in series circuit relationship with the loop circuit 301, as previously noted. More specifically, the circuit including the telegraph line 101 extends from one portion of the telegraph line 101 by way of the lower winding of R110, the lower winding of R120 and RA111 to another portion of the telegraph line 101, positive and negative battery potentials appearing upon the respective portions of the telegraph line 101 as previously traced. The above-mentioned loop circuit 301 extends from the positive terminal of battery by way of the resistor 435, RC415, RA414, RA432, RA412, RC473, RA422, C310, the winding of the line relay R310, C303, RA411, the lower winding of R130, the lower winding of R140, C302, RA431, RA411, RA421, RA411, RC412 and the resistor 434 to the negative terminal of battery. Thus, the lower windings of the relays R110 and R120 are normally energized in series over the circuit including the telegraph line 101; and the lower windings of the relays R130 and R140 are normally energized in series over the loop circuit 301. The upper winding of the relay R110 is provided with a normally completed energizing circuit extending from the positive terminal of battery by way of the resistor 150, the upper winding of R110 and the resistor 151 to the negative terminal of battery. Also, a path is provided for short-circuiting the upper winding of the relay R110 which extends, when completed, from the positive terminal of battery by way of RA131, RC132, the upper winding of R110 and the resistor R150 to the positive terminal of battery. The upper winding of the relay R140 is provided with a normally completed energizing circuit extending from the positive terminal of battery by way of the resistor 157, the upper winding of R140 and the resistor 156 to the negative terminal of battery. Also, a path is provided for short-circuiting the upper winding of the relay R140 which extends, when completed, from the positive terminal of battery by way of RA121, RC122, the upper winding of R140 and the resistor 157 to the positive terminal of battery. The upper winding of the relay R120 is provided with an energizing circuit around which a short-circuiting path is normally completed, the energizing circuit extending, when completed, from the positive ter-

5 minal of battery by way of the resistor 152, the upper winding of R120 and the resistor 153 to the negative terminal of battery, and the normally completed short-circuiting path extending from the positive terminal of battery by way of RA121, 5 RC123 and the resistor 154 to the negative terminal of battery. The upper winding of the relay R130 is provided with an energizing circuit around which a short-circuiting path is normally completed, the energizing circuit extending, when completed, from the positive terminal of battery by way of the resistor 155, the upper winding of R130 and the resistor 154 to the negative terminal of battery, and the normally completed short-circuiting path extending from the positive terminal of battery by way of RA131, RC133 and the resistor 153 to the negative terminal of battery.

When the previously traced circuit including the telegraph line 101 is interrupted at the beginning of the first impulse transmitted thereto, the above-traced circuit for energizing in series the lower windings of the relays R110 and R120 is interrupted. The relay R110 remains in its operated position due to the fact that the previously traced circuit for energizing the upper winding thereof is retained completed, the upper winding of the relay R110 producing a magnetic flux predominating over that produced by the lower winding thereof, as previously noted. However, the relay R120 restores. Upon restoring, the relay R120 interrupts, at RA121 and RC123, a point in the previously traced path for short-circuiting the upper winding of the relay R130, thereby to cause the previously traced circuit for energizing the upper winding thereof to be completed. Also, upon restoring, the relay R120 completes, at RA121 and RC122, the previously traced path for short-circuiting the upper winding of the relay R140. When the upper winding of the relay R140 is short-circuited, the latter relay restores due to the fact that the upper winding thereof produces a magnetic flux which predominates over that produced by the lower winding thereof. Upon restoring, the relay R140 interrupts, at RA141, a point in the previously traced loop circuit, thereby to cause the circuit for energizing in series the lower windings of the relays R130 and R140 to be interrupted. It is noted that the relay R130 does not restore when the circuit for energizing the lower winding thereof is interrupted due to the fact that the previously traced circuit for energizing the upper winding thereof is completed when the relay R120 restores.

When the previously mentioned loop circuit 301 is interrupted, the line relay R310 restores. Upon restoring, the line relay R310 interrupts, at RA311 and RC312, an obvious circuit for energizing the hold relay R320. The latter relay, being of the slow-to-release type, does not immediately restore. Also, upon restoring, the line relay R310 completes, at RA311 and RC313, a circuit for energizing in series the control relay R330 and the vertical magnet M357, this circuit being prepared, at RA324 and RC325, due to the operated condition of the hold relay R320. The above-mentioned series circuit extends from the positive terminal of battery at RA311 by way of RC313, RA324, RC325, the switch springs S366 and S364 of the set of switch springs S367, the winding of R330 and the winding of M357 to the negative terminal of battery. When energized over the above-traced circuit, the relay R330 operates to prepare, at RA332 and RC333, an alternative circuit for energizing the winding thereof.

in series with the winding of the vertical magnet M357; and to complete, at RA341, a circuit for energizing the control relay R340, the latter circuit extending from the positive terminal of battery by way of RA331 and the winding of R340 to the negative terminal of battery. Also, when energized over the previously traced circuit, the vertical magnet M357 operates to move the carriage of the Strowger mechanism 488 one step in the vertical direction at which time the sets of switch springs S367, S368 and S488 are actuated. More particularly, the switch springs S364 and S366 and the switch springs S365 and S366 of the set of switch springs S367 are actuated into disengagement and into engagement, respectively. When the switch springs S364 and S366 are actuated into disengagement, the previously traced circuit for energizing in series the winding of the relay R338 and the winding of the vertical magnet M357 is interrupted; and when the switch springs S365 and S366 are actuated into engagement, the previously mentioned alternative circuit for energizing in series the winding of the relay R338 and the winding of the vertical magnet M357 is completed. The last-mentioned alternative circuit extends from the positive terminal of battery at RA311 by way of RC313, RA324, RC325, S366, S365, RA332, RC333, the winding of R338 and the winding of M357 to the negative terminal of battery. More particularly, the set of switch springs S366 are actuated into engagement, thereby to prepare a circuit, traced hereinafter, for energizing the release magnet M355; and the switch springs S488 are actuated into engagement, thereby to prepare a circuit, traced hereinafter, for energizing the lower winding of the switch-through relay R410.

Upon operating, the control relay R340 completes, at RA341, a holding circuit for energizing the winding thereof extending from the positive terminal of battery by way of RA341 and the winding of R340 to the negative terminal of battery. Also, upon operating, the control relay R340 completes, at RA342, a circuit for energizing the control relay R400, this circuit extending from the positive terminal of battery at RA342 by way of C314, RA411, RC419 and the winding of R400 to the negative terminal of battery. When energized over the above-traced circuit, the relay R400 operates to interrupt, at RA407 and RC409, a point in a circuit, traced hereinafter, for energizing the control relay R410; and to complete, at RA407 and RC408, a circuit for applying positive battery potential to the control conductor C538 of the trunk line 535 extending into the multiple 530, the latter path extending from the positive terminal of battery by way of RA342, C314, RA411, RC419, RC408 and RA407 to the control conductor C538. This application of positive battery potential marks, by way of the trunk line 535 and the multiple 530, the contacts in the contact banks of the Strowger mechanisms included in the selector switches 520 and 700 terminating the control conductor C538 with positive battery potential, thereby to mark the trunk line 535 and the selector switch 380 individually associated therewith as busy to the selector switches 520 and 700. Also, upon operating, the relay R340 interrupts, at RA343 and RC345, a circuit, traced hereinafter, for energizing the release magnet M355; and completes, at RA343 and RC344, a circuit for energizing the control relay R380. The last-mentioned circuit extends from the positive terminal of battery by way of RA321, RC323, RA371, RC373, RA343,

RC344, the winding of R380 and the resistor 388 to the negative terminal of battery, the control relay R370 being operated at this time. Shortly after the relay R380 is energized over the previously traced circuit, the latter relay, being of the slow-to-operate type, operates to initiate a timing operation, in a manner more fully described subsequently.

Also, upon operating, the relay R380 completes, at RA385, a circuit for energizing the control relay R370, this circuit extending from the positive terminal of battery by way of the set of switch springs S488, C316, RA385, C323 and the winding of R370 to the negative terminal of battery. Upon operating, the relay R370 completes, at RA375, a holding circuit for energizing the winding thereof, this circuit extending from the positive terminal of battery by way of the set of switch springs S488, RA425, RA424, RA462, C321, RA375 and the winding of R370 to the negative terminal of battery. Also, upon operating, the relay R370 prepares, at RA374, a point in a circuit, traced hereinafter, for energizing in series the rotary magnet M358 and the control relay R380.

Continuing now with the operation of the repeater 100, when the circuit including the telegraph line 101 is again completed at the end of the first impulse, the previously traced circuit for energizing in series the lower windings of the relays R110 and R120 is recompleted. When this series circuit is recompleted, the relay R110 is retained in its operated position and the relay R120 is operated. Upon operating, the relay R120 interrupts, at RA121 and RC122, the previously traced path for short-circuiting the upper winding of the relay R140, thereby to cause the previously traced circuit for energizing the upper winding of the relay R140 to be completed. When the upper winding of the relay R140 is then energized, this relay operates to complete, at RA141, the previously traced loop circuit 381, thereby to complete the previously traced series circuit for energizing the lower windings of the relays R140 and R130. When this series circuit is completed, the relays R130 and R140 are retained in their operated positions. Finally, upon operating, the relay R120 completes, at RA121 and RC123, the previously traced path for short-circuiting the upper winding of the relay R130, the relay R130 being retained in its operated condition at this time due to the completed circuit for energizing the lower winding thereof.

When the loop circuit 381 is recompleted, the previously traced circuit for energizing the line 51 relay R310 is recompleted, thereby to cause the latter relay to reoperate. Upon reoperating, the relay R310 completes, at RA311 and RC312, the previously mentioned circuit for energizing the hold relay R320; and interrupts, at RA311 and RC313, the previously traced alternative circuit for energizing in series the control relay R330 and the vertical magnet M357. It will be understood that the impulses comprising the first series of impulses are transmitted over the circuit including the telegraph line 101 at a relatively fast rate of between ten and fourteen impulses per second. Accordingly, the repeater 100 is repeatedly operated to cause the series of impulses to be repeated to the loop circuit 381 in the previously described manner. Thus, the line relay R310 follows the series of impulses comprising the first digit dialed, thereby to cause the control relays R320 and R330 to be alternatively and repeatedly energized. The last two mentioned

relays, being of the slow-to-release type, remain operated during the first series of impulses comprising the first digit dialed. At the conclusion of the first digit dialed, the wiper set of the Strowger mechanism 480 included in the selector switch 300 occupies a vertical position and is associated with a lever in the associated contact bank corresponding to the first digit dialed, and the line relay R310 is reoperated.

10 Also, shortly following the conclusion of the first digit dialed, the control relay RR330, being of the slow-to-release type, restores to prepare, at RA332 and RC334, the previously mentioned circuit for energizing in series the control relay

15 R360 and the rotary magnet M356.

At the beginning of the first impulse comprising the second digit dialed, the repeater 100 operates in the previously described manner in order to cause the series of impulses comprising the second digit to be repeated to the loop circuit 301, thereby to cause the line relay R310 to follow the series of im-

10 pulses comprising the second dialed digit. Each time the relay R310 operates, it completes, at RA311 and RC312, the previously mentioned circuit for energizing the hold relay R320 and in-

15 terrupts, at RA311 and RC313, the previously mentioned alternative circuit for energizing in series the control relay R360 and the rotary magnet M356; and each time the relay R310 re-

20 stores, it interrupts, at RA311 and RC312, the previously mentioned circuit for energizing the hold relay R320 and completes, at RA311 and RC313, the previously mentioned alternative cir-

25 cuit for energizing in series the control relay R360 and the rotary magnet M356. As pre- 30 viously noted, the line relay R310 operates and restores at a relatively fast rate, thereby to cause the hold relay R320 and the control relay R360

35 to be alternatively and repeatedly energized. The two last-mentioned relays, being of the slow-to- 35 release type, remain operated during the series of impulses comprising the second digit. Each time the rotary magnet M356 is energized, it operates to move the carriage of the Strowger mechanism 480 included in the selector switch

40 300 one step in the radial direction.

45 At the conclusion of the second digit dialed, the wiper set carried by the carriage of the Strowger mechanism 480 occupies a radial position corresponding to the second digit dialed.

50 Shortly following the conclusion of the second digit dialed, the control relay R360, being of the slow-to-release type, restores to interrupt, at RA362, a point in the alternative circuit for energizing the winding thereof in series with the winding of the rotary magnet M356, thereby to

55 prevent further operation of the rotary magnet M356 and consequently to arrest further movement of the carriage of the Strowger mechanism 480 in the radial direction. Also, upon restoring, the relay R360 interrupts, at RA361, the previously traced circuit for energizing the control relay R460.

60 As previously noted, in the present instance no conductor is terminated by the contact set engaged by the wiper set of the Strowger mechanism 480 when the previously mentioned two digits are dialed. Accordingly, the wiper 483 of the wiper set of the Strowger mechanism 480 engages a contact having no potential thereon. Hence, the test relay R450 is not operated and shortly after the control relay R360

65 restores to interrupt the previously traced circuit for energizing the control relay R460, the latter relay, being of the slow-to-release type, restores. No further operation of the selector switch 300 occurs at this time until the repeater 100 operates to repeat the answer-back signal transmitted over the circuit including the telegraph line 101 to the loop circuit 301.

70 When the selector switch 300 operates to transmit the answer-back signal over the circuit

75 RA461, a point in a circuit, traced hereinafter, for energizing the busy relay R430; prepares, at RA463 and RA464, a circuit, traced hereinafter, for energizing the test relay R450; interrupts, at RA464 and RC465, a holding circuit, traced here- 80 after, for energizing the winding of the test relay R450, and interrupts, at RA463 and RC466, a point in a circuit, traced hereinafter, for energizing the lower winding of the switch-through relay R470.

85 The repeater 100 operates in the previously de- scribed manner in order to cause the series of impulses comprising the second digit to be repeated to the loop circuit 301, thereby to cause the line relay R310 to follow the series of im-

90 pulses comprising the second dialed digit. Each time the relay R310 operates, it completes, at RA311 and RC312, the previously mentioned circuit for energizing the hold relay R320 and in-

95 terrupts, at RA311 and RC313, the previously mentioned alternative circuit for energizing in series the control relay R360 and the rotary magnet M356; and each time the relay R310 re-

100 stores, it interrupts, at RA311 and RC312, the previously mentioned circuit for energizing the hold relay R320 and completes, at RA311 and RC313, the previously mentioned alternative cir-

105 cuit for energizing in series the control relay R360 and the rotary magnet M356. As pre- 110 viously noted, the line relay R310 operates and restores at a relatively fast rate, thereby to cause the hold relay R320 and the control relay R360

115 to be alternatively and repeatedly energized. The two last-mentioned relays, being of the slow-to- 115 release type, remain operated during the series of impulses comprising the second digit. Each time the rotary magnet M356 is energized, it operates to move the carriage of the Strowger mechanism 480 included in the selector switch

120 300 one step in the radial direction.

125 At the conclusion of the second digit dialed, the wiper set carried by the carriage of the Strowger mechanism 480 occupies a radial position corresponding to the second digit dialed.

130 Shortly following the conclusion of the second digit dialed, the control relay R360, being of the slow-to-release type, restores to interrupt, at RA362, a point in the alternative circuit for energizing the winding thereof in series with the winding of the rotary magnet M356, thereby to

135 prevent further operation of the rotary magnet M356 and consequently to arrest further movement of the carriage of the Strowger mechanism 480 in the radial direction. Also, upon restoring, the relay R360 interrupts, at RA361, the previously traced circuit for energizing the control relay R460.

140 As previously noted, in the present instance no conductor is terminated by the contact set engaged by the wiper set of the Strowger mechanism 480 when the previously mentioned two digits are dialed. Accordingly, the wiper 483 of the wiper set of the Strowger mechanism 480 engages a contact having no potential thereon. Hence, the test relay R450 is not operated and shortly after the control relay R360

145 restores to interrupt the previously traced circuit for energizing the control relay R460, the latter relay, being of the slow-to-release type, restores. No further operation of the selector switch 300 occurs at this time until the repeater 100 operates to repeat the answer-back signal transmitted over the circuit including the telegraph line 101 to the loop circuit 301.

150 When the selector switch 300 operates to transmit the answer-back signal over the circuit

including the telegraph line 181, the repeater 188 operates, in the previously described manner, to interrupt the loop circuit 381 and to retain this loop circuit interrupted for a predetermined time 5 interval, thereby to cause the line relay R310 to restore and cause the hold relay R320 to restore. Upon restoring, the hold relay R320 completes, at RA324 and RC326, a circuit for energizing the release magnet M355, this circuit extending from 10 the positive terminal of battery by way of RA311, RC313, RA324, RC326, C317, RA479, C318, the set of switch springs S336 and the winding of M355 to the negative terminal of battery. When energized over the above-traced circuit, the release 15 magnet M355 operates to complete, at MA355, a holding circuit for energizing the winding thereof, this holding circuit extending from the positive terminal of battery by way of MA355, the set of switch springs S336 and the winding of 20 M355 to the negative terminal of battery. Also, upon operating, the release magnet M355 releases the carriage of the Strowger mechanism 480 included in the selector switch 380, thereby to cause the carriage to return to its normal position. When the carriage of the Strowger mechanism 480 included in the selector switch 380 is returned to its normal position, the sets of switch springs S488 and S336 are actuated into disengagement; while the switch springs S365 and 25 S366 and the switch springs S364 and S366 of the set of switch springs S367 are actuated respectively into disengagement and engagement. When the set of switch spring S488 is actuated into disengagement, a further point in the circuit for energizing the lower winding of the switch-through relay R470 is interrupted; when the set of switch springs S336 is actuated into disengagement, the previously traced holding circuit for energizing the winding of the release magnet M355 is interrupted, 30 thereby to cause the release magnet M355 to restore and interrupt, at MA355, a further point in the previously traced holding circuit for energizing the winding thereof; when the switch springs S365 and S366 of the set of switch 35 springs S367 are actuated into disengagement, a further point in the circuit for energizing in series the control relay R360 and the rotary magnet M356 is interrupted; and when the switch springs S364 and S366 of the set of switch 40 springs S367 are actuated into engagement, a point in the previously traced circuit for energizing in series the control relay R330 and the vertical magnet M357 is prepared. Also, upon restoring, the hold relay R320 45 interrupts, at RA321 and RC323, a further point in the previously traced circuit for energizing the release magnet M394 and completes, at RA321 and RC322, an alternative circuit for energizing the control relay R380, this circuit extending from 50 the positive terminal of battery by way of RA321, RC322, RA343, RC344, the winding of R380 and the resistor 388 to the negative terminal of battery. When energized over the above-traced circuit, the relay R380 operates shortly thereafter, 55 this relay being of the slow-to-operate type, to initiate the previously mentioned timing operation. More particularly, the control relay R380 60 interrupts, at RA381 and RC384, a point in the previously mentioned circuit for energizing the rotary magnet M393; interrupts, at RC382 and RC383, an obvious path for short-circuiting the winding of the control relay R385; and completes, at RA381 and RC382, an obvious circuit for energizing the winding of the control relay R385, 65 thereby to cause the latter relay to operate shortly 70 75

thereafter, the latter relay being of the slow-to-operate type. Upon operating, the control relay R385 prepares, at RA387, a point in the previously mentioned circuit for energizing the rotary magnet M393 and completes, at RA388, a path 5 for short-circuiting the winding of the control relay R388, this path extending from the positive terminal of battery at RA388 by way of the winding of R388, RC344, RA343, RC322 and RA321 to the positive terminal of battery. When this 10 short-circuiting path is completed, the relay R380 restores to interrupt, at RA381 and RC382, the previously mentioned circuit for energizing the winding of the control relay R385; to complete, at RC382 and RC383, the previously mentioned path for short-circuiting the winding of the relay R385; and to complete, at RA381 and RC384, the previously mentioned circuit for energizing the rotary magnet M393. The latter circuit 15 extends from the positive terminal of battery by way of RA381, RC384, RA387 and the winding of M393 to the negative terminal of battery. When energized over the above-traced circuit, the rotary magnet M393 operates to drive the wiper 391 of the minor switch 380 away from its normal position one step in the clockwise direction. When the wiper 391 of the minor switch 380 is moved away from its normal position, the switch springs S395 are actuated into engagement, thereby to prepare the previously traced circuit for 20 energizing the release magnet M384. When the previously mentioned path for short-circuiting the winding of the relay R385 is completed, the latter relay restores to interrupt, at RA386, the previously traced path for short-circuiting the 25 winding of the relay R380 and to interrupt, at RA387, a point in the previously traced circuit for energizing the rotary magnet M393. When the previously traced path for short-circuiting the winding of the relay R380 is interrupted, the latter relay reoperates to recomplete, at RA381 and RC382, the previously mentioned circuit for energizing the relay R385, thereby to cause the latter relay to reoperate shortly thereafter. The control relays R380 and R385 interact, in the 30 above-described manner, in order to cause the rotary magnet M393 to be repeatedly energized. When the wiper 391 of the minor switch 380 is rotated into engagement with the contact in the associated contact bank 392 terminating the control conductor C312, a circuit is completed for energizing the control relay R420, this circuit extending from the positive terminal of battery by way of RA341, C322, the wiper 391, the contact in the associated contact bank 392 terminating the control conductor C312, C312 and the winding of R420 to the negative terminal of battery. When energized over the previously traced circuit, the relay R420 operates to complete, at RA423, 35 a holding circuit for energizing the winding thereof, this circuit extending from the positive terminal of battery by way of RA342, C314, RA423 and the winding of R420 to the negative terminal of battery. Also, upon operating, the relay R420 40 interrupts, at RA421 and at RA422, additional points in the loop circuit 381. When the wiper 391 of the rotary switch 380 is driven into engagement with the contact in the associated contact bank terminating the control conductor C313, a path is completed for short-circuiting the winding of the control relay R340, this path extending from one terminal of the winding of R340 by way of C322, the wiper 391 and contact in the associated contact bank terminating the control conductor C313 and C313 to the other terminal of the winding of R340. When the previously 45 50 55 60 65 70 75

2,911,927
the latter relay to operate and initiate the timing operation, as previously explained. At the beginning of the first impulse of the second series of impulses comprising the second digit of the lockout number, the control relay R360 operates in order to cause the control relay R460 to operate, in the previously described manner. Upon operating, the control relay R460 interrupts, at RA462, the previously traced holding circuit for energizing the control relay R310, thereby to cause the latter relay to restore and complete, at RA371 and RC372, the previously traced circuit for energizing the release magnet M394, thereby to cause the wiper 391 of the minor switch 390 to be restored to its normal position in the previously described manner. It is noted that the minor switch 390 is released before the wiper 391 thereof engages the contact in the associated contact bank terminating the control conductor C313. Accordingly, the control relay R340 is retained in its operated position at this time.

When the selector switch 800 operates to terminate the return of the answer-back signal over the circuit including the telegraph line 101, the repeater 100 operates to recomplete the loop circuit 301, thereby to cause the line relay R310 to reoperate. Upon operating, the line relay R310 completes, at RA311 and RC312, the previously mentioned circuit for energizing the hold relay R320, which latter relay operates to complete, at RA321 and RC323, the previously mentioned circuit for energizing the release magnet M394, this circuit extending from the positive terminal of battery by way of RA321, RC323, RA371, RC372, the set of switch springs S395 and the winding of M394 to the negative terminal of battery. When energized over the above-traced circuit, the release magnet M394 operates to release the wiper 391 of the minor switch 390 and to cause this wiper to be returned to its normal position. At this time the selector switch 300 is completely released.

When the operator at the central switching station C dials at the dial mechanism 161 of the mechanism 160 included in the central switching station C the two predetermined digits comprising the lockout number, the two corresponding series of impulses transmitted over the circuit including the telegraph line 101 are repeated by the repeater 100 to the loop circuit 301, thereby to cause the selector switch 300 to be operated in order to cause the carriage of the Strowger mechanism 480 therein to be moved to the vertical and radial positions corresponding to the lockout positions. The apparatus in the selector switch 300 operates in response to these two successive digits in the previously described manner. At this time the wiper set including the wipers 481, 482, 483 and 484 of the Strowger mechanism 480 engage in the associated contact bank the contact set comprising the lockout position. More particularly, the wipers 481 and 482 engage the contacts in the associated contact bank terminating the shorting strap 402 and the wiper 483 engages the contact associated with the resistor 401 which is connected to the negative terminal of battery.

At the beginning of the first series of impulses comprising the first digit of the lockout number, the control relay R330 operates in order to cause the control relays R340 and R370 to operate in the previously described manner. Upon operating, the control relays R340 and R370 complete the previously traced circuit for energizing the control relay R380 in order to cause the latter relay to operate and initiate the timing operation, as previously explained. At the beginning of the first impulse of the second series of impulses comprising the second digit of the lockout number, the control relay R360 operates in order to cause the control relay R460 to operate, in the previously described manner. Upon operating, the control relay R460 interrupts, at RA462, the previously traced holding circuit for energizing the control relay R310, thereby to cause the latter relay to restore and complete, at RA371 and RC372, the previously traced circuit for energizing the release magnet M394, thereby to cause the wiper 391 of the minor switch 390 to be restored to its normal position in the previously described manner. It is noted that the minor switch 390 is released before the wiper 391 thereof engages the contact in the associated contact bank terminating the control conductor C313. Accordingly, the control relay R340 is retained in its operated position at this time.

When the wiper 483 engages the previously mentioned contact, a path is completed for short-circuiting the winding of the test relay R450, this path extending from the negative terminal of battery by way of the resistor 401, the contact engaged by the associated wiper 483, the wiper 483, RA463, RA464, RA476 and the winding of R450 to the negative terminal of battery. Short- 30 following the conclusion of the second digit dialed, the control relay R460 restores, as previously noted. Upon restoring, the relay R460 interrupts, at RA463 and RA464, a point in the previously traced path for short-circuiting the 35 winding of the test relay R450 and completes, at RA463 and RC466, a point in the previously mentioned circuit for energizing the lower winding of the switch-through relay R470, the latter circuit extending from the negative terminal of battery by way of the resistor 401, the contact in the contact bank engaged by the associated wiper 483, the wiper 483, RA463, RC466, the lower winding of R470, RC453, RA451, RA425 and the set of switch springs S488 to the positive terminal 45 of battery. When energized over the above-traced circuit, the switch-through relay R470 partially operates to close the "X" contacts associated with the armature RA470, thereby to complete a holding circuit for energizing the 50 upper winding thereof, this circuit extending from the positive potential of battery by way of the set of switch springs S488, RA425, RA424, RA470 and the upper winding of R470 to the negative terminal of battery. When the above-traced holding circuit is completed, the relay 55 R470 fully operates to complete, at RA477, a path for short-circuiting the lower winding thereof, this path extending from the positive terminal of battery by way of RA477, RA463, RC466, the lower winding of R470, RC453, RA451, RA425 and the set of switch springs S488 to the positive terminal of battery. Also, at RA477, the relay 60 R470 completes an obvious path for applying positive battery potential to the wiper 483 for a 65 purpose described subsequently. Also, upon operating, the switch-through relay R470 interrupts, at RA471 and at RA472 and RC473, points in the loop circuit 301, thereby to cause the line relay R310 to restore and cause the hold relay 70 R320 to restore shortly thereafter, as previously explained. Upon restoring, the hold relay R320 completes, at RA321 and RC322, the previously traced alternative circuit for energizing the control relay R380, thereby to cause the latter relay 75

to operate and initiate the timing operation. Also, upon operating, the switch-through relay R478 prepares, at RA478, a point in a circuit traced hereinafter for energizing the control relay R440, which latter circuit is completed when the wiper 381 of the minor switch 380 is driven into engagement with the contact in the associated contact bank 392 terminating the control conductor C311, this circuit extending from the positive terminal of battery by way of RA481, C322, the wiper 381, the contact in the associated contact bank terminating the control conductor C311, C311, RA478, and the winding of R440 to the negative terminal of battery. Also, upon operating, the switch-through relay R478 interrupts, at RA478, a point in an alternative circuit, traced hereinafter, for energizing the release magnet M355 and prepares, at RA472 and RC474, a path, traced hereinafter, for including the shorting strap 402 in the loop circuit 301.

When energized over the above-traced circuit, the control relay R440 operates to complete, at RA443, a holding circuit for energizing the winding thereof, this circuit extending from the positive terminal of battery by way of the set of switch springs S488, RA425, RA424, RA443, RA475 and the winding of R440 to the negative terminal of battery. Also, the relay R440 completes, at RA441 and at RA442, points in the previously mentioned path for including the shorting strap 402 in the loop circuit 301. The loop circuit 301 extends, at this time, from the positive terminal of battery by way of the resistor 435, RC415, RA414, RA432, RA472, RC474, the wiper 481, the contact in the associated contact bank terminating one end of the shorting strap 402, the shorting strap 402, the contact in the contact bank terminating the other end of the shorting strap 402, the associated wiper 482, RA442, RA422, C310, the winding of the line relay R310, C303, RA414, the lower windings of the relays R130 and R140, C302, RA441, RA421, RA411, RC412, and the resistor 434 to the negative terminal of battery. Finally, upon operating, the relay R440 completes, at RA445, a circuit for illuminating dimly the supervisor lamp L388 subsequent to the reoperation of the line relay R310. This circuit extends from the positive terminal of battery by way of RA445, C318, the resistor 389 and the lamp L388 to the negative terminal of battery. When the supervisory lamp L388 is dimly illuminated, the operator at the central switching station C is given an indication that the selector switch 300 and consequently the telegraph line 101 are busy.

When the loop circuit 301 is thus recompleted, the line relay R310 reoperates, thereby to complete, at RA311 and RC312, the previously mentioned circuit for energizing the hold relay R320 in order to cause the latter relay to reoperate and to interrupt, at RA314, the previously mentioned circuit for illuminating the supervisory lamp L388, whereby the lamp L388 is dimly illuminated over the previously traced circuit completed at RA445, upon the operation of the relay R440. Upon reoperating, the hold relay R320 interrupts, at RA321 and RC322, the previously traced alternative circuit for energizing the control relay R380, thereby to cause the latter relay to restore and arrest the timing operation. Also, upon reoperating, the hold relay R320 completes, at RA321 and RC323, the previously traced circuit for energizing the release magnet M394, thereby to cause the release magnet

to operate. Upon operating, the release magnet M394 releases the wiper 381 of the minor switch 380 and causes the wiper 381 to be returned to its normal position. When the wiper 381 of the minor switch 380 is returned to its normal position, the set of switch springs S385 is actuated into disengagement, thereby to interrupt the previously traced circuit for energizing the release magnet M394. Also, it is noted that the wiper 381 of the minor switch 380 is released and returned to its normal position shortly after it engages the contact in the associated contact bank 392 terminating the control conductor C311 and prior to the time it engages the contact in the associated contact bank 392 terminating the control conductor C312. Accordingly, the control relay R420 is not operated at this time. At this time the selector switch 300 occupies its lockout position.

In order to release the established connection between the central switching station C and the terminal station S, the operator at the central switching station C operates the key switch 167 in order to move the switch springs thereof into disengagement, thereby to interrupt the circuit including the telegraph line 101. When the circuit including the telegraph line 101 is interrupted, the repeater 100 operates in the previously described manner to cause the loop circuit 301 to be interrupted, thereby to cause the selector switch 300 to be restored to its normal position, in a manner more particularly described hereinafter. Also, when the circuit including the telegraph line 101 is interrupted, the selector switches included in the stations associated with the telegraph line 101 are released. More particularly, the selector switch 860 is released, thereby to cause the Strowger mechanism included therein to be returned to its normal position at which time the wiper 881 disengages the associated contact terminating the control conductor included in the circuit for energizing the start relay R820, thereby to cause the latter relay to restore. Upon restoring, the start relay R820 interrupts, at RA821, the previously mentioned circuit for operating the motor 828 and for illuminating the supervisory lamp L827, thereby to arrest further operation of the mechanism 810 and to extinguish the supervisory lamp L827 in the terminal station S.

More particularly, when the circuit including the telegraph line 101 is interrupted, the repeater 100 operates, in the previously described manner, to interrupt the loop circuit 301, thereby to cause the line relay R310 to restore. The circuit including the telegraph line 101 is retained in its interrupted condition a predetermined time interval in order to cause the hold relay R320 to restore. Upon restoring, the hold relay R320 completes, at RA321 and RC322, the previously traced alternative circuit for energizing the control relay R380, thereby to cause the latter relay to operate and initiate the timing operation. The control relays R380 and R385 interact, in the previously described manner, in order to cause the wiper 381 of the minor switch 380 to be driven step by step from the normal position thereof. The wiper 381 of the minor switch 380 is then driven step by step until it engages the contact in the associated contact bank 392 terminating the control conductor C312 at which time the previously traced circuit for energizing the control relay R420 is completed in order to cause the latter relay to operate. Upon operating, the control

relay R420 completes, at RA423, the previously traced holding circuit for energizing the winding thereof; interrupts, at RA424 and at RA425, points in the previously traced holding circuit for energizing in multiple the winding of the control relay R440 and the upper winding of the switch-through relay R470; and interrupts, at RA425, a point in the previously traced original circuit for energizing the lower winding of the switch-through relay R470, thereby to cause the control relay R440 and the switch-through relay R470 to restore. Upon restoring, the switch-through relay R470 prepares, at RA471 and at RA472 and RC473, points in the previously traced original loop circuit 301. Also, upon restoring, the switch-through relay R470 interrupts, at RA472 and RC474, a point in the previously traced path for including the shorting strap 402 in the loop circuit 301; interrupts, at RA475, a point in the previously traced original circuit for energizing the relay R440; interrupts, at RA476, a further point in the holding circuit for energizing the upper winding thereof; prepares, at RA476, a point in the previously traced circuit for energizing the test relay R450; and interrupts, at RA477, a point in the previously mentioned path for applying positive battery potential to the wiper 483. Upon restoring, the control relay R440 interrupts, at RA441 and at RA442, additional points in the previously traced path for including the shorting strap 402 in the loop circuit 301 and interrupts, at RA443, an additional point in the previously traced holding circuit for energizing the winding thereof. Also, upon operating, the control relay R420 interrupts, at RA421 and at RA422, additional points in the previously traced path for including the shorting strap 402 in the loop circuit 301. Finally, upon restoring, the switch-through relay R470 completes, at RA479, the alternative circuit for energizing the release magnet M355, this circuit extending from the positive terminal of battery by way of RA311, RC313, RA324, RC326, C317, RA479, C318, the set of switch springs S336 and the winding of the release magnet M355 to the negative terminal of battery. When energized over the above-traced circuit, the release magnet M355 operates to complete, at MA355, the previously traced holding circuit for energizing the winding thereof and to release the wiper set of the Strowger mechanism 480 included in the selector switch 300, thereby to cause the wiper set to be returned to its normal position. When the wiper set of the Strowger mechanism 480 is returned to its normal position, the sets of switch springs S367, S336 and S488 are actuated in the previously described manner. More particularly, the set of switch springs S336 is actuated into disengagement, thereby to interrupt a point in the previously traced holding circuit for energizing the winding of the release magnet M355 in order to cause the release magnet M355 to restore.

When the wiper 391 of the minor switch 390 is driven into engagement with the contact in the associated contact bank 392 terminating the control conductor C313, the previously traced path for short-circuiting the winding of the control relay R340 is completed, thereby to cause the latter relay to restore. Upon restoring, the control relay R340 interrupts, at RA341, a point in the previously traced holding circuit for energizing the winding thereof and interrupts, at RA342, a point in the previously traced circuits for energizing in multiple the windings of the

control relays R400 and R420, thereby to cause the latter relays to restore. Upon restoring, the control relay R400 interrupts, at RA407 and RC408, a point in the previously traced path for applying positive battery potential to the control conductor C538, thereby to remove the busy marking potential from the control conductor C538 of the trunk line 535 extending into the multiple 530. Upon restoring, the control relay R420 interrupts, at RA423, an additional point 10 in the previously traced holding circuit for energizing the winding thereof and prepares, at RA421 and RA422, additional points in the previously traced original loop circuit 301. Also, upon restoring, the control relay R340 interrupts, at RA343 and RC344, a point in the previously traced alternative circuit for energizing the control relay R380, thereby to cause the latter relay to restore and arrest the timing operation.

After the operator at the central switching station C has operated the key switch 167 to retain the circuit including the telegraph line 101 interrupted for a predetermined time interval, she withdraws the plug 105 from the jack 103, thereby to cause the circuit including the telegraph line 101 to be recompleted. When the circuit including the telegraph line 101 is recompleted, the repeater 100 operates in the previously described manner in order to recomplete the loop circuit 301, thereby to cause the line relay R310 to reoperate and cause the hold relay R320 to reoperate, in the previously described manner. Upon reoperating, the hold relay R320 completes, at RA321 and RC323, the previously traced circuit for energizing the release magnet M394, thereby to cause the release magnet M394 to operate and release the wiper 391 of the minor switch 390, whereupon the wiper 391 is returned to its normal position. When the wiper 391 of the minor switch 390 is returned to its normal position, the set of switch springs S395 is actuated into disengagement, thereby to interrupt the previously traced circuit for energizing the release magnet M394 in order to cause the release magnet M394 to restore. At this time the selector switch 300 is completely released for further use.

From the foregoing description of the manner of setting up and releasing a connection from the central switch station C to the terminal stations S by way of the telegraph lines 101, it will be understood that a connection may be extended in a similar manner from the central switching station C by way of the telegraph line 101 to the terminal station N or to a wayside associated with the telegraph line 101. Similarly, a connection may be extended from the central switching station C by way of the telegraph line 102 to either one of the terminal stations N or S or to one of the wayside stations associated with the telegraph line 102. Likewise, a connection may be extended in a similar manner from the central switching station C to the terminal stations E or W or to the wayside stations associated with the telegraph lines 501 or 502. A connection which is to be extended from the central switching station C to either one of the terminal stations E or W may be routed thereto by way of either one of the telegraph lines 501 or 502. However, a connection which is to be extended from the central switching station C to a particular wayside station associated with the telegraph lines 501 or 502 must be routed over the particular one of the telegraph lines 501 or 502 with which the wayside station is associated.

More particularly, it is noted that when a connection is to be extended from the central switching station C over the telegraph lines 102, 501 and 502, respectively, the jacks 104, 503 and 504, respectively, are utilized in connection with the plug associated with the particular dial-transmitting-printing mechanism utilized in the central switching station C.

10 *Extending connections from the station N or S or wayside stations on the telegraph lines 101 or 102 to the station C*

A connection which is to be extended from one of the terminal stations N or S to the central switching station C may be routed thereto by way of either one of the telegraph lines 101 or 102. However, a connection which is to be extended from one of the wayside stations to the central switching station C must be routed thereto by way of the one of the telegraph lines 101 or 102 with which the wayside station is associated. For example, in order to extend a connection from the terminal station S to the central switching station C by way of the telegraph line 101 or to a wayside station associated with the telegraph line 101, the operator at the terminal station S first initiates operation of the dial-transmitting-printing mechanism 810 associated with the telegraph line 101. More particularly, the operator actuates the switch 825, thereby to complete the previously traced circuit for operating the motor 828 and for illuminating the supervisory lamp L827. The operator at the station S then actuates the key switch 814 thereafter to move the switch springs thereof into disengagement, thereby to interrupt the circuit including the telegraph line 101. This circuit is retained in its interrupted condition for a predetermined time interval, thereby to insure that all of the selector switches in the stations associated with the telegraph line 101 initially occupy their released positions. The operator at the station S then returns the key switch 814 to its normal position in order to move the switch springs thereof into engagement, thereby to recomplete the circuit including the telegraph line 101. The operator at the station S then actuates the dial mechanism 811 in order to cause two predetermined series of impulses comprising two predetermined digits to be transmitted over the circuit including the telegraph line 101. The selector switches in the stations associated with the telegraph line 101 follow these two predetermined digits, in the previously described manner, and the repeater 100 operates, in the previously described manner, in order to repeat the two predetermined digits to the loop circuit 301. When the two predetermined digits are repeated to the loop circuit 301, the selector switch 300 operates to follow the two predetermined digits repeated thereto, in the previously described manner. At this time the Strowger mechanisms in the selector switches included in all of the stations associated with the telegraph line 101 occupy predetermined and corresponding positions. More particularly, the wiper sets of the Strowger mechanisms included in these switches engage predetermined and corresponding contact sets in the associated contact banks. These corresponding contact sets in all of the contact banks of the Strowger mechanisms included in the selector switches, with the exception of the contact set in the contact bank included in the Strowger mechanism 480 in the selector switch

300, terminate no line; while this contact set in the contact bank in the Strowger mechanism 480 included in the selector switch 300 terminates the printer line extending to the first printing mechanism in the central switching station C. Accordingly, only the selector switch 300 operates further. More particularly, the selector switch 300 operates as a trunk hunting switch to find a printer line extending to an idle printing mechanism in the central switching station C, in a manner more particularly described subsequently.

When the printer line extending to the idle printing mechanism is found by the selector switch 300, this selector switch switches through 15 and causes the answer-back signal to be transmitted over the loop circuit 301 and repeated by the repeater 100 to the circuit including the telegraph line 101. When the answer-back signal is transmitted over the circuit including the 20 telegraph line 101, all of the selector switches included in the stations associated with the telegraph line 101 are released, as previously explained. Shortly thereafter when the selector switch 300 operates to terminate the return of 25 the answer-back signal over the circuit including the telegraph line 101, the operator at the station S dials the two predetermined digits comprising the lockout number, thereby to cause the selector switches included in each of the other 30 stations associated with the telegraph line 101 to be operated to their lockout positions. At this time the connection between the terminal station S and the central switching station C is completed and the operator at the station S operates the transmitting mechanism 812 therat in order to cause telegraphic impulses to be transmitted over the previously traced loop circuit including the telegraph line 101. These telegraphic impulses are repeated by the repeater 40 100 to the loop circuit 301 and subsequently therefrom to the printing magnet included in the seized printing mechanism included in the central switching station C, thereby to cause the seized printing mechanism to operate and print 45 the telegraphic message transmitted, in a manner more fully described subsequently.

In the event all of the printing mechanisms included in the central switching station C are busy, at this time, the selector switch 300 operates to return a busy signal over the loop circuit 301, which is repeated by the repeater 100 to the circuit including the telegraph line 101. When the busy signal is repeated over the circuit including the telegraph line 101 the supervisory 50 lamp associated with the selector switch 300 in the terminal station S is flashed, thereby to indicate to the operator in the terminal station S that the desired connection cannot immediately be had due to the fact that all of the printing mechanisms included in the central switching station are busy. The operator at the terminal station S then releases the apparatus included in the stations associated with the telegraph line 55 101 in the previously described manner.

More particularly, when the operator at the terminal station S dials the series of impulses comprising the first digit, the repeater 100 operates, in the previously described manner, in order to cause this series of impulses to be repeated to the loop circuit 301, thereby to cause the line relay R310 to follow this series of digits in the previously described manner. The line relay R310 alternately operates and restores at 70 this time in order to cause the previously traced 75 5

5 circuit for energizing in series the control relay 8330 and the vertical magnet M357 to be repeatedly completed, the control relay R330 operating at the beginning of the first impulse of this series of impulses, as previously noted. The first time the vertical magnet M357 is energized, it operates to cause the wiper set of the Strowger mechanism 480 included in the selector switch 300 to be moved one step in the vertical direction, 10 whereupon the sets of switch springs S367, S336 and S488 are actuated in the previously described manner. Upon operating, the control relay R330 causes the control relays R340 and R370 to operate, which latter relays cause the control 15 relay R380 to operate, in the previously described manner. Upon operating, the control relay R380 initiates the timing operation, as previously noted. Also, upon operating, the control relay R340 causes the control relay R400 to operate and apply positive battery potential to the control conductor C538 of the trunk line 535 extending into the multiple 530, thereby to mark the selector switch 300 as busy, as previously noted.

20 25 At the conclusion of the first digit dialed, the wiper set of the Strowger mechanism 480 occupies a vertical position corresponding to the first digit dialed; and shortly thereafter, the control relay R330 restores to prepare the previously traced 30 circuit for energizing the control relay R360 in series with the rotary magnet M356. At the beginning of the first impulse comprising the second digit dialed, the previously traced circuit for energizing in series the control relay R360 and 35 the rotary magnet M356 is completed, whereupon the control relay R360 operates and the rotary magnet M356 operates to drive the wiper set of the Strowger mechanism 480 one step in the radial direction. Upon operating, the control relay R360 causes the control relay R460 to operate, as previously noted. Also, upon operating, the control relay R360 interrupts, at RA363, a point in a circuit, traced hereinafter, for energizing the control relay R350. Upon operating, the 40 control relay R460 interrupts, at RA462, the previously traced holding circuit for energizing the control relay R370, thereby to cause the latter relay to restore. Upon restoring, the control relay R370 interrupts, at RA371 and RC373, the 45 previously traced circuit for energizing the control relay R380, thereby to cause the latter relay to restore and arrest the timing operation. Also upon restoring, the control relay R370 completes, at RA371 and RC372, the previously traced circuit 50 for energizing the release magnet M394, thereby to cause the release magnet M394 to operate and release the wiper 391 of the minor switch 390, whereupon the wiper 391 is returned to its normal position. When the wiper 391 of the minor switch 390 is returned to its normal position, the set of switch springs S395 is actuated to interrupt the previously traced circuit for energizing the release magnet M394. At the conclusion of the second digit dialed, the wiper set 55 of the Strowger mechanism 480 occupies a radial position corresponding to the second digit dialed and engages the contact in the associated contact bank terminating the printer line extending to the first printing mechanism 490. More particularly, the wipers 481 and 482 engage the contacts in the associated contact bank terminating the line conductors C561 and C562 of the printer line extending to the first printing mechanism 490; the wiper 483 engages the contact 60 65 in the associated contact bank terminating the

control conductor C563 of the printer line extending to the first printing mechanism 490; and the wiper 484 engages the contact in the associated contact bank strapped to the contact terminating the control conductor C563. The subsequent operation of the selector switch 300 depends upon the idle or busy condition of the first printing mechanism 490.

70 Assuming that the first printing mechanism 490 is busy, positive battery potential appears upon the control conductor C563. Accordingly, a circuit is completed for energizing the test relay R450, this circuit extending from positive battery potential appearing upon the control conductor C563 by way of the contact terminating this control conductor, the associated wiper 483, RA463, RA464, RA476 and the winding of R450 to the negative terminal of battery. When energized over the above-traced circuit, the test relay R450 operates to prepare, at RA451, a circuit, traced hereinafter, for energizing the busy relay R430 and completes, at RA454, a circuit for energizing the control relay R350, the latter circuit being prepared at RA467 when the control relay R460 operated and at RA363 when the control relay R360 restored shortly following the conclusion of the second digit dialed. The previously mentioned circuit for energizing the control relay R350 extends from the positive terminal of battery appearing upon the control conductor C563 by way of the contact terminating this control conductor, the strap connecting the last-mentioned contact to the contact engaged by the wiper 484, the last-mentioned contact, the associated wiper 484, RA467, RA454, C319, RA363, MA356 and the winding of R350 to the negative terminal of battery. When energized over the above-traced circuit, the relay R350 operates to complete, at RA353, a holding circuit for energizing the winding thereof, this circuit extending from the positive terminal of battery by way of RA353, MA356 and the winding of R350 to the negative terminal of battery. Also, upon operating, the control relay R350 completes, at RA351, an alternative circuit for energizing the control relay R460, this circuit extending from the positive terminal of battery by way of RA351, C320 and the winding of M460 to the negative terminal of battery. Accordingly, the operation of the control relay R460, which latter relay is of the slow-to-release type, prevents the control relay R350 from restoring at this time. Finally, upon operating, the control relay R350 completes, at RA352, an obvious circuit for energizing the rotary magnet M356 in order to cause the rotary magnet M356 to operate. Upon operating, the rotary magnet M356 interrupts, at MA356, a point in the previously traced holding circuit for energizing the winding of the control relay R350 and drives the wiper set of the Strowger mechanism 480 an additional step in the radial direction. When the previously traced circuit for energizing the winding of the control relay R350 is interrupted, the latter relay restores to interrupt, at RA351, the previously traced alternative circuit for energizing the control relay R460; to interrupt at RA353, a further point in the holding circuit for energizing the winding thereof; and to interrupt, at RA352, the previously mentioned circuit for energizing the rotary magnet M356, thereby to cause the rotary magnet M356 to restore. Upon restoring, the rotary magnet M356 reprepares, at MA356, the original circuit for energizing the winding of the control relay R350. When the wiper set of the Strowger 75

mechanism 488 is driven the previously mentioned additional step in the radial direction, the wipers thereof engage the corresponding contacts in the associated contact bank terminating the conductors of the printer line extending to the second printing mechanism 487. At this time further operation of the selector switch 300 depends upon the idle or busy condition of the second printing mechanism 487.

Assuming that the second printing mechanism 487 is busy, positive battery potential appears upon the control conductor C588 thereof, thereby to recomplete the previously traced circuit for energizing the test relay R458, which latter relay reoperates to recomplete, at RA454, the previously traced original circuit for energizing the winding of the control relay R358. The control relay R358 then reoperates to cause the rotary magnet M358 to be reenergized, whereupon the wiper set of the Strowger mechanism 488 is driven an additional step in the radial direction. The test relay R458, the control relay R358 and the rotary magnet M358 interact in the above-described manner in order to cause the wiper set of the Strowger mechanism 488 to be driven step by step in the radial direction until a printer line extending to an idle printing mechanism or the printer line extending to the last busy printing mechanism in this group of printing mechanisms is seized by the wiper set thereof.

Assuming that the third printing mechanism 488 is the last printing mechanism in this group of printing mechanisms and that this printing mechanism is busy when the wiper set of the Strowger mechanism engages in the associated contact bank the contact set terminating the printer line extending thereto, at this time the wiper 488 engages the contact in the associated contact bank terminating the control conductor C588 of the printer line extending to the third printing mechanism 488 and positive battery potential appears upon this control conductor, whereupon the previously traced circuit for energizing the winding of the test relay R458 is recompleted. However, upon operating, the test relay R458 does not recomplete the previously traced circuit for energizing the winding of the control relay R358 due to the fact that the contact in the associated contact bank engaged by the wiper 488 is not strapped to the contact terminating the control conductor C588. Accordingly, the control relay R358 is not reoperated and consequently the rotary magnet M358 is not reoperated to drive the wiper of the Strowger mechanism 488 an addition step in the radial direction. Shortly after the test relay R458 reoperates, the slow-to-release relay R460 restores to complete, at RA464 and RC465, a holding circuit for energizing the winding of the test relay R458, this circuit extending from the positive terminal of battery by way of the set of switch springs S488, RA452, RA451, RC452, RC455, RA464, RA478 and the winding of R458 to the negative terminal of battery. Also, upon restoring, the control relay R460 completes, at RA461, the previously mentioned circuit for energizing the busy relay R458, this circuit extending from the positive terminal of battery by way of RA461, RA451, the winding of R458 and the resistor 488 to the negative terminal of battery. Shortly after the busy relay R458 is energized over the above-traced circuit, the latter relay, being of the slow-to-operate type, operates to complete, at RA453, a path for short-circuiting the winding thereof, this path extending from RA453 by way of RA451 and the winding of R458

to RA453. When the above-mentioned path for short-circuiting the winding of the busy relay R458 is completed, the latter relay restores to interrupt, at RA453, the previously traced path for short-circuiting the winding thereof, whereupon the previously traced circuit for energizing the winding thereof is completed. Shortly thereafter the busy relay R458 reoperates. Accordingly, the busy relay R458 operates and restores periodically. Each time the busy relay R458 operates, it interrupts, at RA451 and RA452, points in the loop circuit 301; and each time the busy relay R458 restores, it recomplices, at RA451 and RA452, points in the loop circuit 301. Accordingly, a busy signal is transmitted over the loop circuit 301 to the repeater 100 and is repeated thereby to the circuit including the telegraph line 101, thereby to indicate to the operator at the terminal station S that the desired connection may not immediately be had due to the fact that all of the printing mechanisms at the central switch station C are busy at this time.

More particularly, each time the loop circuit 301 is interrupted, the circuit for energizing in series the lower windings of the relays R138 and R140 is interrupted. When the circuit for energizing the lower winding of the relay R140 is interrupted, the latter relay is retained in its operated position due to the previously traced completed circuit for energizing the upper winding thereof; however, when the circuit for energizing the lower winding of the relay R138 is interrupted, the latter relay restores due to the fact that the previously traced path for short-circuiting the upper winding thereof is completed at this time. Upon restoring, the relay R138 interrupts, at RA131 and RC133, a point in the previously traced path for short-circuiting the upper winding of the control relay R128, thereby to cause the upper winding of the latter relay to be energized. Finally, upon restoring, the relay R138 completes, at RA131 and RC133, the previously traced path for short-circuiting the upper winding of the relay R118, thereby to cause the latter relay to restore due to the fact that the magnetic flux produced by the upper winding of the latter relay predominates over the magnetic flux produced by the lower winding thereof. Upon restoring, the relay R118 interrupts, at RA111, the circuit for energizing in series the lower windings of the relays R118 and R128. However, the relay R128 does not restore due to the fact that the previously traced circuit for energizing the upper winding thereof is completed at this time. Also, upon restoring the relay R118 interrupts, at RA111, a point in the circuit including the telegraph line 101.

When the loop circuit 301 is recompleted, the relay R138 reoperates to interrupt, at RA131 and RC132, the previously traced path for short-circuiting the upper winding of the relay R118, thereby to cause the latter relay to operate and complete, at RA111, the previously traced circuit for energizing in series the lower windings of the relays R118 and R128. Also, the relay R138 completes, at RA131 and RC133, the previously traced path for short-circuiting the upper winding of the relay R128. However, the latter relay does not restore due to the fact that the previously traced circuit for energizing the lower winding thereof is completed at this time. Also, at RA111, the relay R118 completes the circuit including the telegraph line 101. Thus, when the loop circuit 301 is alternately interrupted and completed, due to the operation of the busy

relay R430, the repeater 100 operates to cause the circuit including the telegraph line 101 to be alternately interrupted and completed in the manner described above.

The busy signal transmitted over the circuit including the telegraph line 101 causes the supervisory lamp associated with the selector switch 300 in the terminal station S to flash, thereby to indicate to the operator thereat that the desired connection cannot immediately be had, as previously noted.

The operator at the terminal station S then releases the apparatus associated with the telegraph line 101 by operating the key switch 814 thereat to cause the switch springs thereof to be actuated into disengagement. The key switch 814 is retained in its operated position for a predetermined time interval, thereby to cause the circuit including the telegraph line 101 to be retained interrupted for this predetermined time interval. When the circuit including the telegraph line 101 is retained interrupted for this predetermined time interval, the selector switches included in the stations associated with the telegraph line 101 are released. Also, the repeater 100 causes the selector switch 300 to be released in the previously described manner.

Assuming that the first printing mechanism 490 in the group of printing mechanisms included in the central switching station C is idle when the wiper set of the Strowger mechanism 480 included in the selector switch 300 is operated to engage the contact set in the associated contact bank terminating the printer line extending thereto, negative battery potential appears upon the control conductor C563. This negative battery potential is derived at the negative terminal of battery and extends by way of the winding of the start relay R494 to the control conductor C563. This application of negative battery potential to the control conductor C563 completes a path for short-circuiting the winding of the test relay R450, this path extending from negative battery potential appearing upon the control conductor C563 by way of the contact in the contact bank terminating this control conductor, the associated wiper 483, RA463, RA464, RA476 and the winding of R450 to the negative terminal of battery. Thus, the test relay R450 does not operate due to the above-traced completed path for short-circuiting the winding thereof and shortly thereafter, the control relay R460 restores, as previously noted. Upon restoring, the control relay R460 completes, at RA463 and RC466, the previously traced circuit for energizing the lower winding of the switch-through relay R470, which latter relay operates partially to close the "X" contacts associated with the armature RA470, thereby to complete the previously traced holding circuit for energizing the upper winding thereof. When the previously traced holding circuit for energizing the upper winding of the switch-through relay R470 is completed, the latter relay operates fully to complete, at RA477, an obvious path for applying positive battery potential to the wiper 483. This application of positive battery potential to the wiper 483 completes a circuit for energizing the start relay R496, this circuit extending from positive battery potential appearing upon the wiper 483 by way of the contact in the associated contact bank terminating the control conductor C563, the latter control conductor and the winding of R494 to the negative terminal of battery. When energized over the above-traced circuit, the motor

start relay R494 operates to complete, at RA495, an operating circuit for the motor 492, this circuit extending from one terminal of the battery 493 by way of RA495 and the motor 492 to the other terminal of the battery 493. When the above-traced circuit is completed, operation of the motor 492 is initiated which conditions the printing mechanism 490 to be operative to print telegraphic impulses transmitted to the printing magnet PM491 thereof.

Also, upon operating, the switch-through relay R470 interrupts, at RA479, a point in the previously traced alternative circuit for energizing the release magnet M355 and interrupts, at RA471 and at RA472, points in the loop circuit 301. Further, the control relay R470 prepares, at RA472 and RC474, a point in a path, traced hereinafter, for including the printing magnet PM491 in the loop circuit 301 and prepares, at RA475, the previously traced circuit for energizing the control relay R440. When the loop circuit 301 is interrupted, the repeater 100 operates to interrupt the circuit including the telegraph line 101, this interruption of the circuit including the telegraph line 101 constituting an answer-back signal transmitted thereover to the terminal station S, thereby to indicate to the operator thereat that the selector switch 300 included in the central switching station C has operated to seize an idle printing mechanism therein.

Also, when the loop circuit 301 is interrupted, the line relay R310 restores to cause the hold relay R320 to restore shortly thereafter. Upon restoring, the hold relay completes, at RA321 and RC322, the previously traced alternative circuit for energizing the control relay R380, the latter circuit being prepared at RA343 and RC344 due to the operated condition of the control relay R340 at this time. When the previously traced alternative circuit for energizing the control relay R380 is completed the latter relay operates to initiate the timing operation, whereupon the rotary magnet M393 is repeatedly energized, as previously explained. The repeated energization of the rotary magnet M393 causes the wiper 391 of the minor switch 390 to be driven step in the clockwise direction, as previously noted. When the wiper 391 of the minor switch 390 engages the contact in the associated contact bank 392 terminating the control conductor C311, the previously traced circuit for energizing the control relay R440 is completed, which latter relay operates to complete, at RA443, the previously traced holding circuit for energizing the winding thereof and to complete, at RA441 and at RA442, the previously mentioned path for including the printing magnet PM491 in the loop circuit 301. The loop circuit 301 then extends from the positive terminal of battery by way of the resistor 435, RC415, RA414, RA432, RA472, RC474, the wiper 481, the contact in the associated contact bank terminating the line conductor C561 of the printer line extending to the first printing mechanism 490, the last-mentioned line conductor, the winding of the printing magnet PM491, the line conductor C562 of the printer line extending to the first printing mechanism 490, the contact in the associated contact bank terminating the last-mentioned line conductor, the wiper 482, RA442, RA422, C310, the winding of the line relay R310, C303, RA414, the lower windings of the relays R130 and R140, C302, RA441, RA421, RA411, RC412 and the resistor 434 to the negative terminal of battery. When the loop circuit 301 is

thus recompleted, the line relay R318 reoperates and causes the hold relay R328 to reoperate in the previously described manner. Upon reoperating, the hold relay R328 interrupts, at 5 RA321 and RC322, the previously traced alternative circuit for energizing the control relay R388, thereby to cause the latter relay to restore and arrest the timing operation. Also, upon reoperating, the hold relay R328 completes, at 10 RA321 and RC322, the previously traced circuit for energizing the release magnet M384. The release magnet M384 then operates to cause the wiper 381 of the minor switch 380 to be released and returned to its normal position at which 15 time the set of switch springs S385 is actuated into disengagement, thereby to interrupt the previously traced circuit for energizing the release magnet M384.

Also, when the loop circuit 381 is recompleted, 20 the repeater 100 reoperates to cause the circuit including the telegraph line 101 to be recompleted in the previously described manner. When the previously traced circuit including the telegraph line 101 is thus recompleted, the supervisory lamp associated with the selector switch 800 included in the terminal station S is extinguished, thereby to indicate to the operator thereat that the connection between the terminal station S and the central switching station C has 25 been completed. The operator at the terminal station S then dials the two digits comprising the lockout number, thereby to cause the selector switches included in the other stations associated with the telegraph line 101 to be operated to their lockout positions. Finally, the operator at 30 the terminal station S operates the transmitting mechanism 812 in order to cause telegraphic impulses to be transmitted over the circuit including the telegraph line 101, which telegraphic impulses are repeated by the repeater 100 over the loop circuit 381, thereby to cause the printing magnet PM491 to follow the telegraphic impulses and cause the printing mechanism 490 to print the telegraphic message transmitted thereto.

45 The established connection between the terminal station S and the central switching station C may be released under the control of the operator at the station S in the previously described manner, the release being effected by the operator 50 at the terminal station S upon operating the key switch 814 to cause the circuit including the telegraph line 101 to be interrupted for a predetermined time interval.

55 From the foregoing description of the manner of setting up and releasing a connection by way of the telegraph line 101 from the terminal station S to the central switching station C, it will be understood that a connection may be extended in a similar manner by way of the telegraph line 60 101 from the terminal station N or from one of wayside stations associated with the telegraph line 102 to the central switching station C. Likewise a connection may be extended by way of the telegraph line 102 from either one of the 65 terminal stations N or S or from one of the wayside stations associated with the telegraph line 102 to the central switching station C; and a connection may be extended from one of the 70 terminal stations E or W or from one of the wayside stations on the telegraph lines 501 or 502 to the central switching station C. A connection which is to be extended from one of the terminal stations W or E to the central switching station C may be routed thereto by way of either 75 one of the telegraph lines 501 or 502. However,

a connection which is to be extended from a particular wayside station associated with the telegraph lines 501 or 502 must be routed over the particular one of the telegraph lines 501 or 502 with which the wayside station is associated. 5 More particularly, a connection which is to be extended from one of the terminal stations N or S by way of the telegraph line 102 or from one of the wayside stations associated with the telegraph line 102 may be extended to the central switching station C by way of the repeater 100 and the selector switch 518 individually associated therewith. More particularly, a connection which is to be extended from one of the terminal stations E or W by way of the telegraph line 501 or from one of the wayside stations associated with the telegraph line 501 to the central switching station C may be extended thereto by way of the selector switch 708; and a connection which is to be extended from one of the terminal stations 20 E or W by way of the telegraph line 502 or from one of the wayside stations associated with the telegraph line 502 to the central switching station C may be extended thereto by way of the selector switch 520. 25

Extending connections from the stations N or S to the stations W or E

A connection which is to be extended from one of the terminal stations N or S to one of the 30 terminal stations E or W may be routed thereto by way of either one of the telegraph lines 101 or 102 and one of the telegraph lines 501 or 502. For example, in order to extend a connection from the terminal station S to the terminal 35 station E by way of the telegraph line 101 and one of the telegraph lines 501 or 502, the operator at the terminal station S first initiates operation of the dial-transmitting-printing mechanism 810 associated with the telegraph line 101. More particularly, the operator actuates the switch 825, thereby to complete the previously traced circuit for operating the motor 828 and for illuminating the supervisory lamp L827, in the previously described manner. The operator at the station S 45 then operates the key switch 814 thereat in order to move the switch springs into disengagement, thereby to interrupt the circuit including the telegraph line 101. This circuit is retained in its interrupted condition for a predetermined 50 time interval, thereby to insure that all of the selector switches in the stations associated with the telegraph line 101 initially occupy their released positions. The operator at the station S then returns the key switch 814 to its normal position 55 in order to move the switch springs thereof into engagement, thereby to recomplete the circuit including the telegraph line 101. The operator at the station S then actuates the dial mechanism 811 thereat in order to cause two predetermined 60 series of impulses comprising two predetermined digits to be transmitted over the circuit including the telegraph line 101. The selector switches in stations associated with the telegraph line 101 follow these two predetermined digits in 65 the previously described manner and the repeater 100 operates, in the previously described manner, in order to repeat the two predetermined digits to the loop circuit 381 extending between the repeater 100 and the selector switch 380, thereby 70 to cause the selector switch 380 to follow the two predetermined digits dialed. At this time the wiper sets of the Strowger mechanisms in the selector switches included in the stations associated with the telegraph line 101 engage prede- 75

terminated and corresponding contact sets in the associated contact banks; however, only the wiper set of the Strowger mechanism 480 in the selector switch 300 included in the central switching station C engages a contact set terminating a line. More particularly, the wiper set of the Strowger mechanism 480 engages a contact set terminating the trunk line 541 extending into the selector switch 520 associated with the telegraph line 502. In the event the telegraph line 502 is idle, the selector switch 300 switches through and causes the answer-back signal to be returned by way of the repeater 100 over the circuit including the telegraph line 101, thereby to cause the selector switches included in each of the other stations associated with the telegraph line 101 to be released in the previously described manner. However, in the event the telegraph line 502 is busy, the selector switch 520 occupies an operated position and causes the trunk line 541 to be marked as busy, whereupon the selector switch 300 operates to select the trunk line 545 extending into the selector switch 700 associated with the telegraph line 501. In the event the telegraph line 501 is idle, the selector switch 300 switches through in the previously described manner. However, in the event the telegraph line 501 is busy, the selector switch 700 occupies an operated position, thereby to mark the trunk line 545 as busy, whereupon the selector switch 300 operates to cause the busy signal to be returned by way of the repeater 100 over the circuit including the telegraph line 101. Assuming that one of the telegraph lines 501 or 502 is idle, the selector switch 300 switches through, as previously noted, and causes the answer-back signal to be returned by way of the repeater 100 over the circuit including the telegraph line 101. The selector switches included in the stations associated with the telegraph line 101 are then released, as previously explained.

The operator at the terminal station S then dials two additional predetermined digits, thereby to cause the selector switches included in the stations associated with the telegraph line 101 to follow the digits dialed and to cause the repeater 100 to repeat the two digits dialed by way of the operated selector switch 300 and one of the seized selector switches 520 or 700 over the corresponding one of the telegraph lines 502 or 501. The two digits transmitted over the corresponding one of the telegraph lines 501 or 502 cause the selector switches included in the stations associated therewith to follow the two digits dialed. At this time the wiper sets of the Strowger mechanisms in the selector switches included in the stations associated with the telegraph line 101 and with the seized one of the telegraph lines 501 or 502 engage corresponding contact sets in the associated contact banks. However, only the wiper set of the Strowger mechanism in the selector switch included in the terminal station E engages a contact set in the associated contact bank terminating a line. More particularly, the last-mentioned contact set terminates a printer line extending to an idle printing mechanism in the terminal station E. The selector switch included in the terminal station E then switches through to cause the idle printing mechanism to be seized and to cause the answer-back signal to be returned over the seized telegraph line 501 or 502 by way of the corresponding one of the selector switches 700 or 520, the operated selector switch 300 and the repeater 100 to the circuit including

the telegraph line 101, whereupon each of the selector switches included in the stations associated with the telegraph line 101, with the exception of the operated selector switch 300, and each of the selector switches associated with the seized telegraph line 501 or 502, with the exception of the corresponding one of the operated selector switches 700 or 520 and the operated selector switch in the terminal station E, are released. Subsequently, the operated selector switch included in the terminal station E operates to terminate the return of the answer-back signal over the seized one of the telegraph lines 501 or 502.

The operator at the terminal station S then operates the dial mechanism 811 thereat in order to transmit the two series of impulses comprising the two digits of the lockout number over the previously traced circuit including the telegraph line 101, which two digits are repeated by the repeater 100, the selector switch 300 and the operated one of the selector switches 520 or 700 over the corresponding seized one of the telegraph lines 502 or 501, thereby to cause the remainder of the selector switches included in the stations associated with the telegraph line 101 and the seized one of the telegraph lines 501 or 502 to be operated to their lockout positions. Subsequently, the operator at the terminal station S operates the transmitting mechanism 812 thereat in order to transmit telegraphic impulses over the previously traced circuit including the telegraph line 101, which telegraphic impulses are repeated by way of the repeater 100 over the seized telegraph line 501 or 502, thereby to cause the seized printing mechanism included in the terminal station E to operate and print the telegraphic message, as previously explained.

More particularly, when the repeater 100 operates to repeat the first two mentioned digits to the loop circuit 301, the selector switch 300 operates, in the previously described manner, in order to cause the wiper set of the Strowger mechanism 480 thereat to engage a corresponding contact set in the associated contact bank. More particularly, the wipers 481 and 482 of the wiper set engage the contacts in the associated contact bank terminating the line conductors C542 and C543 of the trunk line 541 extending into the multiple 540; while the wiper 483 engages the contact in the associated contact bank terminating the control conductor C544 of the trunk line 541; and the wiper 484 engages the contact in the associated contact bank connected to the contact in the associated contact bank terminating the control conductor C544. At this time the selector switch 300 has operated to seize the trunk line 541 extending to the selector switch 520 associated with the telegraph line 502. In the event the telegraph line 502 is busy, the selector switch 520 occupies an operated position, whereupon positive battery potential appears upon the control conductor C544 of the trunk line 541. This application of positive battery potential to the control conductor C544 of the trunk line 541 completes the previously traced circuit for energizing the test relay R450, which latter relay operates to complete, at RA454, the previously traced circuit for energizing the control relay R350 due to the fact that the contact in the associated contact bank engaged by the wiper 484 is connected to the contact in the associated contact bank terminating the control conductor C544. Accordingly, the control relay R350 operates to cause the rotary magnet M356 to be energized, whereupon the wiper set of the

Strowger mechanism 480 is driven an additional step in the radial direction, in the previously described manner. When the wiper set of the Strowger mechanism 480 is driven this additional step in the radial direction, the wipers 481 and 482 thereof engage the contacts in the associated contact bank terminating the line conductors C546 and C547 of the trunk line 545 extending into the multiple 540; while the wiper 483 engages the contact in the associated contact bank terminating the control conductor C548 of the trunk line 545; and the wiper 484 engages a contact in the associated contact bank which is not connected to the contact in the associated contact bank terminating the control conductor C548. Accordingly, the previously traced circuit for energizing the control relay R350 cannot be again completed and the wiper set of the Strowger mechanism 480 is not driven an additional step in the radial direction. The subsequent operation of the selector switch 300 depends upon the idle or busy condition of the trunk line 545. In the event the trunk line 545 is busy, positive battery potential appears upon the control conductor C548 thereof; and in the event the trunk line 545 is idle, negative battery potential appears upon the control conductor C548 thereof.

Assuming that the trunk line 545 is busy, positive battery potential appearing upon the control conductor C548 thereof causes the above-traced circuit for energizing the winding of the test relay R450 to be completed, whereupon the test relay R450 operates. Shortly thereafter the control relay R460 restores to complete, at RA464 and RC465, the previously traced holding circuit for energizing the winding of the test relay R450 and to complete, at RA461, the previously traced circuit for energizing the busy relay R430. The busy relay R430 operates, in the previously described manner, to intermittently interrupt, at RA431 and RA432, the loop circuit 301, thereby to transmit the busy signal thereover. The busy signal is repeated by the repeater 100 over the circuit including the telegraph line 101, thereby to indicate to the operator at the terminal station S that the desired connection cannot immediately be had due to the fact that both of the telegraph lines 501 and 502 extending to the terminal station E are busy at this time. The operator at the terminal station S then releases the apparatus associated with the telegraph line 101, in the previously described manner, by operating the key switch 814 in order to cause the circuit including the telegraph line 101 to be interrupted for a predetermined time interval.

Assuming that the trunk line 545 is idle at this time, negative battery potential appearing upon the control conductor C548 thereof completes the previously traced path for short-circuiting the winding of the test relay R450. Thus, the test relay R450 does not operate and shortly thereafter the control relay R460 restores to complete, at RA463 and RC466, the previously traced circuit for energizing the lower winding of the switch-through relay R470.

Before proceeding with the subsequent operation of the selector switch 300 in response to the operation of the switch-through relay R470, it is noted that the selector switch 700 is included directly in the telegraph line 501 extending between the terminal stations E and W. More particularly, one end of the telegraph line 501 is connected to the positive terminal of battery in

the terminal station E and extends therefrom by way of the jack 503 into the selector switch 700. This portion of the telegraph line 501 extending into the selector switch 700 is connected by way of RA631, RA671, RA621, RA611 and RC612 to 5 the resistor 634. The other end of the telegraph line 501 is connected to the negative terminal of battery in the terminal station W and extends therefrom into the selector switch 700. This portion of the telegraph line 501 extending into 10 the selector switch 700 is connected by way of the winding of the line relay R710, RA622, RC673, RA672, RA632, RA614 and RC615 to the resistor 635, the resistors 634 and 635 being connected together by a strap 636. 15

Continuing now with the operation of the selector switch 300 subsequent to the operation of the switch-through relay R470, when the lower winding for energizing the latter relay is completed, the latter relay partially operates to close 20 the "X" contacts associated with the armature RA470, as previously explained, thereby to complete the previously traced holding circuit for energizing the upper winding thereof. When the previously traced holding circuit for energizing 25 the upper winding of the switch-through relay R470 is completed, the latter relay fully operates to interrupt, at RA471 and at RA472 and RC473, the loop circuit 301; to prepare, at RA472 and RC473, a point in a circuit, traced hereinafter, 20 for including the trunk line 545 in the loop circuit 301; to prepare, at RA478, a circuit, traced hereinafter, for energizing the control relay R410; to prepare, at RA475, a point in the previously 25 traced circuit for energizing the control relay R440; to interrupt, at RA476, the previously traced path for short-circuiting the winding of the test relay R450; to complete, at RA477, an obvious path for applying positive battery potential to the wiper 483; and to interrupt, at RA479, a 40 point in the previously traced alternative circuit for energizing the release magnet M355. When the loop circuit 301 is interrupted, at RA471 and at RA472 and RC473, the line relay R310 restores in order to cause the hold relay R320 to 45 restore shortly thereafter, in the previously described manner. Also, this interruption of the loop circuit 301 constitutes the answer-back signal and causes the repeater 100 to operate and interrupt the circuit including the telegraph line 101 50 in the previously described manner. When the circuit including the telegraph line 101 is thus interrupted, the selector switches included in the stations associated with the telegraph line 101 are released, in the previously described manner, 55 and the supervisory lamp associated with the selector switch 800 included in the terminal station S is illuminated, thereby to indicate to the operator at the terminal station S that the selector switch 300 has operated to seize an idle 60 telegraph line extending to the terminal station E. Upon restoring, the hold relay R320 completes, at RA321 and RC322, the previously traced alternative circuit for energizing the control relay R380, thereby to cause the latter relay to 65 operate and initiate the timing operation. Due to the interaction of the control relays R380 and R385, the rotary magnet M393 is repeatedly operated, thereby to cause the wiper 391 of the minor switch 390 to be driven step by step in 70 the clockwise direction. When the wiper 391 of the minor switch 390 engages the contact in the associated contact bank 392 terminating the control conductor C311, the previously traced circuit for energizing the control relay R440 is com- 75

pleted, thereby to cause the latter relay to operate. Upon operating, the control relay R448 completes, at RA443, the previously traced holding circuit for energizing the winding thereof and prepares, at RA441 and RA442, additional points in the previously mentioned circuit for including the trunk line 545 in the loop circuit 301.

Also, it is noted that the level in the contact bank of the Strowger mechanism 480 wherein the trunk lines 541 and 545 are terminated has the sets of switch springs S485 and S487 associated therewith, whereby the last-mentioned sets of switch springs are actuated when the wiper set of the Strowger mechanism 480 is moved 15 in the vertical direction to the level mentioned. More particularly, these two sets of contact springs S487 is actuated into engagement, a holding circuit is completed for energizing the winding of the control relay R400, this holding circuit 20 extending from the positive terminal of battery by way of the set of switch springs S487, C538, RA407, RC408 and the winding of R400 to the negative terminal of battery. When the set of switch springs S485 is actuated into engagement, a 25 circuit for energizing the control relay R410 is prepared, which circuit is not completed until the switch-through relay R470 operates. Upon operating, the switch-through relay R470 completes, at RA478, the previously mentioned circuit 30 for energizing the control relay R410, the latter circuit extending from the positive terminal of battery by way of the set of switch springs, S487, RA478, the set of switch springs S485 and the winding of R410 to the negative terminal of 35 battery. Shortly after being energized over the above-traced circuit, the control relay R410, being of the slow-to-operate type, operates to prepare, at RA411 and RC413 and at RA414 and RC416, further points in the previously mentioned 40 circuit for connecting the trunk line 545 in the loop circuit 301.

The application of positive battery potential to the wiper 483 completes a circuit for energizing the control relay R610, this circuit extending from the positive terminal of battery by way of RA477, the wiper 483, the contact in the associated contact bank terminating the control conductor C548 of the trunk line 545, C548, RA607, RC609 and the winding of R610 to the negative 45 terminal of battery. Shortly after the control relay R610 is energized over the above-traced circuit, the latter relay, being of the slow-to-operate type, operates to interrupt, at RA617 and RC619, a point in a circuit, traced hereinafter, 50 for energizing the control relay R600; to interrupt, at RA611 and RC612 and at RA614 and RC615, points in the previously traced circuits for connecting the resistors 634 and 635 in the telegraph line 501; and to complete, at RA611 and RC613 and at RA614 and RC616, a circuit for connecting the loop circuit 301 and the trunk line 545 directly in the telegraph line 501. At this time the telegraph line 501 is included in a circuit extending from the positive terminal of battery in the terminal station E by way of the jack 503, the portion of the telegraph line 501 extending into the selector switch 700, RA631, RA671, RA621, RA611, RC613, RA604, RC605, the line conductor C547 of the trunk line 545, 55 the contact in the contact bank of the Strowger mechanism 480 terminating the line conductor C547, the associated wiper 482, RA442, RA422, C310, the winding of the line relay R310, C303, RA411, the lower windings of the relays R130, 60 and R140, C302, RA441, RA421, RA411, RC413, 65 and R140, C302, RA441, RA421, RA411, RC413, 70 and R140, C302, RA441, RA421, RA411, RC413, 75

RC403, RA401, RC416, RA414, RA432, RA472, RC474, the wiper 481, the contact in the associated contact bank of the Strowger mechanism 480 terminating the line conductor C546 of the trunk line 545, the line conductor C546, RC602, RA601, RC616, RA614, RA632, RA672, RC673, RA622, the winding of the line relay R710 and the portion of the telegraph line 501 extending from the selector switch 700 to the terminal station W, the negative terminal of battery being connected to the end of the telegraph line 501 extending into the terminal station W.

When the above-traced circuit for including the loop circuit 301 directly in the telegraph line 501 is completed, the line relay R310 reoperates to cause the hold relay R320 to reoperate, as previously explained. Upon reoperating, the hold relay R320 interrupts, at RA321 and RC322, the previously traced alternative circuit for energizing the control relay R380, thereby to cause the latter relay to restore and arrest the timing operation. Also, upon reoperating, the hold relay R320 completes, at RA321 and RC323, the previously traced circuit for energizing the release magnet M394, thereby to cause the wiper 391 of the minor switch 390 to be released in the previously described manner.

It is noted that when the control relay R610 operates it interrupts, at RA611 and RC612 and at RA614 and RC615, points in the circuit including the telegraph line 501 for energizing the line relay R710 shortly prior to the time it completes, at RA611 and RC613 and at RA614 and RC616, the previously traced path for directly connecting the loop circuit 301 in the telegraph line 501. Accordingly, the line relay R710 restores instantaneously and completes, at RA711 and RC713, a circuit for energizing in series the control relay R730 and the vertical magnet M757, this circuit extending from the positive terminal of battery by way of RA711, RC713, RA724, RC725, the switch springs S766 and S764 of the set of switch springs S767, the winding of R730 and the winding of M757 to the negative terminal of battery. Also, upon restoring, the line relay R710 interrupts, at RA711 and RC712, the normally completed and obvious circuit for energizing the hold relay R720. However, the latter relay, being of the slow-to-release type, does not immediately restore. Also, as previously noted, the previously traced path for connecting the loop circuit 301 directly in the telegraph line 501 is completed shortly thereafter, thereby to cause the line relay R710 to be reenergized, whereupon the line relay R710 reoperates to recomplete, at RA711 and RC712, the previously mentioned circuit for energizing the hold relay R720 and to interrupt, at RA711 and RC713, the previously traced circuit for energizing in series the control relay R730 and the vertical magnet M757. When energized over the previously mentioned circuit, the control relay R730 operates to complete, at RA731, an obvious circuit for energizing the control relay R740 which latter relay operates to complete, at RA741, an obvious holding circuit for energizing the winding thereof. When the vertical magnet M757 is thus energized, it operates to drive the wiper set of the Strowger mechanism 680 included in the selector switch 700 one step in the vertical direction, thereby to cause the sets of switch springs S767, S736 and S688 to be actuated. More particularly, the set of switch springs S688 are actuated into engagement, thereby to prepare a circuit, traced hereinafter, for energizing the control relay R770; and the switch springs S766 75

and S764 of the set of switch springs S767 are actuated into disengagement, thereby to interrupt a point in the previously traced circuit for energizing in series the control relay R730 and the vertical magnet M751. Also, the switch springs S766 and S765 are actuated into engagement, thereby to prepare an alternative circuit, traced hereinafter, for energizing in series the control relay R730 and the vertical magnet M751. The set of switch springs S736 are actuated into engagement in order to prepare a circuit, traced hereinafter, for energizing the release magnet M755.

Also, upon operating, the control relay R730 completes, at RA732 and RC733, the previously mentioned alternative circuit for energizing in series the winding of R730 and the winding of M751, this circuit extending from the positive terminal of battery by way of RA711, RC713, RA724, RC725, the switch springs S766 and S765, RA732, RC733, the winding of R730 and the winding of M751 to the negative terminal of battery. Also, upon operating, the control relay R730 completes, at RA735, the previously mentioned circuit for energizing the control relay R770, the latter circuit extending from the positive terminal of battery by way of the set of switch springs S688, C716, RA735, C723 and the winding of R770 to the negative terminal of battery. When energized over the above-traced circuit, the control relay R770 operates to complete, at RA775, a holding circuit for energizing the winding thereof, this circuit extending from the positive terminal of battery by way of the set of switch springs S688, RA625, RA624, RA662, C721, RA775 and the winding of R770 to the negative terminal of battery. Also, upon operating, the control relay R740 prepares, at RA743 and RC744, a circuit, traced hereinafter, for energizing the control relay R780, the latter circuit being completed at RA771 and RC773 upon operation of the control relay R770. The circuit for energizing the control relay R780 extends from the positive terminal of battery by way of RA721, RC723, RA771, RC773, RA743, RC744, the winding of R780 to the negative terminal of battery. Shortly after the control relay R780 is energized over the above-traced circuit, it operates to interrupt, at RC782 and RC783, an obvious path for short-circuiting the winding of the control relay R785 and to complete, at RA781 and RC782, an obvious circuit for energizing the winding of the control relay R785. Shortly after the control relay R785 is thus energized, the latter relay, being of the slow-to-operate type, operates to prepare, at RA787, a point in a circuit, traced hereinafter, for energizing the rotary magnet M793 and to complete, at RA786, a path for short-circuiting the winding of the control relay R780, this path extending from the positive terminal of battery by way of RA786, the winding of R780, RC744, RA743, RC773, RA771, RC723 and RA721 to the positive terminal of battery. When the above-traced path for short-circuiting the winding of the control relay R780 is completed, the latter relay restores to interrupt, at RA781 and RC782, the previously mentioned circuit for energizing the winding of the control relay R785; to complete, at RA782 and RC783, the previously mentioned path for short-circuiting the winding of the control relay R785; and to complete, at RA781 and RC784, the previously mentioned circuit for energizing the rotary magnet M793. The last-mentioned circuit extends from the positive terminal of battery by way of RA781, RC784, RA787

and the winding of M793 to the negative terminal of battery. When the above-traced path for short-circuiting the winding of the relay R785 is completed, the latter relay restores to interrupt, at RA786, the previously traced path for short-circuiting the winding of the relay R788, thereby to cause the previously traced circuit for energizing the winding of the relay R788 to be completed, whereupon the relay P788 reoperates. The control relays R788 and R785 interact, in the above-described manner, in order to cause the previously traced circuit for energizing the rotary magnet M793 to be repeatedly completed. Accordingly, the rotary magnet M793 is repeatedly operated and is effective to drive the wiper 781 of the minor switch 780 step by step in the clockwise direction.

Some time after the previously mentioned path for connecting the loop circuit 301 directly in the telegraph line 501 is completed, the wiper 781 of the minor switch 780 engages the contact in the associated contact bank 792 terminating the control conductor C712, thereby to complete a circuit for energizing the control relay R620, the latter circuit extending from the positive terminal of battery by way of RA741, C722, the wiper 781, the contact in the associated contact bank 792 terminating the control conductor C712, C712 and the winding of R620 to the negative terminal of battery. When energized over the above-traced circuit, the relay R620 operates to complete, at RA623 a holding circuit for energizing the winding thereof, the latter circuit extending from the positive terminal of battery by way of RA742, C714, RA623 and the winding of R620 to the negative terminal of battery. Also, upon operating the relay R620 interrupts, at RA621 and at RA622, points in the previously traced path for connecting the loop circuit 301 directly in the telegraph line 501, thereby to cause the line relays R318 and R710 in the selector switches 300 and 700, respectively, to restore.

Shortly thereafter the hold relay R320 in the selector switch 300 restores to complete, at RA321, the previously traced circuit for energizing the control relay R380, thereby to cause the latter relay to operate and initiate the timing operation, in the previously described manner. Also, shortly thereafter the hold relay R720 in the selector switch 700 restores to complete, at RA721 and RC722, an alternative circuit for energizing the control relay R780, the latter circuit extending from the positive terminal of battery by way of RA721, RC722, RA743, RC744, the winding of R780 and the resistor 788 to the negative terminal of battery. Accordingly, the control relays R780 and R785 continue to interact in the above described manner. Shortly thereafter the wiper 781 of the minor switch 780 is driven into engagement with the contact in the associated contact bank 792 terminating the control conductor C713, thereby to complete a path for short-circuiting the winding of the control relay R740, this path extending from the wiper 781 of the minor switch 780, the contact in the associated contact bank 792 terminating the control conductor C713, C713, the winding of R740 and C722 to the wiper 781. When the above-traced path for short-circuiting the winding of the control relay R740 is completed, the latter relay restores to interrupt, at RA741, a point in the previously mentioned holding circuit for energizing the winding thereof; to interrupt, at RA742, a point in the previously traced holding circuit for energizing the winding of the control relay R620 and to complete, at 75

RA743 and RC745, a circuit for energizing the release magnet M755. The last-mentioned circuit extends from the positive terminal of battery by way of RA721, RC722, RA743, RC745, the set of switch springs S736 and the winding of M755 to the negative terminal of battery. When energized over the above-traced circuit, the release magnet M755 operates to release the wiper set of the Strowger mechanism 680 included in the selector switch 700 and to cause this wiper set to be returned to its normal position. Also, upon operating, the release magnet M755 completes, at MA755, a holding circuit for energizing the winding thereof, this circuit extending from the positive terminal of battery by way of MA755, the set of switch springs S736 and the winding of M755 to the negative terminal of battery. When the wiper set of the Strowger mechanism 680 is returned to its normal position, the sets 20 of switch springs S761, S736 and S688 are actuated. More particularly, the set of switch springs S736 are actuated into disengagement, thereby to interrupt the previously traced holding circuit for energizing the winding of the release magnet 25 M755; and the set of switch springs S688 are actuated into disengagement, thereby to interrupt the previously traced holding circuit for energizing the control relay R770. When the previously traced circuit for energizing the control relay 30 R620 is interrupted at RA742, upon the restoration of the control relay R740, the relay R620 restores to recomplete, at RA621 and at RA622, the previously traced path for connecting the loop circuit 301 directly in the telegraph line 501. Upon restoring, the control relay R770 prepares, at RA771 and RC772, a circuit, traced herein-after, for energizing the release magnet M794.

When the previously traced path for connecting the loop circuit 301 directly in the telegraph line 501 is recompleted, at RA621 and RA622, upon the restoration of the control relay R620, the line relays R310 and R710 in the selector switches 300 and 700, respectively, reoperate, thereby to cause the hold relays R320 and R720 to reoperate. Upon reoperating, the hold relay R720 completes, at RA721 and RC723, a circuit for energizing the release magnet M794, this circuit extending from the positive terminal of battery by way of RA721, RC723, RA771, RC772, the set of switch springs S795 and the winding of M794 to the negative terminal of battery. When energized over the above-traced circuit, the release magnet M794 operates to release the wiper 791 of the minor switch 790, thereby to cause the wiper 791 to be returned to its normal position, whereupon the set of switch springs S795 are actuated into disengagement, thereby to interrupt the previously traced circuit for energizing the release magnet M794. At this time the Strowger mechanism 680 included in the selector switch 700 occupies its normal position and only the control relay R610 in the selector switch 700 occupies an operated position.

Upon reoperating, the hold relay R320 in the selector switch 300 completes, at RA321 and RC323, the previously traced circuit for energizing the release magnet M394, thereby to cause the release magnet M394 to operate and release the wiper 391 of the minor switch 390, whereupon the wiper 391 is restored to its normal position. It is noted that the wiper 391 of the minor switch 390 is restored to its normal position before the contact in the associated contact bank 392 terminating the control conductor C312 is engaged thereby. Accordingly, the control relay R420 is not energized at this time. When the previously

traced path for connecting the loop circuit 301 directly in the telegraph line 501 is recompleted, the repeater 100 operates to cause the circuit including the telegraph line 101 to be recompleted, thereby to cause the supervisory lamp associated with the selector switch 800 included in the terminal station S to be extinguished. When this supervisory lamp is extinguished, the operator at the terminal station S is advised that one of the telegraph lines 501 or 502 extending to the terminal station E has been seized and that the second-mentioned two predetermined digits may be dialed in order to cause the selector switch associated with the seized telegraph line included in the terminal station E to operate and initiate the operation of the printing mechanism included in the terminal station E and associated with the seized telegraph line 501 or 502.

The operator at the terminal station S then dials the second-mentioned two digits at the dial mechanism 811 thereat, thereby to cause two corresponding series of impulses to be transmitted over the circuit including the telegraph line 101. The repeater 100 operates, in the previously described manner, in order to repeat the two series of impulses comprising the two digits dialed over the loop circuit 301 and consequently over the telegraph line 501. Each of the selector switches included in the stations associated with the telegraph line 501, and including the selector switch 700 in the central switching station C and the selector switch included in the terminal station E and associated with the telegraph line 501, is operated in accordance with the two digits dialed. Also, each of the selector switches included in the stations associated with the telegraph line 101 is operated in accordance with the two digits dialed. However, only the wiper set of the Strowger mechanism in the selector switch included in the terminal station and associated with the telegraph line 501 engages a contact set in the associated contact bank terminating a line, as previously noted. More particularly, the wiper set of the Strowger mechanism in the last-mentioned selector switch engages a contact set in the associated contact bank terminating the printing line extending to the associated printing mechanism included in the terminal station E. The last-mentioned selector switch then switches through to seize this printing line and connect the printing magnet associated therewith and included in the printing mechanism directly in the telegraph line 501. Also, this selector switch operates to return the answer-back signal over the telegraph line 501 and the loop circuit 301 connected therein. When the answer-back signal is returned over the telegraph line 501, the selector switches included in the stations associated with the telegraph line 501, with the exception of the seized selector switch included in the terminal station E, are released. Furthermore, the repeater 100 repeats the answer-back signal over the circuit including the telegraph line 101, thereby to cause the selector switches in the stations associated with the telegraph line 101 to be released, in the previously described manner.

The operator at the terminal station S then dials the two digits comprising the lockout number, thereby to transmit two corresponding series of impulses over the circuit including the telegraph line 101 and cause the repeater 100 to repeat these two series of impulses over the loop circuit 301 and consequently the circuit including the telegraph line 501, whereupon each of the non-

- operated selector switches included in the stations associated with the telegraph lines 101 and 501 is operated to its lockout position in the previously described manner. At this time the established connection between the terminal stations S and E and routed therebetween by way of the telegraph line 101, the repeater 100, the selector switch 300, the selector switch 700 and the telegraph line 501 is completed. The operator at the 10 terminal station S then operates the transmitting mechanism 812 therein, thereby to cause telegraphic impulses to be transmitted over the circuit including the telegraph line 101 and to be repeated by the repeater 100 over the circuit including the telegraph line 501. The printing mechanism included in the terminal station E operates in response to the telegraphic impulses transmitted thereto, thereby to print the telegraphic message.
- 20 The release of the established connection between the terminal stations S and E may be effected by the operator at the terminal station S by operating the key switch 814 thereat in order to cause the circuit including the telegraph line 101 to be interrupted for a predetermined time interval. The release of the operated apparatus associated with the telegraph lines 101 and 501 is effected in the manner previously described. From the foregoing description of the operation 30 of the apparatus in setting up and in releasing an established connection between the terminal stations S and E and routed therebetween by way of the telegraph line 101, the repeater 100, the selector switch 300, the selector switch 700 and the telegraph line 501, it will be understood that a connection from either of the terminal stations N or S may be completed in a similar manner to either of the terminal stations E or W. More particularly, a connection between 40 either of the terminal stations N or S may be routed to either of the terminal stations E or W by way of the telegraph line 101, the repeater 100 and the selector switch 300 and therefrom by way of the selector switch 700 and the telegraph line 501 to the terminal station E or W, or from the selector switch 300 by way of the selector switch 520 and the telegraph line 502 to the terminal stations E or W; and a connection between either of the terminal stations N or S may be 50 routed to either of the terminal stations E or W by way of the telegraph line 102, the repeater 105 and the selector switch 510 and therefrom by way of the selector switch 700 and the telegraph line 501 to the terminal station E or W. or from the selector switch 510 by way of the selector switch 520 and the telegraph line 502 to the terminal stations E or W. Also, it will be understood that a connection from either the terminal stations E or W may be extended to 60 either of the terminal stations N or S. More particularly, a connection between either the terminal stations E or W may be routed to either of the terminal stations N or S by way of the telegraph line 501 and the selector switch 700 and therefrom by way of the selector switch 300, the repeater 100 and the telegraph line 101 to the terminal station N or S, or from the selector switch 700 by way of the selector switch 510, the repeater 105 and the telegraph line 102 to the 70 terminal station N or S; and a connection between either of the terminal stations E or W may be routed to either of the terminal stations N or S by way of the telegraph line 502 and the selector switch 520 and therefrom by way of the selector switch 300, the repeater 100 and the

telegraph line 101 to the terminal station N or S, or from the selector switch 520 by way of the selector switch 510, the repeater 105 and the telegraph line 102 to the terminal station N or S.

Extending connections from the stations N or S to the stations C and W or E

A connection from one station on a given telegraph line may be extended to two or more stations associated with the same line; and this may be done even though the connection involves interconnected telegraph lines. For example, a connection from the terminal station S associated with the telegraph line 101 may be extended to the central switching station C and the terminal station E associated with the telegraph line 501. In order to set up this connection, the operator at the terminal station S operates the dial mechanism 811 thereat in order to cause the selector switch 300, associated by way of the repeater 100 with the telegraph line 101, to seize the selector switch 700 associated with the telegraph line 501 in the previously described manner. After the selector switches 300 and 700 have operated in the previously described manner in order to connect the loop circuit 301 directly in the telegraph line 501, the apparatus is in condition to be responsive to two series of digits in order to cause the selector switch 700 to seize a printing line extending to an idle printing mechanism in the central switching station C. More particularly, the operator at the terminal station S then dials the two predetermined digits mentioned at the dial mechanism 811, thereby to cause the two predetermined series of impulses to be transmitted over the circuit including the telegraph line 101 and to be repeated, by way of the repeater 100, to the loop circuit 301 and consequently the telegraph line 501, in the previously described manner. The selector switches associated with the telegraph lines 101 and 501 follow the two predetermined digits mentioned. However, at the conclusion of the two digits, only the wiper set of the Strowger mechanism 680 in the selector switch 700 engages a contact set terminating a line, as previously noted. More particularly, the wiper set of the Strowger mechanism 680 in the selector switch 700 engages the printing line extending to the first printing mechanism 490 in the central switching station C. Subsequent operation of the selector switch 700 depends upon the idle or busy condition of the first printing mechanism 490. In the event the first printing mechanism 490 is idle, the selector switch 700 switches through, and in the event the first printing mechanism 490 is busy, the selector switch 700 operates as a trunk hunting switch to hunt for a printing line extending to an idle printing mechanism. In the event a printing line extending to an idle printing mechanism is found, the selector switch 700 switches through; and in the event there is no idle printing mechanism in the group of printing mechanisms included in the central switching station C, the selector switch 700 operates to cause the busy signal to be returned over the loop circuit 301 and repeated therefrom by the repeater 100 over the circuit including the telegraph line 101. Upon switching through, the selector switch 700 returns the answer-back signal over the loop circuit 301 and consequently over the telegraph line 101 which is repeated by the repeater 100 over the telegraph line 101. When the answer-back signal is repeated over the telegraph lines 101 and 501, the selector switches included in the sta-

tions associated therewith are released, in the previously described manner. Subsequently, the operator at the terminal station S then dials at the dial mechanism 811 two additional predetermined digits, thereby to cause two additional series of impulses to be transmitted over the circuit including the telegraph line 101 and to be repeated by the repeater 100 over the loop circuit 301 and consequently over the telegraph line 501. The selector switches included in the stations associated with the telegraph lines 101 and 501 follow the two additional digits and, at the conclusion thereof, only the wiper of the Strowger mechanism in the selector switch included in the terminal station E and associated with the telegraph line 501 engages a contact set in the associated contact bank terminating a line. More particularly, the last-mentioned wiper set engages the line extending to the printer in the terminal station E. Subsequently, the last-mentioned selector switch operates to return the answer-back signal over the telegraph line 501, thereby to cause the repeater 100 to return the answer-back signal over the telegraph line 101. When the answer-back signal is returned over the telegraph lines 501 and 101, the non-operated selector switches included in the stations associated with these lines are released. Finally, the operator at the terminal station S operates the dial mechanism 811 thereat to transmit two further series of impulses comprising the two digits of the lockout number over the circuit including the telegraph line 101, thereby to cause the repeater 100 to repeat the two series of impulses over the loop circuit 301 and consequently over the telegraph line 501. The nonoperated selector switches included in the stations associated with the telegraph lines 101 and 501 follow the impulses comprising the two digits of the lockout number and at the conclusion thereof occupy their lockout positions. The operator at the terminal station S then operates the transmitting mechanism 812 thereat, thereby to transmit telegraphic impulses over the circuit including the telegraph line 101, which telegraphic impulses are repeated by the repeater 100 over the loop circuit 301 and consequently over the telegraph line 501. The telegraphic impulses transmitted over the telegraph line 501 cause the printing mechanism seized by the selector switch 700 and the printing mechanism seized by the selector switch included in the terminal station E and associated with the telegraph line 501 to operate, in the previously described manner, in order to print the telegraphic message.

More particularly, the selector switch 700 operates to select an idle printing mechanism in the group of printing mechanisms included in the central switching station C in response to the second two digits dialed by the operator at the terminal station S at the dial mechanism 811 and subsequent to the operation of the selector switches 300 and 700 to connect the loop circuit 301 directly in the telegraph line 501. More specifically, when the repeater 100 operates at the beginning of the first impulse of the first of these digits, the loop circuit 301 is interrupted, thereby to cause the line relays R310 and R710 included in the selector switches 300 and 700, respectively, to restore. Upon restoring, the line relay R710 interrupts, at RA711 and RC712, the previously mentioned circuit for energizing the hold relay R720 and completes, at RA711 and RC713, the previously traced original circuit for energizing in series the control relay R720 and

the vertical magnet M720. Upon restoring, the line relay R310 interrupts, at RA311 and RC312, the previously mentioned circuit for energizing the hold relay R320. However, no circuit is completed at RA311 and RC313 due to the fact that the switch springs S364 and S366 of the set of switch springs S367 have been actuated into disengagement and the control relay R360 has previously restored. Accordingly, the selector switch 300 does not respond to these two series of digits 10 dialed.

When the previously traced circuit for energizing in series the control relay R730 and the vertical magnet M757 is completed, the control relay R730 operates, in the previously described manner, and the vertical magnet M757 operates to drive the wiper set of the Strowger mechanism 680 included in the selector switch 700 one step in the vertical direction. The operation of the selector switch 700 in response to the first series 20 of digits dialed therewith is similar to the operation of the selector switch 300 previously described. At the conclusion of this first series of digits, the wiper set of the Strowger mechanism 680 occupies a vertical position corresponding to 25 the digit dialed. Also, the operation of the selector switch 700 in response to this second series of digits dialed therewith is similar to the operation of the selector switch 300 previously described; and at the conclusion of this second 30 series of digits, the wiper set of the Strowger mechanism 680 engages the contact set in the associated contact bank terminating the printing line extending to the first printing mechanism 490. More particularly, the wipers 681 and 682 35 of this wiper set engage the contacts in the associated contact bank terminating the line conductors C561 and C562, respectively, of the printing line extending to the first printing mechanism 490; the wiper 683 engages the contact in the 40 associated contact bank terminating the control conductor C563 of this printing line; while the wiper 684 engages the contact in the associated contact bank which is connected to the contact terminating the control conductor C563. 45

The subsequent operation of the selector switch 700 depends upon the idle or busy condition of the printing line extending to the first printing mechanism 490. Assuming that the first printing mechanism 490 is busy, positive battery potential appears upon the control conductor C563, thereby to complete a circuit for energizing the test relay R650, this circuit extending from the positive terminal of battery appearing upon the control conductor C563 of the printing line extending to the first printing mechanism 490 by way of the contact in the associated contact bank terminating the control conductor C563, the wiper 683, RA663, RC664, RA676 and the winding of R650 to the negative terminal of 50 battery. When energized over the above-traced circuit, the test relay R650 operates to complete, at RA654, a circuit for energizing the control relay R750, this circuit extending from the positive terminal of battery appearing upon the control conductor C563 by way of the contact in the contact bank terminating the control conductor C563, the contact in the associated contact bank engaged by the wiper 684 and connected to the first-mentioned contact, RA667, RA654, C719, 70 RA763, MA756 and the winding of R750 to the negative terminal of battery. When energized over the above-traced circuit, the control relay R750 operates, thereby to cause the rotary magnet M756 to be reenergized whereupon the wiper 75

set of the Strowger mechanism 680 is driven an additional step in the radial direction, in a manner similar to that previously explained in connection with the operation of the selector switch 300. The test relay R650, the control relay R750 and the rotary magnet M756 interact in the manner previously explained in connection with the description of the operation of the selector switch 300, thereby to cause the wiper set of the Strowger mechanism 680 to be driven step by step in the radial direction in order to successively test the printing lines extending to the printing mechanisms in the central switching station C. When a printing line extending to an idle printing mechanism is tested, the selector switch 700 switches through in a manner more fully described subsequently; and in the event there is no idle printing mechanism in the group of printing mechanisms included in the central switching station C when the printing line is extending to the last busy printing mechanism in this group of printing mechanisms is tested, the busy relay R630 is caused to operate in order to cause the busy signal to be returned over the loop circuit 301, in a manner similar to that previously described in connection with the operation of the selector switch 300.

Assuming that the printing line extending to the first printing mechanism 490 is idle, at this time, a path is completed for short-circuiting the winding of the test relay R650, this path extending from negative battery potential appearing upon the control conductor C563 by way of the contact in the contact bank terminating the control conductor C563, the associated wiper 683, RA663, RA664, RA676 and the winding of R650 to the negative terminal of battery. Accordingly, the previously traced circuit for energizing the control relay R750 is not completed and further movement of the wiper set of the Strowger mechanism 680 is arrested. Shortly following the conclusion of the second digit, the control relay R660 restores to complete, at RA663 and RC666, a circuit for energizing the lower winding of the switch-through relay R670, this circuit extending from negative battery potential appearing upon the control conductor C563, the contact in the contact bank terminating the control conductor C563, the associated wiper 683, RA663, RC666, the lower winding of R670, RC653, RA651, RA625 and the set of switch springs S688 to the positive terminal of battery. When energized over the above-traced circuit, the switch-through relay R670 partially operates to close the "X" contacts associated with the armature RA670, thereby to complete a holding circuit for energizing the upper winding thereof, this circuit extending from the positive terminal of battery by way of the set of switch springs S688, RA625, RA624, RA670 and the upper winding of R670 to the negative terminal of battery. When the above-traced holding circuit for energizing the upper winding of the switch-through relay R670 is completed, the latter relay operates fully to complete, at RA671, an obvious path for applying positive battery potential to the wiper 683; to interrupt, at RA679, a point in the circuit for energizing the release magnet M755; to interrupt, at RA676, a point in the previously traced circuit for energizing the test relay R650; and to prepare, at RA675, a point in a circuit, traced hereinafter, for energizing the control relay R640. Also, upon operating, the switch-through relay R670 interrupts, at RA671 and at RA672 and RC673, points in the previously traced path

for connecting the loop circuit 301 in the telegraph line 501; and to prepare, at RA672 and RC674, a point in a circuit, traced hereinafter, for including the winding of the printing magnet PM491 in the telegraph line 501.

When the previously traced path for connecting the loop circuit 301 in the telegraph line 501 is interrupted at RA671 and at RA672 and RC673 upon the operation of the switch-through relay R670, the line relays R310 and R710 in the selector switches 300 and 700, respectively, restore, thereby to cause the hold relays R320 and R720, respectively, to restore shortly thereafter. Upon restoring, the hold relay R320 completes the previously traced circuit for energizing the control relay R380, thereby to cause the latter relay to operate and initiate the timing operation whereupon the wiper 391 of the minor switch 390 is driven step by step in the clockwise direction. In a similar manner, when the hold relay R720 restores, it completes, at RA721 and RC722, a circuit for energizing the control relay R780, thereby to cause the latter relay to operate and initiate a timing operation, whereupon the wiper 791 of the minor switch 790 is driven step by step in the clockwise direction, in a manner similar to that described in connection with the operation of the minor switch 390. This interruption of the loop circuit 301 causes the repeater 100 to operate and interrupt the circuit including the telegraph line 101 which constitutes an answer-back signal, thereby to indicate to the operator in the terminal station S that the selector switch 100 has operated to seize an idle printing mechanism in the central switching station C.

Shortly after the operation of the minor switch 790 is initiated, the wiper 791 engages the contact in the associated contact bank 792 terminating the control conductor C711, whereupon a circuit for energizing the control relay R640 is completed. The last-mentioned circuit extends from the positive terminal of battery by way of RA741, C722, the wiper 791, the contact in the associated contact bank 792 terminating the control conductor C711, C711, RA675 and the winding of R640 to the negative terminal of battery. When energized over the above-traced circuit, the control relay R640 operates to complete, at RA643, a holding circuit for energizing the winding thereof, the latter circuit extending from the positive terminal of battery by way of the set of switch springs S688, RA625, RA643, RA675 and the winding of R640 to the negative terminal of battery. Also, upon operating, the relay R640 completes, at RA641 and at RA642, a circuit for connecting the winding of the printing magnet PM491 in series with the loop circuit 301 and the telegraph line 501. The last-mentioned circuit extends by way of the previously traced circuit to the portion of the telegraph line 501 extending into the selector switch 700, RA641, RA621, RA611, RC613, RA604 and RC605 to the line conductor C547 of the trunk line 545; and from the line conductor C547 by way of the previously traced circuit including the looper circuit 301 to the line conductor C546 of the trunk line 545; and from the line conductor C546 by way of RC602, RA601, RC616, RA614, RA632, RA672, RC674, the wiper 681, the contact in the associated contact bank terminating the line conductor C561, C561, the winding of the printing magnet PM491, the line conductor C562, the contact in the contact bank terminating the line conductor C562, the associated wiper 682, 75

RAG42, RAG22 and the winding of the line relay R710 to the portion of the telegraph line 581 extending from the selector switch 100.

When the above-traced circuit for connecting the printing magnet PM481 and the loop circuit 301 in series with the telegraph line 501 is completed, the line relays R310 and R710 included in the selector switches 300 and 700, respectively, are reenergized and reoperate. Upon reoperating, the line relays R310 and R710 cause the hold relays R320 and R720, respectively, to reoperate, in the previously described manner. Upon reoperating, the hold relay R320 completes, at RA321 and RC323, the previously traced circuit for energizing the release magnet M394, thereby to cause the release magnet M394 to operate and release the wiper 391 of the minor switch 390, whereupon the wiper 391 is returned to its normal position. Similarly, when the hold relay R720 reoperates, it completes, at RA721 and RC723, the previously traced circuit for energizing the release magnet M794, thereby to cause the release magnet M794 to operate and release the wiper 791 of the minor switch 780, whereupon the wiper 791 is returned to its normal position. Also, when the above-traced circuit for connecting the printing magnet PM481 and the loop circuit 301 in series with the telegraph line 501 is completed, the repeater 100 operates to recomplete the circuit including the telegraph line 101. When the circuit including the telegraph line 101 is recompleted, the return of the answer-back signal thereover is terminated and the supervisory lamp associated with the selector switch 800 included in the terminal station S is extinguished. The operator at the terminal station S then proceeds to dial the two additional digits in order to cause the selector switch included in the terminal station E and associated with the telegraph line 501 to operate and seize the printing mechanism in the terminal station E and associated with the telegraph line 501. The remaining operation of the apparatus is the same as that previously described in connection with the extension of a connection directly from the terminal station S to the terminal station E. Also, the release of this established connection between the terminal station S and the central switching station C and the terminal station E is the same as that previously described, the release of the apparatus included in this established connection being the same as that previously described and being effected when the operator at the terminal station S operates the key switch 814 thereat to interrupt the circuit including the telegraph line 101 for a predetermined time interval.

From the foregoing description of the operation of the selector switch 700 to select an idle one of the printing mechanisms included in the central switching station C while the selector switch 700 is included in a connection established between the telegraph lines 101 and 501, it will be understood that when the selector switch 700 is included in an established connection between the telegraph lines 102 and 501, that it is operative to select an idle one of the printing mechanisms included in the central switching station C. Similarly, it will be understood that when the selector switch 520 is included in an established connection between the telegraph lines 101 or 102 and the telegraph line 502, it is operative to select an idle one of the printing mechanisms included in the central switching station C. Similarly, it will be understood that when the

selector switch 300 is included in an established connection extending between one of the telegraph lines 501 or 502 and the telegraph line 101, that the selector switch 300 is operative to select an idle one of the printing mechanisms included in the central switching station C; and when the selector switch 510 is included in an established connection extending between one of the telegraph lines 501 or 502 and the telegraph line 102, that the selector switch 510 is operative to select an idle one of the printing mechanisms included in the central switching station C.

Extending connections from the stations E, W, N, S or C to the station X

A connection which is to be extended from the terminal stations N or S to the terminal station X must be routed thereto by way of the telegraph line 101 in view of the fact that the selector switch 300 associated by way of the repeater 100 with the telegraph line 101 has access to the telegraph line 601 extending to the terminal station X; while the selector switch 510 associated by way of the repeater 105 with the telegraph line 102 does not have access to the telegraph line 601 extending to the terminal station X. Similarly, a connection which is to be extended from either the terminal stations E or W to the terminal station X must be routed thereto by way of the telegraph line 502 for a like reason. However, a connection which is to be extended from the central switching station C to the terminal station X may be routed thereto by way of either of the telegraph lines 102 or 502. For example, in order to extend a connection from the central switching station C by way of the telegraph line 101 to the terminal station X, the operator at the central switching station C first inserts the plug of one of the dial-transmitting-printing mechanisms included in the central switching station C into the jack 103 arranged in the telegraph line 101. Assuming that the plug 105 of the dial-transmitting-printing mechanism 160 included in the central switching station C is inserted into the jack 103, the operator at the central switching station C then operates the key switch 167 and the dial mechanism 161, in the previously described manner. First, the key switch 167 is operated to interrupt the circuit including the telegraph line 101 for a predetermined time interval, thereby to insure that the selector switch 300 initially occupies its normal position. Subsequently, the dial mechanism 161 is operated, thereby to transmit two predetermined series of impulses comprising two digits over the circuit including the telegraph line 101. The repeater

100 operates, in the previously described manner, in order to repeat the impulses comprising the two digits to the selector switch 300, whereupon the Strowger mechanism 480 included in the selector switch 300 operates to test the idle or busy condition of the telegraph line 601 extending to the terminal station X. In the event the telegraph line 601 is busy, the selector switch 300 operates to cause the busy signal to be transmitted over the loop circuit 301 and repeated by the repeater 100 over the circuit including the telegraph line 101. In the event the telegraph line 601 is idle, the selector switch 300 switches through to cause the answer-back signal to be returned over the loop circuit 301 and repeated by the repeater 100 over the circuit including the telegraph line 101. The return of the answer-back signal over the circuit including the tele- 75

graph line 101, causes the remainder of the selector switches included in the stations associated with the telegraph line 101 to be released. Also, the return of the answer-back signal over the loop circuit 301 causes the supervisory lamp L388 associated with the selector switch 300 to be illuminated, thereby to indicate to the operator at the central switching station C that the telegraph line 601 has been selected. Subsequently, the selector switch 300 operates to terminate the return of the answer-back signal over the loop circuit 301, thereby to cause the supervisory lamp L388 to be extinguished.

15 The operator at the central switching station C then actuates the dial mechanism 161 thereat, thereby to transmit the two series of impulses comprising two predetermined digits by way of the previously traced connections over the telegraph line 601 in order to cause the selector switch in terminal station X associated with telegraph line 601 to operate and seize the printing mechanism in the terminal station X in the manner previously described. When the selector switch in the terminal station X operates to seize the printing mechanism as noted above it operates to cause the answer-back signal to be returned over the telegraph line 601 in the previously described manner.

20 The operator at the central switching station C then actuates the dial mechanism 161 thereat, thereby to transmit the two series of impulses comprising the two digits of the lockout number over the circuit including the telegraph line 101 in order to cause the nonoperated selector switches associated with the telegraph line 101 to be operated to their lockout positions. The two series of impulses comprising the two digits of the lockout number are repeated by the repeater 100 over the loop circuit 301 and consequently over the telegraph line 601, thereby to cause the nonoperated selector switches in the stations associated with the telegraph line 601 to be operated to their lockout positions.

25 Finally, the operator at the central switching station C operates the transmitting mechanism 162 thereat, thereby to cause telegraphic impulses to be transmitted over the circuit including the telegraph line 101. These telegraphic impulses are repeated by the repeater 100 over the loop circuit 301 and consequently over the telegraph line 601, thereby to cause the seized printing mechanism included in the terminal station X to operate and print the telegraphic message.

30 More particularly, when the two series of impulses comprising the first two mentioned digits are repeated by the repeater 100 to the loop circuit 301, the selector switch 300 operates in the previously described manner, thereby to cause the wiper set of the Strowger mechanism 480 included in the selector switch 300 to engage the contact set in the associated contact bank terminating the telegraph line 601. More particularly, at this time the wipers 481 and 482 of the wiper set engage the contacts in the associated contact bank respectively terminating the telegraph line 601 and the conductor connected by way of the resistor 403 to the negative terminal 60 of battery; while the wiper 483 engages the contact in the associated contact bank terminating the control conductor C601' of the telegraph line 601. Also, it is noted that the sets of contact springs S485 and S487 are associated with the level in the contact bank of the Strowger mech-

anism 400 wherein the telegraph line 601 is terminated and that these sets of contact springs are actuated when the wiper set of the Strowger mechanism is moved vertically to the corresponding level. More particularly, the set of switch spring S487 is actuated into engagement, thereby to complete the previously traced holding circuit for energizing the winding of the control relay R400; and the set of switch springs S485 is actuated into engagement, thereby to 10 prepare the previously traced circuit for energizing the winding of the control relay R410, the circuit for energizing the winding of the control relay R410 being interrupted, at this time, at the armature RA478 of the switch-through relay R470. In the event the telegraph line 601 is busy, positive battery potential appears upon the control conductor C601' thereof, thereby to complete the previously traced circuit for energizing the test relay R450. The test 15 relay R450 then operates, in the previously described manner, thereby to cause the busy relay R430 to operate and return the busy signal over the loop circuit 301, as previously explained. 20 In the event the telegraph line 601 is idle, negative battery potential appears upon the control conductor thereof, thereby to complete the previously traced path for short-circuiting the winding of the test relay R450. Shortly after the conclusion of the second digit dialed, the control relay R460 restores to complete the previously traced circuit for energizing the lower winding of the switch-through relay R470, as previously explained. 25 The switch-through relay R470 then operates in the previously described manner in order to interrupt, at RA471 and at RA472 and RC473, points in the loop circuit 301; to prepare, at RA472 and RC474, a point in a circuit, traced hereinafter, for connecting the loop circuit 301 to the telegraph line 601; and to complete, at 30 RA478, the previously traced circuit for energizing the control relay R410, thereby to cause the latter relay to operate. Upon operating, the control relay R410 interrupts, at RA411 and RC412 and at RA414 and RC415, additional points in the 35 loop circuit 301 and prepares, at RA411 and RC413 and at RA414 and RC416, two points in the previously mentioned circuit for connecting the loop circuit 301 to the telegraph line 601. The interruption of the loop circuit 301 constitutes 40 an answer-back signal which is repeated by the repeater 100 over the circuit including the telegraph line 101, as previously explained. Also, when the loop circuit 301 is interrupted, the line relay R310 restores and causes the hold relay 45 R320 to restore shortly thereafter. Upon restoring, the hold relay R320 completes, at RA321 and RC322, the previously traced circuit for energizing the control relay R380, thereby to cause the latter relay to operate and initiate the timing 50 operation. The control relays R380 and R385 interact, in the previously described manner, thereby to cause the rotary magnet M393 to operate repeatedly and drive the wiper 391 of the minor switch 390 step by step in the clockwise direction, 55 as previously noted. When the wiper 391 of the minor switch 390 is driven into engagement with the contact in the associated contact bank 392 terminating the control conductor C311, the previously traced circuit for energizing the control 60 relay R440 is completed, which latter relay operates to complete, at RA443, the previously traced holding circuit for energizing the winding thereof. Also, upon operating, the control relay R440 completes, at RA441 and at RA442, the 65 70 75 80 85 90 95 100

previously mentioned circuit for connecting the loop circuit 301 to the telegraph line 601, and completes, at RA445, the previously traced circuit for illuminating dimly the supervisory lamp L388 after the termination of the return of the answer-back signal over the loop circuit 301.

At this time the telegraph line 601 and the loop circuit 301 are included in series circuit relationship, the circuit extending from the positive terminal of battery connected to one end of the telegraph line 601 by way of the telegraph line 601 to the contact in the contact bank terminating the telegraph line 601 and engaged by the associated wiper 481, the wiper 481, RC474, RA472, RA432, RA414, RC416, RA401, RC403, RC413, RA411, RA421, RA441, C382, the lower windings of the relays R310 and R400, C383, the winding of the line relay R310, C310, RA422, RA442, the wiper 482, the contact in the associated contact bank terminating the conductor extending to the resistor 403, and the resistor 403 to the negative terminal of battery. When the above-traced circuit for connecting the loop circuit 301 to the telegraph line 601 is completed, the line relay R310 reoperates and causes the hold relay R320 to reoperate. Upon reoperating, the control relay R320 interrupts, at RA321 and RC322, the previously traced circuit for energizing the control relay R380, thereby to cause the latter relay to restore and arrest the timing operation. Also, upon operating, the hold relay R320 completes, at RA321 and RC322, the previously traced circuit for energizing the release magnet M394, thereby to cause the minor switch 390 to be released in the previously described manner.

While the answer-back signal is returned over the loop circuit 301, the line relay R310 occupies its restored position, thereby to complete, at RA314, the previously mentioned circuit for illuminating the supervisory lamp L388 in order to indicate to the operator at the central switching station C that the selector switch 300 has operated to select the telegraph line 601. When the return of the answer-back signal over the loop circuit 301 is terminated, the line relay R310 reoperates, as previously noted, thereby to interrupt, at RA314, the previously mentioned circuit for illuminating the supervisory lamp L388, whereupon the lamp L388 is illuminated dimly. This illumination of the supervisory lamp L388 is effective to indicate to the operator at the central switching station C that the connection has been established from the central switching station C to the terminal station X and that the telegraph line 101 is busy. The operator at the central switching station C then dials the two digits comprising the lockout number, in the previously described manner, in order to cause the nonoperated selector switches included in the stations associated with the telegraph lines 101 and 601 to be operated to their lockout positions, as previously noted. The operator at the central switching station C then operates the transmitting mechanism 162, thereby to transmit telegraphic impulses over the circuit including the telegraph line 101. The repeater 100 operates to repeat the telegraphic impulses over the loop circuit 301 and consequently over the telegraph line 601, thereby to cause the selected printing mechanism included in the terminal station X to operate and print the telegraphic message.

The release of this established connection between the central switching station C and the

terminal station X is the same as that previously described and is effected when the operator at the central switching station C operates the key switch 107 thereat in order to interrupt the circuit including the telegraph line 101 for a predetermined time interval.

From the foregoing description of the operation of the apparatus to establish and to release a connection from the central switching station C to the terminal station X, it will be understood that a connection may be extended in a similar manner from either one of the terminal stations N or S by way of the telegraph line 101 to the terminal station X. Also, it will be understood that a connection may be extended in a similar manner from the central switching station C or from one of the terminal stations E or W by way of the telegraph line 502 to the terminal station X. However, it is noted that when a connection is extended by way of the telegraph line 502 to the terminal station X, the connection is routed from the telegraph line 502 by way of the selector switch 520 and the repeater 570 to the telegraph line 601.

More particularly, the selector switch 520 is so controlled that it operates to seize the trunk line 571 extending to the repeater 570, assuming that the telegraph line 601 is idle at this time. The selector switch 520 then returns the answer-back signal over the telegraph line 502 in the previously described manner. Subsequently, the selector switch 520 switches through to complete a path for including the trunk line 571 in the circuit including the telegraph line 502, whereupon the relay R580 included in the trunk line 571 operates. More particularly, the circuit for energizing the relay R580 extends from the seized line conductor C572 of the trunk line 571 by way of the winding of R580, RC584 and RA583 to the seized line conductor C573 of the trunk line 571. When energized over the above-traced circuit, the relay R580 operates first to close the "X" contacts associated with the armature RA581, thereby to connect the telegraph line 601 into the portion 570A of the repeater 570. Also, the relay R580 then completes, at RA582 and RA583, a connection between the trunk line 571 and the portion 570B of the repeater 570; and interrupts, at RA583 and RC584, the previously traced original circuit for energizing the relay R580. It is noted that the repeater 570 is connected and arranged in a manner similar to the repeater 100. Accordingly, initially the portion 570A thereof is open and the portion 570B thereof is closed in the event the last connection established between the telegraph lines 502 and 601 was released by interrupting, for a predetermined time interval, the circuit including the telegraph line 502. On the other hand, initially the portion 570A of the repeater 570 is closed and the portion 570B thereof is open in the event the last connection established between the telegraph lines 502 and 601 was released by interrupting, for a predetermined time interval, the circuit including the telegraph line 601, as previously explained.

Accordingly, in the event the portions 570A and 570B of the repeater 570 are initially closed and open, respectively, when the relay R580 operates, it completes, at RA581, a circuit including the telegraph line 601, this circuit extending from the positive terminal of battery at the terminal station X by way of the selector switch therein, the telegraph line 601, RA581, the portion 570A of the repeater 570 and the resistor 582 to the 73

- negative terminal of battery. When this circuit is completed, the repeater 570 operates immediately to close the portion 570B thereof, as previously explained. Accordingly, when the relay 5 R580 completes, at RA582 and RA583, the connection between the trunk line 571 and the portion 570B of the repeater 570, the relay R580 and the portion 570B of the repeater 570 are included in a path extending from the seized 10 line conductor C572 of the trunk line 571 by way of the winding of R580, the portion 570B of the repeater 570, RA582 and RA583 to the seized line conductor C573 of the trunk line 571, the trunk line 571 being included in the circuit 15 including the telegraph line 502, as previously noted.

- On the other hand, in the event the portions 570A and 570B of the repeater 570 are initially open and closed, respectively, when the relay 20 R580 operates to complete, at RA582 and RA583, the previously traced path for including the winding of the relay R580 and the portion 570B of the repeater 570 in the trunk line 571, the repeater 570 immediately operates to close the 25 portion 570A thereof whereupon the circuit including the telegraph line 601 is completed, this circuit being initially prepared at RA581, as previously noted.

- Accordingly, at this time, the circuit including 30 the telegraph line 502 and the circuit including the telegraph line 601 are interconnected by way of the portions 570A and 570B, respectively, of the repeater 570. Hence, the dialed impulses and subsequently the telegraphic 35 impulses transmitted over the circuit including the telegraph line 502 are repeated by the repeater 570 over the circuit including the telegraph line 601, thereby to cause the selector switch and the printing mechanism, respectively, included in the terminal station X to operate, the printing mechanism being effective to print the telegraphic message in the previously described manner. Moreover, it is noted that the relay R580 included in the trunk line 571 does 40 not follow the dialed and telegraphic impulses transmitted thereover due to the fact that the latter relay is of the slow-to-release type.

Release of a selector switch operated to select an inaccessible line

- 50 As previously noted, certain of the selector switches are provided with arrangements for preventing these selector switches from having access to certain of the telegraph lines. More particularly, the selector switches 510 and 700 individually associated with the telegraph lines 102 and 501, respectively, do not have access to the telegraph line 601 and an arrangement is included in each of these selector switches for causing the associated selected switch to be released 55 in the event the selector switch is inadvertently operated to select the telegraph line 601, which telegraph line is inaccessible to the associated switch. For example, assuming that the operator at the central switching station C should seize the selector switch 700 associated with the telegraph line 501 by inserting the plug 105 of the dial-transmitting-printing mechanism 160 at the central switching station C into the Jack 503 included in the telegraph line 501 and then dial at the dial mechanism 161 thereat the two predetermined digits corresponding to the number assigned to the telegraph line 601, the selector switch 700 is automatically released. More particularly, the selector switch 700 operates, in the 65 previously described manner, in response to the

two predetermined digits dialed thereinto and at the conclusion of the second digit, the wiper set of the Strowger mechanism 680 engages a particular contact set in the associated contact bank. More particularly, the wipers 681 and 682 of the 5 wiper set engage the contacts in the associated contact bank which terminate no conductors; and the wiper 683 engages the contact in the associated contact bank terminating the conductor connected by way of the resistor 682 to the negative potential of battery. Accordingly, when the wiper set of the Strowger mechanism 680 engages this particular contact set in the associated contact bank, the previously traced path for short-circuiting the winding of the test relay R650 is 10 completed and shortly thereafter the control relay R660 restores to complete the previously traced circuit for energizing the lower winding of the switch-through relay R670, whereupon the latter relay operates in the previously described 15 manner. Upon operating, the switch-through relay R670 interrupts, at RA671 and at RA672 and RC673, points in the circuit including the telegraph line 501. When the last-mentioned 20 circuit is interrupted, the line relay R710 is de-energized and restores, thereby to cause the hold relay R720 to restore shortly thereafter. Upon restoring, the hold relay R720 completes, at 25 RA721 and RC722, the previously traced circuit for energizing the control relay R780, thereby to 30 cause the latter relay to operate and initiate the timing operation. The control relays R780 and R785 interact, in the previously described manner, thereby to cause the rotary magnet M783 to be repeatedly operated in order to drive the wiper 35 791 of the minor switch 790 step by step in the clockwise direction.

Also, it is noted that the set of switch springs S686 is associated with the level in the contact bank of the Strowger mechanism 680 included in the selector switch 700 wherein the previously mentioned contact set is disposed; and when the wiper set of the Strowger mechanism 680 is moved in the vertical direction to this corresponding level, the set of switch springs S686 is 40 actuated into engagement thereby to prepare a circuit, traced hereinafter, for energizing the release magnet M755.

When the wiper 791 of the minor switch 790 engages the contact in the associated contact bank 792 terminating the control conductor C711, the previously traced circuit for energizing the control relay R640 is completed, thereby to cause the latter relay to operate. Upon operating, the control relay R640 completes, at RA644, the previously mentioned circuit for energizing the release magnet M755, this circuit extending from the positive terminal of battery by way of the set of switch springs S686, RA644, C718, the set of switch springs S736 and the winding of M755 to 50 the negative terminal of battery. When energized over the above-traced circuit, the release magnet M755 operates to complete, at MA755, the previously traced holding circuit for energizing the winding thereof, thus causing the wiper set 55 of the Strowger mechanism 680 to be returned to its normal position. When the wiper set of the Strowger mechanism 680 is returned to its normal position, the sets of contact springs S761, S736 and S688 are actuated. More particularly, 60 the set of switch springs S736 is actuated into disengagement, thereby to interrupt the previously traced holding circuit for energizing the winding of the release magnet M755, thereby to cause the release magnet M755 to restore; and 65 70 75

the set of switch springs S688 is actuated into disengagement, thereby to interrupt the previously traced holding circuits for energizing the winding of the control relay R640 and the upper 5 winding of the switch-through relay R670 thereby to cause the latter relays to restore. Upon restoring, the switch-through relay R670 re-completes, at RA671 and at RA672 and RC673, points in the circuit including the telegraph line 10 501, thereby to cause the line relay R710 to re-operate. Upon reoperating, the line relay R710 causes the hold relay R720 to reoperate and interrupt, at RA721 and RC722, the previously traced circuit for energizing the control relay 15 R180, thereby to cause the latter relay to restore and arrest the timing operation. Also, upon re-operating, the hold relay R720 completes, at RA721 and RC723, the previously traced circuit for energizing the release magnet M794, thereby 20 to cause the minor switch 790 to be released. It is noted that the control relays R740 and R600 remain in their operated positions. While the control relay R600 remains in its operated position, positive battery potential is applied to the 25 control conductor C548 of the trunk line 545 extending from the multiple 540 into the selector switch 700, thereby to mark the selector switch 700 as busy to the selector switches 300 and 510 having access thereto.

30 When the two predetermined digits mentioned were transmitted over the telegraph line 501, the selector switch 700 included in the central switching station C operated and restored in the above-described manner; however, the selector switches 35 included in the other stations associated with the telegraph line 501 also operated, as previously explained. The selector switch included in one of the wayside stations associated with the telegraph line 501 may have operated to select the printing mechanism thereat, in the previously described manner. In this event, at this time, an established connection is completed between the central switching station C and the wayside station associated with the telegraph line 501.

40 Accordingly, it will be understood that the release arrangement described above permits the same number to be assigned to the terminal station X and to the particular wayside station associated with the telegraph line 501. When a 45 connection from the central switching station C to the particular wayside station is desired, the telegraph line 501 is utilized and the two digits comprising the predetermined number are dialed. On the other hand, when a connection from the 50 central switching station C to the terminal station X is desired, the telegraph line 502 is utilized and the two digits comprising the same predetermined number are dialed. From the foregoing description of the operation and release of the selector switch 700 when the telegraph line 501 is utilized in a connection and the two digits comprising the predetermined number are dialed, it will be understood that 55 when the telegraph line 102 is utilized in a connection and the two digits comprising the predetermined number are dialed, the selector switch 510 will be operated and released in a similar manner.

70 *Release of a selector switch operated by a surge on the associated telegraph line*

The timing arrangement incorporated in each of the selector switches constitutes an arrangement for releasing the associated selector switch 75 when the associated selector switch is operated

by a surge on the associated telegraph line. For example, a surge on the telegraph line 101, produced by lightning or the like will cause the repeater 100 to operate and repeat an impulse to the loop circuit 301, whereupon the line relay 5 R310 restores. Upon restoring, the line relay R310 completes, at RA311 and RC313, the previously traced circuit for energizing in series the control relay R330 and the vertical magnet M357, whereupon the vertical magnet M357 operates to 10 drive the wiper set of the Strowger mechanism 480 included in the selector switch 300 one step in the vertical direction; and the control relay R330 operates to complete, at RA331, the previously mentioned circuit for energizing the control relay R340. Also, when the wiper set of the Strowger mechanism 480 is moved away from its normal position, the set of contact springs S361, S336 and S488 are actuated in the previously 15 described manner.

Upon operating, the control relay R330 also completes, at RA335, the previously traced circuit for energizing the control relay R370, which latter relay operates to complete, at RA375, the previously traced holding circuit for energizing 25 the winding thereof. Upon operating, the control relays R340 and R370 complete, at RA343 and RC344 and at RA371 and RC373, respectively, the previously traced original circuit for energizing the control relay R380, thereby to cause the latter relay to operate and initiate the timing operation. The control relays R380 and R385 interact, in the previously described manner, in order to cause the rotary magnet M393 to be 30 repeatedly energized, thereby to drive the wiper 391 of the minor switch 390 step by step in the clockwise direction. When the wiper 391 engages the contact in the associated contact bank 392 terminating the control conductor C312, the previously traced circuit for energizing the control relay R420 is completed, thereby to cause the latter relay to operate. Upon operating, the control relay R420 completes, at RA423, the previously traced holding circuit for energizing the winding thereof, and interrupts, at RA421 and 45 RA422, points in the loop circuit 301, thereby to cause the line relay R310 to restore. Also, upon operating, the control relay R420 interrupts, at RA424 and at RA425, points in the previously traced holding circuit for energizing the 50 winding of the control relay R370, thereby to cause the latter relay to restore. Upon restoring, the control relay R370 interrupts, at RA371 and RC373, points in the previously traced circuit for energizing the control relay R380, thereby to cause the latter relay to restore and arrest the timing operation. Also, upon restoring, the control relay R370 completes, at RA371 and RC372, the previously traced circuit for energizing 55 the release magnet M394, thereby to cause the wiper 391 of the minor switch 390 to be released and returned to its normal position in the previously described manner.

Shortly after the line relay R310 restores, the hold relay R320 restores and completes, at RA321 65 and RC322, the previously traced alternative circuit for energizing the control relay R380, thereby to cause the latter relay to reoperate and initiate the timing operation. The control relays R380 and R385 interact, in the previously described manner, thereby to cause the wiper 391 of the minor switch 390 to be driven step by step in the clockwise direction. After a predetermined time interval the wiper 391 engages the contact in the associated contact bank termi- 70 75

nating the control conductor C313, whereupon the previously traced path for short-circuiting the winding of the control relay R340 is completed thereby to cause the latter relay to restore. Upon restoring, the control relay R340 completes, at RA343 and RC345, the previously traced circuit for energizing the release magnet M355, thereby to cause the wiper set of the Stronger mechanism 480 included in the selector switch 300 to be released and returned to its normal position. Also, upon restoring, the control relay R340 interrupts, at RA342, the previously traced holding circuit for energizing the winding of the control relay R420, thereby to cause the latter relay to restore. Upon restoring, the control relay R420 recomplete at RA421 and at RA422, the loop circuit 301, thereby to cause the line relay R310 to reoperate. Upon reoperating, the line relay R310 causes the hold relay R320 to reoperate. Upon reoperating, the hold relay R320 interrupts, at RA321 and RC322, the previously traced alternative circuit for energizing the control relay R380, thereby to cause the latter relay to restore and arrest the timing operation; and completes, at RA321 and RC323, the previously traced circuit for energizing the release magnet M394, thereby to cause the wiper 391 of the minor switch 390 to be released and returned to its normal position. At this time the selector switch 300 is completely released for further use.

Conclusions

From the foregoing it is apparent that a telegraph system is provided which incorporates an arrangement for rendering nonresponsive to dial impulses each of the selector switches in an established connection prior to the transmission of telegraphic impulses over the established connection. Also the telegraph system incorporates an arrangement for facilitating the extension of a connection in either direction from any telegraph line in a first group of telegraph lines to an idle telegraph line in a second group of telegraph lines. Furthermore, the telegraph system incorporates an improved arrangement for operatively associating a telegraph line having a potential of a given polarity impressed thereupon with any one of a number of other telegraph lines. While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a telegraph system, first and second and third telegraph lines having a station commonly associated therewith, first and second selector switches in said station, a trunk line extending between said selector switches, said first selector switch being provided with a wiper set having access to said trunk line and a control network operatively associated with said first telegraph line, whereby impulses transmitted over said first telegraph line are also transmitted over the control network of said first selector switch, said second selector switch being provided with a wiper set having access to said third telegraph line and a control network operatively associated with said second telegraph line, whereby impulses transmitted over the control network of said second selector switch are also transmitted over said second telegraph line, means included in said first

selector switch and responsive to predetermined series of impulses transmitted over the control network thereof for causing the wiper set of said first selector switch to seize said trunk line and operatively to associate said trunk line with the control network thereof, whereby subsequent impulses transmitted over the control network of said first selector switch are also transmitted over said trunk line, means included in said second selector switch and responsive to the seizure of said trunk line for operatively associating said trunk line with the control network of said second selector switch, whereby subsequent impulses transmitted over said trunk line are also transmitted over the control network of said second selector switch, and means included in said second selector switch and responsive to predetermined series of impulses transmitted over the control network thereof for causing the wiper set of said second selector switch to seize said third telegraph line and operatively to associate said third telegraph line with the control network thereof, whereby subsequent impulses transmitted over the control network of said second selector switch are also transmitted over said third telegraph line.

2. In a telegraph system, first and second and third telegraph lines having a station commonly associated therewith, first and second selector switches in said station, a trunk line extending between said selector switches, said first selector switch having access to said trunk line and provided with a control network operatively associated with said first telegraph line, whereby impulses transmitted over said first telegraph line are also transmitted over the control network of said first selector switch, said second selector switch having access to said third telegraph line and provided with a control network operatively associated with said second telegraph line, whereby impulses transmitted over the control network of said second selector switch are also transmitted over said second telegraph line, means included in said first selector switch and responsive to predetermined series of impulses transmitted over the control network thereof for causing said first selector switch to seize and operatively to associate said trunk line with the control network thereof, whereby subsequent impulses transmitted over the control network of said first selector switch are also transmitted over said trunk line, means included in said second selector switch and responsive to the seizure of said trunk line for operatively associating said trunk line with the control network of said second selector switch, whereby subsequent impulses transmitted over said trunk line are also transmitted over the control network of said second selector switch, and means included in said second selector switch and responsive to predetermined series of impulses transmitted over the control network thereof for causing said second selector switch to seize and operatively to associate said third telegraph line with the control network thereof, whereby subsequent impulses transmitted over the control network of said second selector switch are also transmitted over said third telegraph line.

3. In a telegraph system, first and second and third telegraph lines having a station commonly associated therewith, each of said telegraph lines being connected to a source of current, first and second selector switches in said station, a first trunk line extending between said selector switches, said first selector switch having access

- to said first trunk line and provided with a control network connected in series with a loop circuit, a local source of current normally connected to said loop circuit, means including a first repeater for operatively connecting said first telegraph line and said loop circuit, whereby impulses transmitted over said first telegraph line are repeated over said loop circuit, a second trunk line, said second selector switch having access to said second trunk line and provided with a control network connected in series with said second telegraph line, means included in said first selector switch and responsive to predetermined series of impulses transmitted over the control network thereof for disconnecting said local source of current from said loop circuit and for causing said first selector switch to seize said first trunk line and to connect said first trunk line in series with said loop circuit, means included in said second selector switch and responsive to the seizure of said first trunk line for causing said second selector switch to connect said first trunk line in series with the control network thereof, and means included in said second selector switch and responsive to predetermined series of impulses transmitted over the control network thereof for causing said second selector switch to seize said second trunk line and to connect said second trunk line in series with the control network thereof, and means including a second repeater for operatively connecting said second trunk line and said third telegraph line, whereby impulses transmitted over said second trunk line are repeated over said third telegraph line.
4. In a telegraph system, first and second telegraph lines having a station commonly associated therewith, first and second selector switches in said station, a trunk line extending between said selector switches, said first selector switch being provided with a wiper set having access to said trunk line and a control network operatively associated with said first telegraph line, whereby impulses transmitted over said first telegraph line are also transmitted over the control network of said first selector switch, said second selector switch being provided with a control network operatively associated with said second telegraph line, whereby impulses transmitted over the control network of said second selector switch are also transmitted over said second telegraph line, means included in said first selector switch and responsive to predetermined series of impulses transmitted over the control network thereof for causing the wiper set of said first selector switch to seize said trunk line and operatively to associate said trunk line with the control network thereof, whereby subsequent impulses transmitted over the control network of said first selector switch are also transmitted over said trunk line, and means included in said second selector switch, whereby subsequent impulses transmitted over said trunk line are also transmitted over the control network of said second selector switch.
5. In a telegraph system, first and second telegraph lines having a station commonly associated therewith, first and second selector switches in said station, a trunk line extending between said selector switches, said first selector switch having access to said trunk line and provided with a control network operatively associated with
- said first telegraph line, whereby impulses transmitted over said first telegraph line are also transmitted over the control network of said first selector switch, said second selector switch being provided with a control network operatively associated with said second telegraph line, whereby impulses transmitted over the control network of said second selector switch are also transmitted over said second telegraph line, means included in said first selector switch and responsive to predetermined series of impulses transmitted over the control network thereof for causing said first selector switch to seize and operatively to associate said trunk line with the control network thereof, whereby subsequent impulses transmitted over the control network of said first selector switch are also transmitted over said trunk line, and means included in said second selector switch and responsive to the seizure of said trunk line for causing said second selector switch to seize and operatively to associate said trunk line with the control network thereof, whereby subsequent impulses transmitted over the control network of said second selector switch are also transmitted over said trunk line, and means included in said first selector switch and responsive to the seizure of said trunk line for causing said first selector switch to seize and operatively to associate said trunk line with the control network thereof, whereby subsequent impulses transmitted over the control network of said first selector switch are also transmitted over said trunk line, and means included in said second selector switch and responsive to the seizure of said trunk line for causing said second selector switch to seize and operatively to associate said trunk line with the control network thereof, whereby subsequent impulses transmitted over the control network of said second selector switch are also transmitted over said trunk line.
6. In a telegraph system, first and second telegraph lines having a station commonly associated therewith, each of said telegraph lines being connected to a source of current, first and second selector switches in said station, a trunk line extending between said selector switches, said first selector switch having access to said trunk line and provided with a control network connected in series with a loop circuit, a local source of current normally connected to said loop circuit, means including a repeater for operatively connecting said first telegraph line and said loop circuit, whereby impulses transmitted over said first telegraph line are repeated over said loop circuit, said second selector switch being provided with a control network connected in series with said second telegraph line, means included in said first selector switch and responsive to predetermined series of impulses transmitted over the control network thereof for disconnecting said local source of current from said loop circuit and for causing said first selector switch to seize said trunk line and to connect said trunk line in series with said loop circuit, and means included in said second selector switch and responsive to the seizure of said trunk line for causing said second selector switch to connect said trunk line in series with the control network thereof.
7. In a telegraph system, first and second telegraph lines having a station commonly associated therewith, each of said telegraph lines being connected to a source of current, first and second selector switches in said station, a trunk line extending between said selector switches, said first selector switch having access to said trunk line and provided with a control network connected in series with said first telegraph line, said second selector switch being provided with a control network connected in series with a loop circuit, a local source of current normally connected to said loop circuit, means including a repeater for operatively connecting said loop circuit and said second telegraph line, whereby impulses transmitted over said loop circuit are repeated over said second telegraph line, means included in said first selector switch and responsive to predetermined series of impulses transmitted over the control network thereof for causing said first selector switch to seize said trunk line and to connect said trunk line in series with

- with the control network thereof, and means included in said second selector switch and responsive to the seizure of said trunk line for disconnecting said local source of current from said loop circuit and for causing said second selector switch to connect said trunk line in series with the control network thereof.
8. In a telegraph system, a telegraph line, a selector switch having a trunk line extending thereto, first telegraphic apparatus, said selector switch being provided with a wiper set having access to said first telegraphic apparatus and a control network operatively associated with said telegraph line, whereby impulses transmitted over the control network of said selector switch are also transmitted over said telegraph line, second telegraphic apparatus, means for transmitting impulses over said second telegraphic apparatus, means operatively associated with said second telegraphic apparatus and having access to said trunk line, said last-mentioned means being operative to seize said trunk line, whereby impulses transmitted over said second telegraphic apparatus are also transmitted over said trunk line, means included in said selector switch and responsive to the seizure of said trunk line for operatively associating said trunk line with the control network of said selector switch, whereby impulses transmitted over said trunk line are also transmitted over the control network of said selector switch, and means included in said selector switch and responsive to predetermined series of impulses transmitted over the control network thereof for causing the wiper set of said selector switch to seize said first telegraphic apparatus and operatively to associate said first telegraphic apparatus with the control network thereof, whereby subsequent impulses transmitted over the control network of said selector switch are also transmitted over said first telegraphic apparatus.
9. In a telegraph system, a telegraph line, a selector switch having a trunk line extending thereto, first telegraphic apparatus, said selector switch having access to said first telegraphic apparatus and provided with a control network operatively associated with said telegraph line, whereby impulses transmitted over the control network of said selector switch are also transmitted over said telegraph line, second telegraphic apparatus, means for transmitting impulses over said second telegraphic apparatus, means operatively associated with said second telegraphic apparatus and having access to said trunk line, said last-mentioned means being operative to seize said trunk line, whereby impulses transmitted over said second telegraphic apparatus are also transmitted over said trunk line, means included in said selector switch and responsive to the seizure of said trunk line for operatively associating said trunk line with the control network of said selector switch, whereby impulses transmitted over said trunk line are also transmitted over the control network of said selector switch, and means included in said selector switch and responsive to predetermined series of impulses transmitted over the control network thereof for causing said selector switch to seize said first telegraphic apparatus and operatively to associate said first telegraphic apparatus with the control network thereof, whereby subsequent impulses transmitted over the control network of said selector switch are also transmitted over said first telegraphic apparatus.
10. In a telegraph system, a telegraph line, a selector switch having a trunk line extending thereto, first telegraphic apparatus, said selector switch having access to said first telegraphic apparatus and provided with a control network connected in series with a loop circuit, a local source of current normally connected to said loop circuit, means including a repeater for operatively connecting said loop circuit and said telegraph line, whereby impulses transmitted over said loop circuit are repeated over said telegraph line, second telegraphic apparatus connected to a source of current, means for transmitting impulses over said second telegraphic apparatus, means operatively associated with said second telegraphic apparatus and having access to said trunk line, said last-mentioned means being operative to seize said trunk line and to connect said second telegraphic apparatus in series with said trunk line, means included in said selector switch and responsive to the seizure of said trunk line for disconnecting said local source of current from said loop circuit and for causing said selector switch to connect said trunk line in series with the control network of said selector switch, and means included in said selector switch and responsive to predetermined series of impulses transmitted over the control network thereof for causing said selector switch to seize said first telegraphic apparatus and to connect said first telegraphic apparatus in series with the control network of said selector switch.
11. In a telegraph system, a telegraph line connected to a source of current, a selector switch having a trunk line extending thereto, telegraphic apparatus, said selector switch having access to said telegraphic apparatus and provided with a control network connected in series with said telegraph line, a loop circuit normally connected to a local source of current, means for transmitting impulses over said loop circuit, means operatively associated with said loop circuit and having access to said trunk line, said last-mentioned means being operative to disconnect said local source of current from said loop circuit and to seize said trunk line and to connect said trunk line in series with said loop circuit, means included in said selector switch and responsive to the seizure of said trunk line for connecting said trunk line in series with the control network of said selector switch, and means included in said selector switch and responsive to predetermined series of impulses transmitted over the control network thereof for causing said selector switch to seize said telegraphic apparatus and to connect said telegraphic apparatus in series with the control network of said selector switch.
12. In a telegraph system, a first telegraph line, two stations having a plurality of second telegraph lines extending therebetween, a switching station commonly associated with said first telegraph line and each of said second telegraph lines, telegraphic apparatus in said switching station, a first selector switch and a plurality of second selector switches in said switching station, a plurality of trunk lines individually extending to said second selector switches, said first selector switch having access to each of said trunk lines and provided with a control network operatively associated with said first telegraph line, whereby impulses transmitted over said first telegraph line are also transmitted over the control network of said first selector switch, each of said second selector switches having access to said telegraphic apparatus and provided with a control network operatively associated with a

- corresponding one of said second telegraph lines, whereby impulses transmitted over the control network of one of said second selector switches are also transmitted over the corresponding one 5 of said second telegraph lines, means included in said first selector switch and responsive to predetermined series of impulses transmitted over the control network thereof for causing said first selector switch to operate automatically and seize 10 and operatively to associate one of said trunk lines extending to an idle one of said second selector switches with the control network of said first selector switch, whereby subsequent impulses transmitted over the control network of 15 said first selector switch are also transmitted over the last-mentioned trunk line, means included in each of said second selector switches and responsive to the seizure of the trunk line extending thereto for operatively associating the 20 last-mentioned trunk line with the control network of the second selector switch, whereby impulses transmitted over the last-mentioned trunk line are also transmitted over the control network of the second selector switch, and means 25 included in each of said second selector switches and responsive to predetermined series of impulses transmitted over the control network thereof for causing the second selector switch to seize and operatively to associate said telegraphic apparatus with the control network thereof, whereby subsequent impulses transmitted over the control network of the second selector switch are also transmitted over said telegraphic apparatus. 30
- 35 13. In a telegraph system, a first telegraph line, two stations having a plurality of second telegraph lines extending therebetween, a switching station commonly associated with said first and each of said second telegraph lines, a first selector switch and a plurality of second selector switches in said switching station, a plurality of trunk lines individually extending to said second selector switches, said first selector switch having access to each of said trunk lines and provided with a control network operatively associated with said first telegraph line, whereby impulses transmitted over said first telegraph line are also transmitted over the control network of said first selector switch, each of said second selector switches being provided with a control network operatively associated with a corresponding one of said second telegraph lines, whereby impulses transmitted over the control network of one of said second selector switches are also 40 transmitted over the corresponding one of said second telegraph lines, means included in said first selector switch and responsive to predetermined series of impulses transmitted over the control network thereof for causing said first selector switch to operate automatically and seize and operatively to associate one of said trunk lines extending to an idle one of said second selector switches with the control network of said first selector switch, whereby subsequent impulses transmitted over the control network of said first selector switch are also transmitted over the last-mentioned trunk line, and means included in each of said second selector switches and responsive to the seizure of the trunk line extending thereto for operatively associating the last-mentioned trunk line with the control network of the second selector switch, whereby subsequent impulses transmitted over the last-mentioned trunk line are also transmitted over the control network of the second selector switch. 45
- 50 14. In a telegraph system, two stations having a plurality of telegraph lines extending therebetween, a plurality of selector switches having a plurality of trunk lines individually extending thereto, first telegraphic apparatus, each of said selector switches having access to said first telegraphic apparatus and provided with a control network operatively associated with a corresponding one of said telegraph lines, whereby impulses transmitted over the control network of one of said selector switches are also transmitted over the corresponding one of said telegraph lines, second telegraphic apparatus, means for transmitting impulses over said second telegraphic apparatus, means operatively associated with said second telegraphic apparatus and having access to each of said trunk lines, said last-mentioned means being operative automatically to seize one of said trunk lines extending to an idle one of said selector switches, whereby impulses transmitted over said second telegraphic apparatus are also transmitted over the seized trunk line, means included in each of said selector switches and responsive to the seizure of the trunk line extending thereto for operatively associating the last-mentioned trunk line with the control network of the selector switch, whereby impulses transmitted over the last-mentioned trunk line are also transmitted over the control network of the selector switch, and means included in each of said selector switches and responsive to predetermined series of impulses transmitted over the control network thereof for causing the selector switch to seize said first telegraphic apparatus and operatively to associate said first telegraphic apparatus with the control network thereof, whereby subsequent impulses transmitted over the control network of the selector switch are also transmitted over said first telegraphic apparatus. 55
- 60 15. In a telegraph system, two stations having a first telegraph line extending therebetween, another two stations having a second telegraph line extending therebetween, a switching station commonly associated with said first and second telegraph lines, a first selector switch and a second selector switch in said switching station, a first trunk line extending to said first selector switch, a second trunk line extending to said second selector switch, said first selector switch having access to said second trunk line and provided with a control network operatively associated with said first telegraph line, whereby impulses are transmitted in either direction between the control network of said first selector switch and said first telegraph line, said second selector switch having access to said first trunk line and provided with a control network operatively associated with said second telegraph line, whereby impulses are transmitted in either direction between the control network of said second selector switch and said second telegraph line, means included in said first selector switch and responsive to predetermined series of impulses transmitted over the control network thereof for causing said first selector switch to operate and seize and operatively to associate said second trunk line with the control network of said first selector switch, whereby subsequent impulses transmitted over the control network of said first selector switch are also transmitted over said second trunk line, means included in said second selector switch and responsive to predetermined series of impulses transmitted over the control network thereof for causing said second selector 65
- 70 switch to operate and seize and operatively to associate said first trunk line with the control network of the second selector switch, whereby impulses transmitted over the last-mentioned trunk line are also transmitted over the control network of the second selector switch. 75

switch to operate and seize and operatively to associate said first trunk line with the control network of said second selector switch, whereby subsequent impulses transmitted over the control network of said second selector switch are also transmitted over said first trunk line, means included in said first selector switch and responsive to the seizure of said first trunk line for operatively associating said first trunk line with the control network of said first selector switch, whereby impulses transmitted over said first trunk line are also transmitted over the control network of said first selector switch, and means included in said second selector switch and responsive to the seizure of said second trunk line for operatively associating said second trunk line with the control network of said second selector switch, whereby impulses transmitted over said second trunk line are also transmitted over the control network of said second selector switch.

16. In a telegraph system, two stations having a first group of telegraph lines extending therebetween, another two stations having a second group of telegraph lines extending therebetween, a switching station commonly associated with said first and second groups of telegraph lines, a plurality of first and second selector switches in said switching station, a plurality of first trunk lines individually extending to said first selector switches, a plurality of second trunk lines individually extending to said second selector switches, each of said first selector switches having access to each of said second trunk lines and provided with a control network operatively associated with a corresponding one of the telegraph lines in said first group, whereby impulses are transmitted in either direction between the control network of the last-mentioned first selector switch and the last-mentioned telegraph line in said first group, each of said second selector switches having access to each of said first trunk lines and provided with a control network operatively associated with a corresponding one of the telegraph lines in said second group, whereby impulses are transmitted in either direction between the control network of the last-mentioned second selector switch and the last-mentioned telegraph line in said second group, means included in each of said first selector switches and responsive to predetermined series of impulses transmitted over the control network thereof for causing the first selector switch to operate automatically and seize and operatively to associate one of said second trunk lines extending to an idle one of said second selector switches with the control network of the last-mentioned first selector switch, whereby subsequent impulses transmitted over the control network of the last-mentioned first selector switch are also transmitted over the last-mentioned first trunk line, means included in each of said second selector switches and responsive to predetermined series of impulses transmitted over the control network thereof for causing the second selector switch to operate automatically and seize and operatively to associate one of said first trunk lines extending to an idle one of said first selector switches with the control network of the last-mentioned second selector switch, whereby subsequent impulses transmitted over the control network of the last-mentioned second selector switch are also transmitted over the last-mentioned first trunk line, means included in each of said first selector switches and responsive to the seizure of the first trunk line extend-

ing thereto for operatively associating the last-mentioned first trunk line with the control network of the last-mentioned first selector switch, whereby impulses transmitted over the last-mentioned first trunk line are also transmitted over the control network of the last-mentioned first selector switch, and means included in each of said second selector switches and responsive to the seizure of the second trunk line extending thereto for operatively associating the last-mentioned second trunk line with the control network of the second selector switch, whereby impulses transmitted over the last-mentioned second trunk line are also transmitted over the control network of the last-mentioned second selector switch.

17. In a telegraph system, two stations having a group of telegraph lines associated therewith, another station having a given telegraph line associated therewith, a number of selector switches in said stations individually associated with the telegraph lines at said stations, transmitting mechanism in each of said stations operative to transmit impulses over any one of the telegraph lines thereat, printing mechanism in each of said stations, means included in each of said selector switches and responsive to series of impulses transmitted over the telegraph line associated therewith for causing the selector switch to be selectively operated, means controlled by a particular operation of each of said selector switches for rendering operative by way of the associated telegraph line the printing mechanism in the associated station, a switching mechanism individually associated with said given telegraph line and having access to each of the telegraph lines in said group, and means included in said switching mechanism and responsive to particular series of impulses transmitted over said given telegraph line for causing said switching mechanism to operate automatically and select an idle telegraph line in said group, whereby subsequent impulses transmitted over said given telegraph line are also transmitted over the selected telegraph line in said group.

18. In a telegraph system, two stations having a group of telegraph lines associated therewith, another station having a given telegraph line associated therewith, a number of selector switches in said stations individually associated with the telegraph lines at said stations, transmitting mechanism in each of said stations operative to transmit impulses over any one of the telegraph lines thereat, printing mechanism in each of said stations, means included in each of said selector switches and responsive to series of impulses transmitted over the telegraph line associated therewith for causing the selector switch to be selectively operated, means controlled by a particular operation of each of said selector switches for rendering operative by way of the associated telegraph line the printing mechanism in the associated station, a switching mechanism individually associated with said given telegraph line and having access to each of the telegraph lines in said group, means included in said switching mechanism and responsive to particular series of impulses transmitted over said given telegraph line for causing said switching mechanism to operate automatically and search for an idle telegraph line in said group, means included in said switching mechanism and responsive to the failure of said switching mechanism to find an idle telegraph line in said group.

- for causing the selector switch to switch through and render operative by way of the associated telegraph line the printing mechanism in the associated station, normally effective means included in each of said selector switches and responsive to the transmission of an answer-back signal over the associated telegraph line for causing the selector switch to be released, means included in each of said selector switches and controlled when the selector switch is switched through for rendering said last-mentioned means ineffective, a switching mechanism individually associated with said given telegraph line and having access to each of the telegraph lines in said group, means included in said switching mechanism and responsive to particular series of impulses transmitted over said given telegraph line for causing said switching mechanism to operate automatically and search for an idle telegraph line in said group, means included in said switching mechanism and responsive to the finding thereby of an idle telegraph line in said group for causing said switching mechanism to operate and transmit an answer-back signal over said given telegraph line, a timer associated with said given telegraph line, means responsive to the transmission of an answer-back signal over said given telegraph line for initiating a timing operation of said timer, and means controlled upon the completion of the timing operation of said timer for causing said switching mechanism to switch through and select the found telegraph line in said group, whereby subsequent impulses transmitted over said given telegraph line are also transmitted over the selected telegraph line in said group.
23. In a telegraph system, two stations having a first group of telegraph lines associated therewith, another two stations having a second group of telegraph lines associated therewith, a number of selector switches in said stations individually associated with the telegraph lines at said stations, transmitting mechanism in each of said stations operative to transmit impulses over any one of the telegraph lines thereat, printing mechanism in each of said stations, means included in each of said selector switches and responsive to series of impulses transmitted over the telegraph line associated therewith for causing the selector switch to be selectively operated, means controlled by a particular operation of each of said selector switches for rendering operative by way of the associated telegraph line the printing mechanism in the associated station, a plurality of first switching mechanisms individually associated with the telegraph lines in said first group and having access to each of the telegraph lines in said second group, a plurality of second switching mechanisms individually associated with the telegraph lines in said second group and having access to each of the telegraph lines in said first group, and means included in each of said switching mechanisms and responsive to particular series of impulses transmitted over the associated telegraph line in one of said groups for causing the switching mechanism to operate automatically and select an idle telegraph line in the other of said groups, whereby subsequent impulses transmitted over the associated telegraph line in said one group are also transmitted over the selected telegraph line in said other group.
24. In a telegraph system, two stations having a group of telegraph lines associated therewith, another station having a given telegraph line associated therewith, a number of selector switches in said stations individually associated with the telegraph lines at said stations, transmitting mechanism in each of said stations operative to transmit impulses over any one of the telegraph lines thereat, printing mechanism in each of said stations, means included in each of said selector switches and responsive to series of impulses transmitted over the telegraph line associated therewith for causing the selector switch to be selectively operated, means controlled by a particular operation of each of said selector switches for rendering operative by way of the associated telegraph line the printing mechanism in the associated station, a switching office commonly associated with the telegraph lines in said group and said given telegraph line, a switching mechanism in said switching office individually associated with said given telegraph line and having access to each of the telegraph lines in said group, a group of printing mechanisms in said switching office, means included in said switching mechanism and responsive to series of impulses transmitted over said given telegraph line for causing said switching mechanism to operate automatically and select an idle printing mechanism in said group, whereby the selected printing mechanism in said group is rendered operative by way of said given telegraph line, and means controlled by a second particular operation of said switching mechanism for causing said switching mechanism to operate automatically and select an idle telegraph line in said group, whereby sub-

sequent impulses transmitted over said given telegraph line are also transmitted over the selected telegraph line in said group.

26. In a telegraph system, two stations having a first group of telegraph lines associated therewith, another two stations having a second group of telegraph lines associated therewith, a number of selector switches in said stations individually associated with the telegraph lines at said stations, transmitting mechanism in each of said stations operative to transmit impulses over any one of the telegraph lines thereat, printing mechanism in each of said stations, means included in each of said selector switches and responsive to series of impulses transmitted over the telegraph line associated therewith for causing the selector switch to be selectively operated, means controlled by a particular operation of each of said selector switches for rendering operative by way of the associated telegraph line the printing mechanism in the associated station, a switching office commonly associated with the telegraph lines in said first and second groups, a plurality of first switching mechanisms in said switching office individually associated with the telegraph lines in said first group and having access to each of the telegraph lines in said second group, a plurality of second switching mechanisms in said switching office individually associated with the telegraph lines in said second group and having access to each of the telegraph lines in said first group, a group of printing mechanisms in said switching office, means included in each of said switching mechanisms and responsive to series of impulses transmitted over the associated telegraph line for causing the switching mechanism to be selectively operated, means controlled by a first particular operation of each of said switching mechanisms for causing the switching mechanism to operate automatically and select an idle printing mechanism in said group, whereby the selected printing mechanism in said group is rendered operative by way of the telegraph line associated with the switching mechanism, and means controlled by a second particular operation of each of said switching mechanisms associated with a telegraph line in one of said groups for causing the switching mechanism to operate automatically and select an idle telegraph line in the other of said groups, whereby subsequent impulses transmitted over the associated telegraph line in said one group are also transmitted over the selected telegraph line in said other group.
27. In a telegraph system, a telegraph line having a station associated therewith, a selector switch in said station having a loop circuit extending thereto, a local source of current connected to said loop circuit, means including a repeater provided with a control network associated with said telegraph line and said loop circuit for repeating impulses transmitted over said telegraph line to said loop circuit, a printing mechanism in said station having a control circuit, means included in said selector switch and responsive to series of impulses repeated over said loop circuit for causing said selector switch to be selectively operated, and means included in said selector switch and responsive to a particular operation thereof for connecting the control circuit of said printing mechanism in said loop circuit, thereby to render said printing mechanism operative in response to subsequent impulses repeated over said loop circuit.
28. In a telegraph system, a telegraph line having a station associated therewith, a selector switch in said station having a loop circuit extending thereto, a local source of current connected to said loop circuit, means including a repeater provided with a control network associated with said telegraph line and said loop circuit for repeating impulses transmitted over said telegraph line to said loop circuit, a printing mechanism in said station having a control circuit, said selector switch having a carriage carrying a wiper set, means included in said selector switch and responsive to series of impulses for causing the carriage of said selector switch to be selectively moved, said selector switch being so connected and arranged that the wiper set thereof selects the control circuit of said printing mechanism when the carriage of said selector switch is moved to a particular position, and means included in said selector switch and responsive to the movement of the carriage thereof to said particular position for connecting said loop circuit to the wiper set of said selector switch, thereby to complete an alternative circuit including in series circuit relationship said local source of current, said loop circuit, the control circuit of said printing mechanism and the wiper set of said selector switch, whereupon said printing mechanism is rendered operative in response to subsequent impulses repeated over said loop circuit.
29. In a telegraph system, a telegraph line having a station associated therewith, a selector switch in said station having a loop circuit extending thereto, a local source of current connected to said loop circuit, means including a repeater provided with a control network associated with said telegraph line and said loop circuit for repeating impulses in either direction between said telegraph line and said loop circuit, a printing mechanism in said station having a control circuit, means included in said selector switch and responsive to series of impulses repeated over said loop circuit for causing said selector switch to be selectively operated, means included in said selector switch and responsive to a particular operation thereof for causing said selector switch to test the idle or busy condition of the control circuit of said printing mechanism, means included in said selector switch and controlled in the event the control circuit of said printing mechanism is tested busy for transmitting a particular series of impulses comprising a busy signal over the loop circuit, whereby said repeater repeats the series of impulses over said telegraph line.
30. In a telegraph system, a telegraph line having a station associated therewith, a selector switch in said station having a loop circuit extending thereto, a local source of current connected to said loop circuit, means including a repeater provided with a control network associated with said telegraph line and said loop circuit for repeating impulses in either direction between said telegraph line and said loop circuit, a printing mechanism in said station having a control circuit, means included in said selector switch and responsive to series of impulses repeated over said loop circuit for causing said selector switch to be selectively operated, means included in said selector switch and responsive to a particular operation thereof for causing said selector switch to test the idle or busy condition of the control circuit of said printing mechanism, and means included in said selector switch

- and controlled in the event the control circuit of said printing mechanism is tested idle for transmitting a particular impulse comprising an answer-back signal over said loop circuit, where-
 5 by said repeater repeats the particular impulse over said telegraph line, and for connecting the control circuit of said printing mechanism in said loop circuit, thereby to render said printing mechanism operative in response to subsequent
 10 impulses repeated over said loop circuit.
31. In a telegraph system, a telegraph line connected to a source of current and having a plurality of stations associated therewith, a selector switch in one of said stations connected in said telegraph line, a selector switch in another of said stations connected in a loop circuit extending thereto, a local source of current connected to said loop circuit, means including a repeater provided with a control network associated with
 15 said telegraph line and said loop circuit for repeating impulses in either direction between said telegraph line and said loop circuit, a transmitting mechanism operative to transmit impulses over said telegraph line, a printing mechanism in
 20 said one station, a printing mechanism in said other station having a control circuit, means included in each of said selector switches and responsive to series of impulses transmitted thereto for causing the selector switch to be selectively operated, means controlled by a particular operation of each of said selector switches for causing the selector switch to switch through, means controlled when said selector switch in said one station switches through for transmitting an
 25 answer-back signal over said telegraph line and for rendering the printing mechanism in the associated station operative over said telegraph line, means controlled when said selector switch in said other station switches through for transmitting an answer-back signal over said loop circuit and for connecting the control circuit of the printing mechanism in the associated station in said loop circuit, thereby to render said last-mentioned printing mechanism operative over
 30 said loop circuit, normally effective means included in each of said selector switches and responsive to the interruption of the circuit in which the selector switch is connected a predetermined time interval for causing the selector switch to be released, and means included in each of said selector switches and controlled when the selector switch switches through for rendering the last-mentioned means in the selector switch ineffective.
32. In a telegraph system, a first telegraph line having a station associated therewith, a second telegraph line having a potential of a given polarity impressed thereupon and extending to said station, a selector switch in said station having a loop circuit extending thereto, a local source of current normally connected to said loop circuit, means including a repeater provided with a control network associated with said first telegraph line and said loop circuit for repeating impulses transmitted over said first telegraph line to said loop circuit, means included in said selector switch and responsive to series of impulses repeated over said loop circuit for causing said selector switch to be selectively operated, means included in said selector switch and responsive to a particular operation thereof for disconnecting said local source of current from said loop circuit and for completing an alternative circuit including in series said second telegraph line and said loop circuit, whereby subsequent impulses repeated over said loop circuit are transmitted over said second telegraph line.
33. In a telegraph system, a first telegraph line having a station associated therewith, a second telegraph line having one end upon which there is impressed a potential of a given polarity and another end terminating at said station, a selector switch in said station having a loop circuit extending thereto, a local source of current normally connected to said loop circuit, means including a repeater provided with a control network associated with said first telegraph line and said loop circuit for repeating impulses transmitted over said first telegraph line to said loop circuit, said selector switch having a carriage carrying a wiper set, means included in said selector switch and responsive to series of impulses for causing the carriage of said selector switch to be selectively moved, said selector switch being so connected and arranged that when the carriage thereof is moved to a particular position one

of the wipers in the wiper set thereof selects said second telegraph line and another of the wipers in the wiper set thereof selects a conductor having a potential impressed thereon which is of 5 a polarity opposite to that impressed upon said second telegraph line, and means included in said selector switch and responsive to the movement of the carriage thereof to said particular position for disconnecting said local source of current from said loop circuit and for connecting said loop circuit to the wiper set of said selector switch, thereby to complete an alternative circuit including in series circuit relationship said conductor having a potential of one polarity impressed thereon, the wiper set of said selector switch, said loop circuit and said second telegraph line having a potential of the opposite polarity impressed thereon, whereupon subsequent impulses repeated over said loop circuit are transmitted over said second telegraph line. 10 15 20

35. In a telegraph system, a first telegraph line having a station associated therewith, a second telegraph line having a potential of a given polarity impressed thereupon and extending to 25 said station, a selector switch in said station having a loop circuit extending thereto, a local source of current normally connected to said loop circuit, means including a repeater provided with a control network associated with said first 30 telegraph line and said loop circuit for repeating impulses transmitted over said first telegraph line to said loop circuit, a printing mechanism in said station having a control circuit, means included in said selector switch and responsive to a first particular operation thereof for connecting the control circuit of said 35 printing mechanism in said loop circuit, thereby to render said printing mechanism operative in response to subsequent impulses repeated over said loop circuit, means included in said selector switch and responsive to a second particular 40 operation thereof for disconnecting said local source of current from said loop circuit and for completing an alternative circuit including a series 45 said second telegraph line and said loop circuit, whereby subsequent impulses repeated 50 over said loop circuit are transmitted over said second telegraph line.

36. In a telegraph system, a first telegraph line connected to a source of current and having one station and another station associated therewith, 55 a second telegraph line having a potential of a given polarity impressed thereupon and extending to said other station, a selector switch in said one station connected in said first telegraph line, a selector switch in said other station connected 60 in a loop circuit extending thereto, a local source of current normally connected to said loop circuit, means including a repeater provided with a control network associated with said first telegraph line and said loop circuit for repeating 65 impulses in either direction between said first telegraph line and said loop circuit, a transmitting mechanism operative to transmit impulses over said first telegraph line, a printing mechanism in said one station, means included in each 70 of said selector switches and responsive to series of impulses transmitted thereto for causing the selector switch to be selectively operated, means controlled by a particular operation of each of said selector switches for causing the selector switch to switch through, means controlled 75

when said selector switch in said one station switches through for transmitting an answer-back signal over said first telegraph line and for rendering the printing mechanism in the associated station operative over said first telegraph line, means controlled when said selector switch in said other station switches through for transmitting an answer-back signal over said loop circuit and then for disconnecting said local source of current from said loop circuit and for completing an alternative circuit including in series said second telegraph line and said loop circuit, whereby subsequent impulses repeated over said loop circuit are transmitted over said second telegraph line, normally effective means included in each of said selector switches and responsive to the transmission of an answer-back signal thereto for causing the selector switch to be released, and means included in each of said selector switches and controlled when the selector switch switches through for rendering said last-mentioned means ineffective. 10 15 20

37. In a telegraph system, a telegraph line connected to a source of current and having a plurality of stations associated therewith, a selector switch in each of said stations associated with said telegraph line, a printing mechanism in each of said stations, a transmitting mechanism operative to transmit impulses over said telegraph line, means included in each of said selector switches and responsive to series of impulses transmitted over said telegraph line for causing the selector switch to be selectively operated, means controlled by a first particular operation of each of said selector switches for causing the selector switch to switch through and render the printing mechanism in the associated station operative in response to subsequent impulses transmitted over said telegraph line, means controlled by a second particular operation of each of said selector switches for causing the selector switch to switch through without rendering the printing mechanism in the associated station operative, normally effective means included in each of said selector switches and responsive to the transmission of an answer-back signal over said telegraph line for causing the selector switch to be released, and means included in each of said selector switches and controlled when the selector switch switches through for rendering ineffective the last-mentioned means in the selector switch and for transmitting an answer-back signal over said telegraph line. 30 35 40 45 50 55

38. In a telegraph system, a telegraph line connected to a source of current and having a plurality of stations associated therewith, a selector switch in each of said stations associated with said telegraph line, a printing mechanism in each of said stations, a transmitting mechanism operative to transmit impulses over said telegraph line, normally effective impulse responsive means included in each of said selector switches and controlled by impulses transmitted over said telegraph line for causing the selector switch to be selectively operated, said impulse responsive means being so connected and arranged that said selector switches are normally operative correspondingly in response to series of impulses transmitted over said telegraph line, means controlled by a first particular operation of each of said selector switches for causing the selector switch to switch through and render the printing mechanism in the associated station operative in response to subsequent impulses trans- 60 65 70 75

- mitted over said telegraph line, means controlled by a second particular operation of each of said selector switches for causing the selector switch to switch through without rendering the printing mechanism in the associated station operative, normally effective release means included in each of said selector switches and controlled by the transmission of an answer-back signal over said telegraph line for causing the selector switch to be released, and means included in each of said selector switches and controlled when the selector switch switches through for rendering ineffective the impulse responsive means and the release means in the selector switch and for transmitting an answer-back signal over said telegraph line.
39. In a telegraph system, a telegraph line connected to a source of current and having a plurality of stations associated therewith, a selector switch in each of said stations associated with said telegraph line, a printing mechanism in each of said stations, a transmitting mechanism operative to transmit impulses over said telegraph line, normally effective impulse responsive means included in each of said selector switches and controlled by impulses transmitted over said telegraph line for causing the selector switch to be selectively operated, said impulse responsive means being so connected and arranged that said selector switches are normally operative correspondingly in response to series of impulses transmitted over said telegraph line, means controlled by a first particular operation of each of said selector switches for causing the selector switch to switch through and render the printing mechanism in the associated station operative in response to subsequent impulses transmitted over said telegraph line, means controlled by a second particular operation of each of said selector switches for causing the selector switch to switch through without rendering the printing mechanism in the associated station operative, normally effective release means included in each of said selector switches and controlled by the transmission of an answer-back pulse or a release pulse over said telegraph line for causing the selector switch to be released, means included in each of said selector switches and controlled when the selector switch switches through for rendering ineffective the impulse responsive means and the release means in the selector switch and for transmitting an answer-back pulse over said telegraph line, a release device operative to transmit a release pulse over said telegraph line, and means included in each of said selector switches and controlled by the transmission of a release pulse over said telegraph line for again rendering effective the release means in the selector switch.
40. In a telegraph system, a telegraph line connected to a source of current and having a plurality of stations associated therewith, a multi-position selector switch in each of said stations associated with said telegraph line, a printing mechanism having a printing line in each of said stations, a connecting strap in each of said stations, a transmitting mechanism operative to transmit impulses over said telegraph line, means included in each of said selector switches and responsive to series of impulses transmitted over said telegraph line for causing the selector switch to be selectively operated to the different positions thereof, said impulse responsive means being so connected and arranged that said selector switches are operative to corresponding positions in response to series of impulses transmitted over said telegraph line, each of said selector switches being operative to a first particular position to seize the printing line in the associated station and to a second particular position to seize the connecting strap in the associated station, the first particular positions of said selector switches being non-corresponding positions thereof and the second particular positions of said selector switches being corresponding positions thereof, means included in each of said selector switches and responsive to the operation thereof to its first particular position for causing the selector switch to switch through, thereby to connect the printing line of the printing mechanism in the associated station in said telegraph line, means included in each of said selector switches and responsive to the operation thereof to its second particular position for causing the selector switch to switch through, thereby to connect the connecting strap in the associated station in said telegraph line, normally effective means included in each of said selector switches and responsive to the transmission of an answer-back signal over said telegraph line for causing the selector switch to be released, and means included in each of said selector switches and controlled when the selector switch switches through for rendering ineffective the last-mentioned means in the selector switch and for transmitting an answer-back signal over said telegraph line.
41. In a telegraph system, a telegraph line connected to a source of current and having a plurality of stations associated therewith, a multi-position selector switch in each of said stations associated with said telegraph line, a printing mechanism in each of said stations, a connecting strap in each of said stations, a transmitting mechanism operative to transmit impulses over said telegraph line, means included in each of said selector switches and responsive to series of impulses transmitted over said telegraph line for causing the selector switch to be selectively operated to the different positions thereof, said impulse responsive means being so connected and arranged that said selector switches are operative to corresponding positions in response to series of impulses transmitted over said telegraph line, each of said selector switches being operative to a first particular position to control the operation of the printing mechanism in the associated station and to a second particular position to seize the connecting strap in the associated station, the first particular positions of said selector switches being non-corresponding positions thereof and the second particular positions of said selector switches being corresponding positions thereof, means included in each of said selector switches and responsive to the operation thereof to its first particular position for causing the selector switch to switch through, thereby to render the printing mechanism in the associated station operative in response to subsequent impulses transmitted over said telegraph line, means included in each of said selector switches and responsive to the operation thereof to its second particular position for causing the selector switch to switch through, thereby to connect the connecting strap in the associated station in said telegraph line, normally effective means included in each of said selector switches and responsive to the transmission of an answer-back signal over said telegraph line for causing the selector switch to be released, and means included in each of said selector switches and controlled when the selector switch switches through for rendering ineffective the last-mentioned means in the selector switch and for transmitting an answer-back signal over said telegraph line.

stations associated with said telegraph line, a printing mechanism in each of said stations, a transmitting mechanism operative to transmit impulses over said telegraph line, means included in each of said selector switches and responsive to series of impulses transmitted over said telegraph line for causing the selector switch to be selectively operated to the different positions thereof, said impulse responsive means being so connected and arranged that said selector switches are operated to corresponding positions in response to given series of impulses transmitted over said telegraph line, each of said selector switches being operative to a first particular position, at least one of said selector switches being operative to a second particular position, the particular positions of said selector switches being non-corresponding positions thereof, means included in each of said selector switches and responsive to the operation thereof to its first particular position for causing the selector switch to switch through, thereby to render the printing mechanism in the associated station operative in response to subsequent impulses transmitted over said telegraph line, normally effective means included in each of said selector switches and responsive to the transmission of an answer-back signal over said telegraph line for causing the selector switch to be released, means included in each of said selector switches and controlled when the selector switch switches through for rendering ineffective the last-mentioned means in the selector switch and for transmitting an answer-back signal over said telegraph line, additional means included in said one selector switch and operative to cause the selector switch to be released, and means included in said one selector switch and responsive to the operation thereof to the second particular position thereof for operating said last-mentioned means in the selector switch and for

transmitting an answer-back signal over said telegraph line.

46. In a telegraph system, a telegraph line having a plurality of stations associated therewith, a printing mechanism in each of said stations, a transmitting mechanism operative to transmit impulses over said telegraph line, normally effective impulse responsive means included in each of said selector switches for causing the selector switch to be selectively operated to the different positions thereof, said impulse responsive means being so connected and arranged that said selector switches are normally operative to corresponding positions in response to series of impulses transmitted over said telegraph line, each of said selector switches being operative to first and second particular positions, the first particular positions of said selector switches being non-corresponding positions thereof and the second particular positions of said selector switches being corresponding positions thereof, means responsive to the operation of each of said selector switches to its first particular position for causing the selector switch to switch through and render operative the printing mechanism in the associated station, means responsive to the operation of each of said selector switches to its second particular position for causing the selector switch to switch through without rendering operative the printing mechanism in the associated station, means for transmitting a signal over said telegraph line, normally effective signal responsive means included in each of said selector switches for causing the selector switch to be released, and means included in each of said selector switches and controlled when the selector switch switches through for rendering ineffective the impulse responsive means and the signal responsive means in the selector switch. 40
